UNITED STATES PATENT OFFICE

2,273,139

TELEPHONE SYSTEM

Seth E. Peterson, Chicago, Ill., and Irvin Geitgey, Elyria, Ohio, assignors to Associated Electric Laboratories, Inc., Chicago, Ill., a corporation of Delaware

Application July 20, 1940, Serial No. 346,592

84 Claims. (Cl. 179—27)

The present invention relates to telephone systems and has for one of its objects the provision of improved switching apparatus of the character utilized in setting up and supervising connections extending between the substations served by different exchanges of a multi-exchange network.

In a system of this character, inter-exchange calls are routed over toll lines and trunks interconnecting the exchanges, and the line switching operations which are required in routing the calls to the desired substations are either performed manually at switchboards of the manual type or are effected on a semi-automatic basis through the provision of toll and local switching equipment of the automatic type which is controllable from the various operators' positions. In handling calls of this character, the connections are usually routed through at least one and frequently three or more operators' positions in tandem, the different operators' positions being located in different exchanges, and it is necessary to provide facilities whereby supervisory signals may be dispatched to the proper operator's position or operators' positions in response to call answering, connection release and operator recall operations performed at the calling and called substation. In setting up toll connections, the use of voice current amplifiers for increasing the voice current transmission level at appropriate points along the toll lines is frequently necessary. In the usual arrangement, wherein a call routed over one of the toll lines to a central exchange may be terminated locally at a substation served by the central exchange or extended over an inter-office trunk to a substation served by an exchange distant from the central exchange, the transmission level is increased by the amplifiers associated with the toll line in use by an amount sufficient to compensate for the loss introduced by the presence of an inter-office trunk in the established connection. This, of course, means that the voice current gain over the toll line in use is in excess of that required if the connection is to be terminated locally at the central exchange. Accordingly, loss pad networks are usually provided in the toll line terminating circuits which include loss resistors that may selectively be switched in and out of the voice current channels to control the voice current transmission level. In the usual arrangement this is accomplished manually by key operations performed at one of the operators' positions

through which the toll line connections are routed.

It is an object of the present invention to provide in a system of the character described, improved facilities whereby the supervision of calls routed by way of one or more tandem connected operators' positions may be accomplished in a simple and reliable manner with a minimum of equipment in the switching apparatus through which the calls are extended.

It is another object of the invention to provide in a system of the character described, which utilizes automatic toll switching apparatus for extending connections from the toll lines, an improved arrangement whereby the voice current transmission level of the toll lines is selectively and automatically controlled in accordance with the character of the lines to which connections are extended from the toll lines.

It is another object of the invention to provide in a system of the character described, improved toll switching apparatus which is so connected and arranged that the same relay equipment may be utilized for both supervisory and pad control purposes in setting up and supervising toll calls, thus minimizing the amount of equipment required to effect these separate and distinct ends.

It is another object of the invention to provide in a system of the character described, improved toll switching apparatus which is so connected and arranged that the selective control of the transmission level control pads is automatically accomplished in a simple and reliable manner without any supervision or thought on the part of the toll operators.

It is another object of the invention to provide in a system of the character described, an arrangement whereby a supervisory operation performed by the operator attending one of a plurality of tandem connected operators' positions causes a supervisory signal of one character to be transmitted over the connection to the operator attending a second of the tandem connected positions and a supervisory signal of different character to be transmitted over the connection to a third of the tandem connected operators' positions.

It is still another object of the invention to provide for use in a system of the character described, an improved operator's trunk or access circuit which is so connected and arranged that after a connection has been routed thereto

through associated impulse controlled automatic switching equipment, any further impulse digits transmitted over the connection are utilized solely for the purpose of controlling the line signal lamp embodied therein.

It is a further object of the invention to provide in a system of the character described, improved automatic switching apparatus which comprises toll switching selectors and access or trunk circuits and which is so connected and arranged that the same control path extending between a selector and an access circuit occupied with a call may be utilized for the purpose of controlling the transmission of call signals over the trunk associated with the access circuit, and also for the purpose of transmitting supervisory signals over the trunk incoming to the selectors, thus minimizing the amount of equipment required for these purposes in the selectors and access circuits.

It is a further object of the invention to provide in improved automatic switching apparatus of the character just described, an arrangement whereby the duration of the signals transmitted over the trunks associated with the access circuits are controlled by timing equipment provided in the preceding selectors.

It is a further object of the invention to provide in a system of the character described, improved automatic switching apparatus including selector switches of the voice current repeating type which have access to succeeding switching units arranged for both loop circuit and simplex circuit control over their incoming trunks, and which is so arranged that the voice current repeating elements of the selector switches are only excluded from talking channels established through these switches when the channels are extended through succeeding switching units arranged for simplex circuit control.

It is a still further object of the invention to provide for use in a system of the character described, improved automatic switching apparatus which is so arranged that the setting of the control equipment embodied in at least one of the selectors is arranged to be controlled by a digit counting device which is provided in a succeeding switching unit, such, for example, as a succeeding impulse repeater.

It is still another object of the invention to provide in a system of the character described, an arrangement wherein calls routed to certain lines or substations of the system are intercepted and routed to an intercepting operator's position, and wherein facilities are provided for transmitting to the intercepting operator's position signals which identify calls routed thereto from calling toll or trunk lines, and signals are also transmitted over the calling toll or trunk lines for the purpose of informing the calling operators that the calls have been intercepted.

It is a still further object of the invention to provide for use in conjunction with automatic toll switching equipment of the character described, improved alarm signaling equipment which is so arranged that the condition of a large number of switching units may be closely supervised and accurately indicated with a minimum of circuit apparatus.

In the illustrated embodiment of the system, there is provided a central exchange which is connected by means of one-way, voice current repeatered toll lines with a distant toll point and by means of different groups of inter-office trunks with a plurality of remotely located

smaller exchanges. The switching equipment of the central exchange includes a switchboard at which are provided the usual inward toll, C. L. R., delayed call, information and intercepting operators' positions. Toll calls handled at this

switchboard are routed to the operators' positions and extended therefrom through automatic toll switching apparatus of the well-known Strowger type. This apparatus includes toll transmission selectors, toll switching selectors and appropriate operators' access circuits and trunk circuits, and is so arranged that in setting up connections routed from the toll switching point to the central exchange, the central exchange is utilized in certain instances as a tandem exchange, the assistance of the operators attending the switchboard in the central exchange not being required. In one case wherein the central exchange is utilized as a tandem exchange, a connection may be extended from a calling toll line through a toll transmission selector of the impulse repeating type, a toll second selector, a repeater and additional automatic switching equipment to the desired line terminating at the distant exchange. In setting up a toll connection of this type, the control equipment of the toll transmission selector is held in its impulse repeating setting until all of the digits designating the desired line have been dialed at the calling operator's position located at the toll switching point. For the purpose of switching this control equipment to its ringing setting after the dialing operation is completed, there is provided in the succeeding repeater a digit counting device which functions, after a predetermined number of digits have been transmitted to the repeater, to transmit a signal back to the toll transmission selector indicating that the dialing operation is ended, whereupon the control equipment of this selector is automatically switched to its ringing or called line signaling setting. After this setting is attained, the control equipment of the toll transmission selector is selectively controlled by the back-bridge relay of the succeeding repeater, so that it is changed from its ringing setting to its call answered setting, or vice versa, each time the switchhook provided at the called substation is operated between its two operating positions. Provisions are also made in the selector for transmitting an appropriate supervisory signal over the calling toll line each time the setting of the control equipment is changed from one of the two last-mentioned settings to the other.

In another instance where the central exchange is used as a tandem exchange between the toll switching point and another distant exchange, a connection is routed from the calling toll line through a toll transmission selector and a toll switching selector of the central exchange to an access circuit associated with a ring-down trunk extending to the distant exchange. In accordance with another feature of the present invention, the control equipment of the toll switching selector and the succeeding access circuit is so arranged that a single control path may be utilized for controlling the application of ringing voltage to the ring-down trunk and for the purpose of controlling the transmission of supervisory signals over the calling end of the connection to the toll switching point. Further, in accordance with the invention, the period during which ringing voltage is applied to the ring-down trunk is controlled through the provision of a timing switch in the toll switching

selector of the train, and provisions are made whereby ringing signals may be transmitted over the ring-down trunk and flashing recall signals may be transmitted to the calling operator at the toll switching point. All of these supervisory operations are achieved through the operation of relay equipment which is controlled over the single control path extending between the toll switching selector and the access circuit of the switch train.

Calls originating at the toll switching point may also be routed over the toll lines to the various operators' positions in the central exchange, these operators' positions having associated therewith appropriate trunk or access circuits which are accessible to the toll switching selectors. In accordance with another feature of the invention, provisions are made in these access circuits whereby impulse digits transmitted thereto after the seizure thereof are absorbed, thus permitting a more universal directory numbering scheme to be used. The arrangement of the digit absorbing relay equipment is such that this equipment also functions to control the incoming call signal lamps of the associated operators' position circuits.

In accordance with another feature of the invention, the access circuits which are provided in association with the delay operators' positions of the central exchange switchboard are arranged to pass supervisory signals to the distant toll switching point. These access circuits are also arranged for the selective control of the toll pad switching relays in accordance with the character of the lines to which calls are extended from the delay operator's position. The arrangement of the relay equipment embodied in these circuits is such that a single control path, which is independent of the talking or communication channel of a connection, may be utilized for both pad switching control and supervisory control purposes. These circuits are also so arranged that when connections are extended therefrom to inter-office trunks of the ring-down variety requiring the use of alternating current supervisory signals, splashes of ringing current transmitted thereto over the extended portions of the ring-down trunk connections cause the production of supervisory signals of one character, namely, steady signals, at the delay operator's position, and supervisory signals of a different character, namely, intermittent signals of the flashing recall type, at the distant toll switching point.

Further features of the invention pertain to the particular arrangement of the toll switching apparatus and its associated alarm equipment, whereby the above-outlined and additional objects are achieved.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figure 1 illustrates the general arrangement of a telephone system embodying the present invention; Figs. 2 to 13, inclusive, taken together, illustrate the details of a system having incorporated therein the features of the invention as briefly outlined above; and Fig. 14 illustrates the mode of combining Figs. 2 to 13, inclusive, to form a unified system.

GENERAL DESCRIPTION OF THE SYSTEM

Referring now more particularly to Fig. 1 of the drawings, the telephone system there illustrated comprises a central exchange 20, a remote exchange or toll switching point 30, a distant exchange 40, a distant exchange 10, a C. A. X 50 and a C. A. X 60. The remote exchange 30, the distant exchange 40 and the distant exchange 10 may be of any well-known type; each serving a number of subscriber substations, not shown; while the central exchange 20, the C. A. X 50 and the C. A. X 60 are of the automatic type, each serving a number of subscriber substations. More particularly, the central exchange 20 serves a number of subscriber substations including the subscriber substations T1 and T4; the C. A. X 50 serves a number of subscriber substations including the subscriber substation T2; and the C. A. X 60 serves a number of subscriber substations including the subscriber substation T3. The remote exchange 30 and the central exchange 20 are interconnected by a group of one-way toll lines, each of which is equipped with voice current repeaters or amplifiers. Thus the toll line 440, which terminates in the central exchange 20 in a toll line circuit 442, is equipped with a number of voice current repeaters 440a which function in a well-known manner to raise the voice current level at appropriately spaced points along the length of the line 440. The central exchange 20 is also connected with the distant exchanges 40 and 10 by means of groups of one-way trunks, which respectively include the trunks 1105 and 1141. Further the central exchange 20 is connected with the C. A. X 50 by means of a group of two-way trunk lines, including the trunk line 405, and with the C. A. X 60 by means of a group of two-way trunk lines, including the trunk line 415.

The remote and distant exchanges 30, 40 and 10 respectively comprise toll operator positions 441, 1160 and 1142; while the central exchange 20 comprises an automatic dial switchboard 1150 which includes a plurality of operators' positions including an intercepting operator's position 1151, a toll operator's position 1152, an information operator's position 1153 and a delay operator's position 1154. As indicated above, each toll line in the group of toll lines extending from the remote exchange 30 to the central exchange 20 terminates at the operator's position 441 in the remote exchange 30 and in a toll line circuit in the central exchange 20. Similarly, each trunk in the group of trunks extending from the central exchange 20 to the distant exchange 40 terminates in a trunk circuit in the central exchange 20 and at the operator's position 1160 in the distant exchange 40, the trunk 1105 terminating in the trunk circuit 1101 and at the operator's position 1160. Also each trunk in the group of trunks extending between the C. A. X 50 and the central exchange 20 terminates in automatic switching equipment 403 provided in the C. A. X 50 and in a trunk circuit in the central exchange 20, the trunk 405 terminating in the trunk circuit 404. Each trunk in the group of trunks extending between the C. A. X 60 and the central exchange 20 similarly terminates in automatic switching equipment 413 provided in the C. A. X 60 and in a trunk circuit in the central exchange 20, the trunk 415 terminating in the trunk circuit 414.

Each of the subscriber lines extending to the central exchange 20 terminates in a line circuit

individually thereto, the line 691 terminating in the line circuit 692 and the line serving the substation T4 terminating in a similar circuit. It is noted that the subscriber lines terminating in the C. A. X 50 have access to and are accessible to the automatic switching equipment 403, and the subscriber lines terminating in the C. A. X 60 have access to and are accessible to the automatic switching equipment 413. Also the subscriber lines in the central exchange 20 have access to and are accessible to local switching equipment, not shown, but forming a part of the automatic switching apparatus, provided in the central exchange 20.

The central exchange 20 is provided with a toll switching equipment which comprises the sets of toll switching apparatus 420, 430 and 1140; a group of toll transmission selectors, including the toll transmission selector 300; a group of toll second selectors, including the toll second selector 676; a group of toll switching selectors, including the toll switching selector 700; a group of toll incoming selectors, including the toll incoming selector 460; and a group of toll connectors, including the toll connector 681. Further the toll switch train comprises a first group of repeaters, including the repeater 600, individually associated with the toll incoming selectors; a second group of repeaters, including the repeater 686, associated with the automatic switches having access to the trunks extending to the C. A. X 60; a first group of access circuits, including the access circuit 800, associated with the trunks extending to the distant exchange 40; a second group of access circuits, including the access circuit 900, associated with the information operator's position 1153; a delay operator's position circuit 1130 associated with the delay operator's position 1154; and a third group of access circuits, including the access circuit 1000, associated with the delay operator's position 1154. The switching equipment provided in the central exchange 20 further comprises a call intercepting circuit 693 which is associated with certain of the subscriber lines terminating at the central exchange 20 and functions to forward calls routed to these lines to the intercepting operator's position 1151. Alarm equipment 200 is also provided in the central exchange 20 for the purpose of testing and indicating the condition of the associated line switching and auxiliary equipment.

Preferably, the automatic switching equipment 403 provided in the C. A. X 50, the automatic switching equipment 413 provided in the C. A. X 60, and the local automatic switching equipment of the central exchange 20, are of the well-known Strowger type although this equipment may be connected and arranged in any convenient manner. The toll switching equipment provided in the central exchange in association with the operators' positions at the switchboard 1150 and including the sets of switching apparatus 420, 430 and 1140, may also be of any desired arrangement although preferably this equipment is also of the well-known Strowger type. The toll second selector 676 and the toll connector 681, together with the other switches of similar character, may be of the general character disclosed in Patent No. 1,736,041, Tharp et al., granted December 23, 1930. Also, the operator's position equipment provided at the toll operator's position 1150 and at the intercepting operator's position 1151, and the call intercepting circuit 693, may be of substantially conventional design and arrange-

ment. The repeater 686, the trunk circuit 404, the trunk circuit 414, the trunk circuit 1101 and the other corresponding repeaters and trunk circuits forming a part of the central exchange switching apparatus may also be of conventional design and arrangement.

The manner in which calls completed locally through the automatic switching apparatus provided in the C. A. X 50, the C. A. X 60 and the central exchange 20, forms no part of the present invention and, accordingly, an explanation of the details of this apparatus is deemed to be unnecessary. For the same reason, the manner in which toll calls initiated on the lines terminating at the central exchange 20 and routed through the local and toll switching apparatus of the exchange to one of the toll operator's positions are handled, and the manner in which calls are transferred through the toll switching apparatus between the various operators' positions provided in the switchboard 1150, are not disclosed herein since it is believed that the novel features of the system may readily be understood without a detailed explanation of the entire system arrangement. It is noted, however, that the in and out trunks indicated as extending to the toll switching units 420, 430 and 1140 are utilized in setting up connections between the toll operators' positions and the lines terminated locally in the central exchange 20.

The toll line circuits provided in the central exchange 20 to terminate the toll lines extending to the remote exchange 30 are of identical arrangement. The toll line circuit 442 is illustrated in Fig. 13 of the drawings as comprising a voice current repeating coil 1360, a line or pulsing relay R1300, a retard coil 1304, a supervisory relay R1310 and associated signal lamp 1314, a slow-to-release hold relay R1320, a series control relay R1340, a second control relay R1350 which is a slave to the hold relay R1320, a line balancing coil 1358 and a transmission pad network 1370. This network includes loss resistors which are preferably connected and arranged in the manner disclosed in Fig. 2 of Patent No. 2,167,710, Crocker, granted August 1, 1939, and a pad switching relay which is arranged to be controlled over the control lead C1309 by a pad control relay R1330. As indicated above, the purpose of this network is to determine the voice current transmission level of a communication channel established through the toll line circuit 442. More specifically, the pad network is provided for a two-fold purpose. One function of this network is to introduce a definite loss in the communication channel when the toll line 440 is connected through the switching equipment of the central exchange 20 to a subscriber line terminating at this exchange. On the other hand, when the toll line 440 is connected through the switching equipment of the central exchange to an inter-office trunk, the loss resistors of the network are excluded from the communication channel, whereby the transmission level is enhanced to compensate for the loss occasioned by the presence of the inter-office trunk in the connection. The second function of this network is to introduce a circuit loss which tends to balance the artificial line network at the repeater 440a nearest the central exchange regardless of the transmission characteristics of the line to which a connection is extended from the toll line 440. The manner in which the pad switching relay embodied in the network 1370 is automatically controlled in accordance with the terminating

point of a connection extended to the toll line 440, is pointed out with particularity hereinafter.

The toll transmission selectors provided in the central exchange 20 are of the impulse and voice current repeating type and are identical in arrangement. Thus, the toll transmission selector 300 is illustrated in Figs. 3 and 5 of the drawings as comprising a voice current repeating element 310 and a switching mechanism 510 of the well-known Strowger type. Briefly described, this mechanism includes a wiper set which is provided with four wipers 511, 512, 513 and 514, capable of both vertical and rotary movements, and an associated contact bank including ten horizontal levels of contact sets. The switching mechanism 510 further comprises a vertical magnet 520 for moving the wiper set in a vertical direction, a rotary magnet 521 for moving the wiper set in a rotary direction, and a release magnet 523 for releasing the wiper set so that it may be returned to rotary and vertical normal. The switching mechanism 510 is also provided with a number of auxiliary switch springs which include the vertical off-normal springs 390, the normal post springs 395 and 396, and the 11th step cam or off-normal springs 397 and 525. These various sets of contact springs are controlled in accordance with the vertical and rotary movements of the wipers 511 to 514, inclusive, in a manner more fully described hereinafter. The control equipment of the toll transmission selector 300 comprises a ballast lamp 317 of the double filament type and a group of control relays. More specifically, the relay equipment of the selector includes a switch-through or simplex relay R320, an answer or back-bridge relay R330, a switch-through or ring position relay R340, a combined battery supply and back-bridge relay R350, a tone relay R355, a loop circuit control relay R360, a slow-to-operate control relay R370, a slow-to-release ring start relay R530, a line or impulsive relay R535, a supervisory relay R540, a slow-to-release hold relay R545, a line switching relay R550, a transfer relay R560 of the slow-to-release type, and an automatic cut-in or stepping relay R570. The manner in which the enumerated relays are connected and arranged is more fully described in the following portion of the specification wherein the details of operation of the selector 300 are explained.

Preferably each of the toll switching selectors provided in the central exchange 20 is identical in arrangement with the toll switching selector 700, illustrated in Fig. 7 of the drawings. Briefly described, this selector comprises a switching mechanism 710 which is identical in construction and arrangement with the switching mechanism 510 of the toll transmission selector 300, and comprises a set of wipers 711 to 714, inclusive, a vertical magnet 715, a rotary magnet 718, a release magnet 720 and auxiliary control switch springs including the normal post springs 725, the vertical off-normal springs 722, 723 and 724, and the 11th step cam or off-normal springs 728. The control equipment of this selector comprises a timing switch 740 of the well-known minor type, a line balancing coil 704 and a group of control relays. More specifically, the relay equipment of the selector 700 includes a line or impulsive relay R760, a slow-acting hold relay R765, a slow-acting transfer relay R770, an automatic cut-in or stepping relay R780, a combined line test and line switching relay R750, a ringing control relay R790, a timer start relay R795, a timer

reset relay R720 and a supervisory or recall relay R785.

The repeaters utilized in forwarding connections from the toll transmission selectors to the 5 automatic switching equipment 403 provided in the C. A. X 50 are identical in arrangement with the repeater 600. This repeater is illustrated in Fig. 6 of the drawings as comprising a voice current repeating coil 610, a digit counting device in the form of a minor switch 620, and a plurality of control relays. These relays include a line or impulsive relay R650, a slow-to-operate hold relay R640, a slow-acting digit counting relay R630, a line switching relay R660 and a back-bridge relay 10 R655 of the electro-polarized type.

The access circuits associated with the inter-office trunks connecting the central exchange 20 with the distant exchange 40 are of the character 20 illustrated in Fig. 8 of the drawings. Briefly described, this access circuit includes a voice current repeating coil 810, a simplex controlled line relay R840, a slow-acting cut-off relay R850, an alternating current recall relay R860, a ringing control relay R870 and a line switching relay 25 R880.

The access circuit 900 and associated operator's position equipment provided in association 30 with the information operator's position 1153 are illustrated in Figs. 9 and 12 of the drawings. Briefly described, this apparatus includes a voice current repeating coil 910, a combined talk and hold key 1211 of the locking type, a trunk busy lamp 1207, an answer lamp 1206, an incoming call buzzer 1203, an operator's telephone set 1210, a battery feed coil 1205 and a group of control 35 relays. These relays include a simplex controlled line relay R960, a hold relay R970, a digit absorbing relay R980, a ring-back or supervisory relay R965, a slow-to-operate line switching relay R990, a slow-acting supervisory control relay R930, a signal control relay R1200 and a night transfer relay R950. If desired, two keys may be used in lieu of the single key 1211, these two keys being utilized for talk and hold functions, respectively.

The details of the access circuit 1000 and associated delay operator's position equipment are 40 partially illustrated in Figs. 10 and 11 of the drawings as comprising a voice current repeating coil 1010, operator's position equipment 1196, a combined monitor and talk key 1180 of the locking type, a release key 1191 of the non-locking type, a trunk busy lamp 1195, a line lamp 1193, a supervisory lamp 1194 and a group of control 45 relays. This group of relays includes a simplex controlled line relay R1055, a slow-to-operate hold relay R1070, a digit absorbing relay R1080, a disconnect relay R1090, a ring-back relay R1040, a pair of slow-acting supervisory relays R1065 and R1045, the last of which is of the differentially wound type, a slow-acting differentially wound pad switching control relay R1050, a line seizure relay R1060, a night transfer relay R1030, a split relay R1110, an answer relay R1120, a supervisory relay R1135, a line switching relay R1170 and a pair of additional control relays R1125 and R1130. The manner in which the various enumerated relays are connected and arranged is more fully explained subsequently with reference to the operation of the circuit 1000 and its associated position equipment.

The alarm equipment which is associated with the various switching units briefly described above, is shown in Fig. 2 of the drawings as com-

prising a timing switch 260 of the well-known minor type, a plurality of alarm leads C231, C232, etc., a plurality of alarm signal lamps 213, 214, etc., individually associated with the alarm leads, a plurality of alarm relays R220, R225, etc., also individually associated with the alarm leads, and a group of auxiliary control relays R210, R240 and R250. This equipment also includes an interrupter 237 of the motor-driven type for transmitting timing pulses to the minor switch 260, a normally energized signal lamp 235, an alarm signal bell 236, and a reset key 238.

CALL TO CENTRAL EXCHANGE 20 FROM THE REMOTE EXCHANGE 30

Referring now more particularly to the operation of the system to set up different types of connections, a call originating on a line terminating at the remote exchange 30 and intended for a line terminating at the central exchange 20 will first be considered. Assuming that the call is routed to the operator's position 441 in the remote exchange 30, the operator attending this position may forward the call to the central exchange by seizing one of the central exchange trunks, such, for example, as the trunk 440. When this trunk is seized, negative battery potential is impressed upon the two conductors thereof. The line relay R1300 of the toll line circuit 442 is thus energized. More specifically, the two lower windings of this relay are energized over a circuit which extends from ground through the resistor 1302, the two series connected lower windings of R1300 and the two repeating coil windings 1361 and 1362 in parallel to battery as impressed upon the two sides of the trunk 440. The intermediate windings of the relay R1300 is further energized over a circuit which extends from ground by way of the contacts 1312, the winding of the retard coil 1304, the intermediate winding of R1300 and the two repeating coil windings 1361 and 1362 in parallel to battery as impressed upon the two sides of the trunk 440. It will be observed that the upper winding of the line relay R1300 is normally energized over a circuit including the resistor 1303. Accordingly, this relay is exceedingly sensitive to changes in the energization of its two lower windings. When these two windings are energized over the circuits traced above, the relay R1300 operates to complete, at its contacts 1301, a circuit for energizing the relay R1340 in series with the winding of the line or pulsing relay R535 embodied in the toll transmission selector 300. One branch of this circuit extends from ground by way of the contacts 1301, the winding of R1340, the resistor 1356, the upper winding of the line balancing coil 1358, C451, the contacts 321, the repeating coil winding 311, the resistors 301, 303 and 304, C382, the winding of R535 and the contacts 524 to battery. The other branch of this circuit extends from ground by way of the contacts 1301, the winding of R1340, the resistor 1357, the lower winding of the balancing coil 1358, C452, the contacts 323, the repeating coil winding 312, the resistors 302, 303 and 304, C382, the winding of R535 and the contacts 524 to battery. When energized over this simplex circuit, the relay R1340 operates to complete, at its contacts 1341, an obvious circuit for energizing the slow-to-release hold relay R1320. The relay R1320, in operating, closes its contacts 1321 and 1322 to connect the line terminals of the repeating coil windings 1363 and 1364 through the pad circuit 1370 to the

taking conductors C451 and C452 of the trunk 450 incoming to the toll transmission selector 300. At its contacts 1323, the relay R1320 connects the absorbing network comprising the condenser 1306 and the resistor 1307 in shunt with the winding of the series relay R1340. At its contacts 1324, the relay R1320 completes an obvious circuit for energizing the relay R1350.

The relay R1350, upon operating, closes its contacts 1351 to complete an obvious path for impressing ground potential upon the control conductor C453 of the trunk 450. At its contacts 1354, the relay R1350 completes a path including the contacts 1331 for impressing ground potential upon the pad switching relay control lead C1309, thereby to short-circuit the pad switching relay conventionally embodied in the pad circuit 1370. At its contacts 1355, the relay R1350 opens a point in the normally completed path for impressing negative battery potential upon the indicated pad switching relay control lead. Thus, the relay R1350, in operating, de-energizes the pad switching relay of the circuit 1370 so that the resistance pad of this circuit is rendered effective. In this regard it is pointed out above that the usual vacuum tube repeating equipment is provided at appropriately spaced intervals along the trunk 440 for increasing the voice current transmission level in both directions in order to maintain satisfactory voice current transmission over this trunk. In accordance with conventional practice, the terminating pad embodied in the circuit 1370 is of the resistive type and is associated with the repeating coil 1360 for the purpose of controlling the transmission level over connections including the trunk 440. Thus, if a call routed over this trunk is to be extended through the central exchange 20 to a distant exchange, more amplification, i. e., a higher voice current transmission level, is required than if the call is to be terminated locally at a substation served by the switching equipment of the central exchange. On a call of the first type, therefore, it is desirable to render the resistance pad ineffective by controlling the pad switching relay of the network 1370 to exclude the resistance pad from the voice current transmission channel. On the other hand, if the call is to be terminated locally at the central exchange 20, an adequate transmission level is maintained if the pad is retained in the voice current channel.

In order to provide for the selective control of the pad switching relay embodied in the network 1370, the pad control relay R1330 is provided. It will be noted that when the relay R1350 operates in the manner explained above, the winding of the pad control relay R1330 is bridged through the contacts 1352 and 1353 across the series connected resistors 1356 and 1357. Thus, the winding of the relay R1330 is, in effect, connected across opposite terminals of a resistance bridge, two arms of which comprise the resistors 1356 and 1357, respectively. The third arm of the bridge includes the upper winding of the balancing coil 1358, the trunk conductor C451, the contacts 321, the repeating coil winding 311, the resistor 301 and the upper half of the resistor 303. The fourth arm of the bridge similarly comprises the lower winding of the balancing coil 1358, the trunk conductor C452, the contacts 323, the repeating coil winding 312, the resistor 302 and the lower half of the resistor 303. With this wiring arrangement, the pad control relay R1330 is only energized when the

bridge is unbalanced to produce a difference of potential between the end terminals of the resistors 1356 and 1357. In the present case, the resistance values of the circuit elements included in the two branches of the above-traced simplex circuit are so proportioned that the bridge is balanced and no potential difference is produced across the winding of the pad control relay R1330. The relay R1330 is thus prevented from operating. If it is desired to operate the pad control relay in response to seizure of the toll transmission selector 300, the upper terminal of the resistor 304 may be disconnected from the center tap of the resistor 303 and connected to the upper terminal of the resistor 303. In such case, the voltage drop between the positive trunk conductor C452 and the upper terminal of the resistor 303, resulting from ground current over the above-traced simplex circuit is greater than the voltage drop between the trunk conductor C451 and the upper terminal of the resistor 303. Accordingly, the bridge is unbalanced and a difference of potential is produced across the winding of the pad control relay R1330, causing this relay to operate. In operating, the relay R1330 opens its contacts 1331 to interrupt the above-traced path for grounding the pad switching control lead C1309. At its contacts 1332, the relay R1330 completes a path including the resistor 1308 and the contacts 1354 for impressing negative battery potential upon the control lead C1309, thereby to energize the pad switching relay embodied in the circuit 1370. As a consequence of the switching operation performed by the latter relay, the resistance pad of this network is excluded from the voice current transmission channel connecting the inter-office trunk 440 with the trunk 450.

When energized over the above-traced simplex circuit, the line relay R535 of the toll transmission selector 300 operates and, at its contacts 538, opens a point in the circuit for energizing the release magnet 523. At its contacts 537, the relay R535 completes an obvious circuit for energizing the slow-to-release hold relay R545. At its contacts 536, the relay R535 prepares a circuit for repeating impulses over the line wipers 511 and 512 of the switching mechanism 510 to the trunk extending to a succeeding numerical switch.

The hold relay R545, upon operating, opens its contacts 548, thereby further to interrupt the circuit for energizing the release magnet 523, and prepares, at its contacts 547, a circuit for energizing the transfer relay R560 in parallel with the vertical magnet 520. At its contacts 546, the relay R545 completes a path including the contacts 541 for impressing ground potential upon the alarm conductor C231. The purpose of the arrangement for grounding the alarm conductor C231 when the toll transmission selector 300 is seized is described with particularity hereinafter. Following the operation of the line and hold relays R535 and R545, respectively, the selector 300 is conditioned to respond to the impulses comprising the first digit of the directory number designating the desired operator in the central office, or the desired subscriber line terminating at the central office.

During the operation of the impulse sending device provided at the toll operator's position 441 in the remote exchange 30 and utilized to transmit impulses over the trunk 440, the line relay R1300 functions to repeat the impulses over the established simplex circuit to the line relay R535. Accordingly, the latter relay is caused to

follow the impulses transmitted over the trunk 440 from the toll operator's position 441. This relay, upon restoring at the beginning of the open-circuit period of the first impulse, opens its contacts 537 to interrupt the operating circuit for the hold relay R545. The latter relay, due to its slow-to-release characteristic, remains operated during impulsion. At its contacts 538, the relay R535 completes the above-mentioned circuit for energizing the transfer relay R560 and the vertical magnet 520 in parallel. One branch of this circuit extends from ground by way of the contacts 538 and 547, and the winding of R560 to battery. The other branch of this circuit extends from ground by way of the contacts 538, 547 and 556, and the winding of the magnet 520 to battery. The relay R560, upon operating, closes its contacts 561 to complete a path including the resistor 504 and the two conductors C377 and C379 in shunt with the upper winding of the control relay R370. At its contacts 563, the relay R560 opens a point in the operating circuit for the rotary magnet 521. At its contacts 562, the relay R560 completes an obvious path for short-circuiting the winding of the line switching relay R550. Due to its slow-to-release characteristic, the transfer relay R560 remains operated during the impulses of the first digit transmitted to the toll transmission selector 300.

The vertical magnet 520 operates to elevate the wipers 511 to 514, inclusive, one step in the vertical direction each time the line relay R535 restores to complete its operating circuit as traced above. When these wipers are moved off normal, the vertical off-normal springs 391, 392 and 393 are respectively operated into engagement. At the contact springs 392, the circuit for energizing the release magnet 523 is prepared. At the contacts 393, a circuit is prepared for energizing the stepping relay R570. At the contacts 391, a circuit including the conductor C388 is completed for energizing the supervisory relay R540. The relay R540, upon operating, completes a multiple path including the contacts 546 and 542 for impressing ground potential upon the control conductor C453. At its contacts 542, the relay R540 also completes the prepared operating circuit for the stepping relay R570, this circuit extending from ground by way of the contacts 546, 542, 555 and 562, the winding of R570, C388, the off-normal springs 393, the conductor C384 and the contacts 524 to battery. At its contacts 541, the relay R540 opens the above-traced path for impressing ground potential upon the alarm conductor C231. At its contacts 543, the relay R540 prepares a path for grounding the supervisory lead C505.

The stepping relay R570 operates when energized in the manner explained above and, in operating, locks to ground over a path including the contacts 522 and 571. At its contacts 572, the relay R570 prepares the operating circuit for the rotary magnet 521. Following the operations just described, the wipers 511 to 514, inclusive, are elevated step by step under the control of the vertical magnet 520, so that at the conclusion of the digit they are positioned opposite the level of bank contacts terminating the group of trunks which correspond to the numerical value of the digit. In this regard it will be understood that the numerical value of the digit determines the path which the call will take.

Extending the call to a central office subscriber substation

Assuming that the call under consideration is intended for the substation T1 served by the central office switching equipment, the first digit transmitted to the toll transmission selector 300 from the toll operator's position 441 will comprise the number of impulses designating the group of toll second selectors in which the selector 676 is included. Accordingly, at the end of the digit the wipers 511 to 514, inclusive, are left standing opposite the level of bank contacts terminating the group of trunks including the trunk 675.

At the end of the first digit, the line relay R535 is held energized over its simplex operating circuit. With this relay operated, the circuit for energizing the transfer relay R560 and the vertical magnet 520 in parallel is held open at the contacts 538. Accordingly, the transfer relay R560 is caused to release shortly following the end of the digit. Upon restoring, this relay opens its contacts 561 to interrupt the above-described path shunting the upper winding of the relay R370. At its contacts 562, the relay R560 opens a point in the previously traced operating circuit for the stepping relay R570. At its contacts 563, the relay R560 completes the prepared operating circuit for the rotary magnet 521, this circuit extending from ground by way of the contacts 546, 542, 555, 563 and 572, and the winding of the magnet 521 to battery. When thus energized, the rotary magnet 521 operates to rotate the wipers 511 to 514, inclusive, into engagement with the contacts terminating the conductors of the first trunk in the selected group. At its contacts 522, the magnet 521 opens the above-traced locking circuit for the relay R570. The relay R570, upon restoring, opens its contacts 572 to interrupt the above-traced operating circuit for the rotary magnet 521. At its contacts 571, the relay R570 opens a further point in its locking circuit. The operations which occur following the first rotary step of the switch wipers depend upon the condition of the trunk terminated at the contacts engaged by these wipers at the end of this step. Thus, if the first trunk of the selected group is busy, ground potential is present upon the control or private conductor thereof and, accordingly, an alternative circuit is completed for energizing the stepping relay R570. This alternative circuit extends by way of the grounded private or control wiper 513, the contacts 554 and 522, the winding of R570, C388, the contacts 393, C384 and the contacts 524 to battery. When energized over the above-traced alternative circuit, the relay R570 again operates and locks to ground through the contacts 522 and 571. At its contacts 572, the relay R570 again completes the operating circuit for the rotary magnet 521. When reenergized in this manner, the rotary magnet 521 operates to advance the wipers 511 to 514, inclusive, a second step in the rotary direction, so that the bank contacts terminating the conductors of the second trunk in the selected group are engaged thereby. In operating, the magnet 521 also interrupts the locking circuit for the stepping relay R570, causing the latter relay to restore. If the second trunk is also busy, the stepping relay R570 is again energized over a circuit including the grounded private or control wiper 513, with the result that the rotary magnet 521 is again energized to advance the wipers of the switching mechanism 510 a third

step. The interrelated operation of the magnet 521 and the stepping relay R570 continues until the wipers 511 to 514, inclusive, have been driven into engagement with the contacts terminating an idle trunk of the selected group, or until all of the trunks of this group have been tested and found to be in a busy condition. During the rotary movement of the switch wipers the relay R550 is short-circuited over a path including the grounded wiper 513 and the contacts 554, 546 and 542.

Assuming that all of the trunks of the selected group are busy at the time the call under consideration is initiated, the wipers of the switching mechanism 510 are operated through eleven steps in the rotary direction. In response to the eleventh step of these wipers, the off-normal springs 525 of the switching mechanism 510 are disengaged to open a point in the common portion of the operating circuits for the relays R320 and R370, and the off-normal springs 397 are operated into engagement to complete a circuit including the pulsing lead C308 for energizing the tone relay R355. In this regard it is pointed out that the lead C308 is connected to a continuous operating pulsing device which functions to impress ground pulses upon this lead at the rate of 120 pulses per minute. The tone relay R355 accordingly operates at a corresponding rate and functions intermittently to close its contacts 358 so that ground pulses are impressed upon the supervisory pulse lead C454 intermittently to energize the supervisory relay R1310. These pulses are repeated by the relay R1310 as negative battery pulses which are impressed upon the two sides of the trunk 440 over a path including the filament of the lamp 1314, the winding of the retard coil 1304, the intermediate winding of the relay R1300 and the two repeating coil windings 1361 and 1362. A supervisory relay associated with the trunk 440 and provided in the trunk circuit terminating this trunk in the remote exchange 30 is energized by the negative battery pulses applied to the two sides of the trunk and responds by operating to transmit current pulses to the supervisory signal device provided at the position 441 of the operator handling the call in the remote exchange 30. The resulting flashing of this signal device serves to inform the operator that an all-trunks-busy condition exists at the first switching stage of the connection. Each time the supervisory relay R1310 operates it functions to open its contacts 1312 and thus interrupt the above-traced circuit for energizing the intermediate winding of the relay R1300. At its contacts 1311, the relay R1310 completes an obvious multiple circuit for energizing the lower winding of the relay R1300. With the latter circuit completed the relay R1300 is prevented from releasing until the operator handling the call at the position 441 releases the connection.

When the wiper 513 is operated to its eleventh rotary off-normal position in the manner explained above, it is disconnected from ground so that no circuit is thereafter available for energizing the stepping relay R570. Accordingly, the stepping operation of the wipers 511 to 514, inclusive, is arrested. When the wiper 513 is disconnected from ground, the above-traced path short-circuiting the switching relay R550 during the rotary movement of the selector switch wipers is broken, permitting the winding of this relay to be energized in series with the relay

R570 over a circuit which extends from ground by way of the contacts 546 and 542, the winding of R550, the contacts 522, the winding of R570, C388, the contacts 393, C384 and the contacts 524 to battery. Due to the relatively high resistance of the winding of R550, the relay R570 is insufficiently energized to operate when this circuit is completed. The relay R550, however, operates and closes its contacts 551 and 552 to connect the link line conductors C374 and C380 to the line wipers 511 and 512 of the switching mechanism 510. At its contacts 553, the relay R550 completes a path including the contacts 546 and 542 for impressing ground potential upon the control or private wiper 513. At its contacts 554, the relay R550 opens a further point in the path for short-circuiting its winding during the rotary movement of the switch wipers. At its contacts 556, the relay R550 opens a further point in the previously traced operating circuit for the vertical magnet 528. At its contacts 557, the relay R550 prepares a point in the common portion of the operating circuits for the two relays R320 and R370. At its contacts 558, the relay R550 completes a path for impressing ground potential upon the extra control wiper 514. Following the operations just described, no further operation of the control equipment embodied in the toll transmission selector 300 occurs until the partially established connection is released at the operator's position 441 in the remote exchange 30. The manner in which this selector is restored to normal when the connection is released is explained in detail hereinafter.

Assuming that the toll second selector 676 is idle at the time the above-described trunk-hunting operation of the toll transmission selector 300 is initiated, operation of the wipers 511 to 514, inclusive, is arrested when these wipers are moved into engagement with the contacts terminating the conductors of the trunk 675. More specifically, the private or control conductor of this trunk is not marked with ground potential when the associated second selector 676 is idle. Accordingly, when the wiper 513 engages the contact terminating this conductor, no further circuit is available for energizing the stepping relay R570, with the result that this relay remains in its restored position and the rotary movement of the wipers 511 to 514, inclusive, is arrested. Also, the path short-circuiting the winding of the relay R550 during rotary movement of the wipers 511 to 514, inclusive, is interrupted when the wiper 513 engages the contact terminating the control conductor of the trunk 675. The relay R550 is thus energized over its operating circuit as traced above, and operates to complete, at its contacts 553, the previously traced path for impressing ground potential upon the wiper 513. At its contacts 551 and 552, the relay R550 connects the link line conductors C374 and C380 to the line wipers 511 and 512. At its contacts 558, the relay R550 completes the above-mentioned path for impressing ground potential upon the extra control wiper 514, this path extending from ground by way of the contacts 532, C502, the contacts 327, C501 and the contacts 558 to the wiper 514. At its contacts 557, the relay R550 completes a circuit for energizing the lower winding of the slow-to-release relay R370. In this regard it is pointed out that the selector 300 has access to trunks arranged for both loop and simplex operation. In the case under consideration, the selected group of toll second selectors, of which

the selector 676 forms a part, are arranged for loop operation. The toll switching selector 700, on the other hand, and the other corresponding selectors of the system, are arranged for simplex operation. In order to accommodate the two different arrangements just described, the normal post spring combination comprising the contact springs 395 and 396 is provided, the arrangement of the switching mechanism 510 being such that, when the wipers 511 to 514, inclusive, are operated to a vertical position opposite a level of bank contacts terminating a group of trunks extending to selectors arranged for simplex circuit control, the contacts 396 are disengaged and the contacts 395 are moved into engagement. On the other hand, when the wipers 511 to 514, inclusive, are operated to a position opposite a level of bank contacts terminating trunks extending to second selectors arranged for loop circuit control, the normal post spring combination remains in its normal position such that the springs 396 are engaged and the contact springs 395 are disengaged.

As indicated above, the relay R550 completes, in the case under consideration, the operating circuit for the control relay R370, this circuit extending from ground by way of the off-normal springs 525, the contacts 557, C389, the normal post springs 396, the contacts 349 and 363, and the lower winding of R370 to battery. In operating, the relay R370 completes, at its contacts 372, an obvious multiple path for impressing ground potential upon the extra control wiper 514. At its contacts 373, the relay R370 opens a point in the operating circuit for the switch through relay R340. At its contacts 371, the relay R370 completes the operating circuits for the loop relay R360 and the slow-to-release ringing start relay R530. These two circuits commonly extend from ground by way of the off-normal springs 525, the contacts 557, C389, the normal post springs 396, the contacts 349 to the contacts 371 where they divide, one circuit extending through the winding of R360 to battery, and the other circuit extending by way of C386 and the winding of R530 to battery. The relay R530, in operating, closes its contacts 531 to impress ground potential upon the supervisory lead C505 and opens its contacts 532 to interrupt the initially completed path for impressing ground potential upon the extra control wiper 514. The relay R360, upon operating, first locks to ground over a path including its preliminary make contacts 365, the contacts 349, the normal post springs 396, C389, the contacts 557 and the off-normal springs 525. In completing this locking path, the relay R360 also clears an obvious locking circuit for the ringing start relay R530. After completing this circuit, the relay R360 closes its contacts 366 to prepare the operating circuit for the relay R340. At its contacts 363, the relay R360 interrupts the above-traced operating circuit for the relay R370. At its contacts 364, the relay R360 prepares a circuit for energizing the lower winding of R370 in parallel with the transfer relay R560. At its contacts 361 and 362, the relay R360 completes a direct current path in bridge with the line wipers 511 and 512 of the switching mechanism 510. This bridging path may be traced as extending from the negative line wiper 511 by way of the contacts 551, C374, the contacts 341 and 361, C375, the contacts 536, C379, the upper winding of R370, the contacts 362 and 346, C380 and the contacts 552 to the positive line wiper 512.

When the above-traced bridging path is completed, the upper winding of the control relay R370 is energized in series with the winding or windings of the line relay embodied in the seized toll second selector 676 and, accordingly, the relay R370 is held energized. The resulting operation of the line relay embodied in the toll second selector 676 causes the control equipment of this selector to be conditioned to respond to the impulses comprising the second digit of the directory number designating the desired subscriber line in the usual manner. Following the operations just described, the toll transmission selector 300 is conditioned to repeat further impulses transmitted thereto from the operator's position 441 to the seized toll second selector 676. In this regard it will be understood that the line relay R535 follows the impulses of the second digit and, by opening and closing its contacts 536, functions to repeat the impulses over the loop extending to the toll second selector 676. When the relay R535 restores at the beginning of the first impulse of the second digit, the previously traced circuit is completed for energizing the transfer relay R560. Also, the above-mentioned circuit for energizing the lower winding of the relay R370 is completed, this circuit extending from ground by way of the contacts 538 and 541, C381, the contacts 364 and the lower winding of R370 to battery. Thus, the relay R370 is prevented from releasing during operation of the line relay R535 to repeat pulses to the seized second selector 676 and the following switches. The relay R560, upon operating at the beginning of the first impulses of the second digit, completes, at its contacts 561, the above-mentioned path for connecting the resistor 504 in shunt with the upper winding of R370, whereby the resistance of the loop circuit extending to the seized second selector 676 is reduced and the relay R370 is rendered slow to release. Due to the slow-to-release characteristic thus imparted to the relay R370, and the inherent slow-to-release characteristic of the relay R560, these two relays are not released until the digit is ended.

At the end of the second digit transmitted to the toll transmission selector 300, the second selector 676 operates automatically to select an idle one of the toll connector switches of the selected group, providing an idle switch is available in this group. The manner in which the trunk-hunting operation is carried out by the second selector 676 is well understood in the art and will be clearly apparent from the above explanation of the corresponding operation of the selector 300.

If all of the connector switches of the selected group are busy at the time the trunk-hunting operating of the second selector 676 is initiated, the wipers of the latter switch are stepped to the eleventh rotary off-normal position. As a result, the control equipment of the second selector 676 operates to open the previously traced pulse repeating loop extending from the toll transmission selector 300 over the talking conductors of the trunk 675 to the second selector 676. When this loop is opened, the control relay R370 is deenergized and restores. In releasing, the relay R370 opens its contacts 371 to interrupt the previously traced operating circuits for the relays R360 and R530. At its contacts 373, the relay R370 completes a circuit including the engaged contacts 366 for energizing the switching-through relay R340. The relay R340, upon operating, locks to ground over a path including the contacts 348,

the normal post springs 396, C389, the contacts 557 and the off-normal springs 525. After this locking circuit is completed, the relay R340 opens its contacts 349 to interrupt the previously traced locking circuits for the relays R360 and R530. At these contacts the relay R340 also opens a point in the initially completed circuit for energizing the lower winding of the control relay R370. At its contacts 349', the relay R340 opens another point in the prepared operating circuit for the release magnet 523. At its contacts 343, 344 and 345, the relay R340 bridges the two windings of the battery supply relay R350 across the talking conductors of the trunk 675 in series with the filaments of the lamp 317, the upper winding of the answer or back-bridge relay R330, the repeating coil windings 313 and 314, the line wipers 511 and 512 of the toll transmission selector 300. Under the condition assumed, namely, when all of the toll connectors of the selected group are busy, the control equipment of the toll second selector 676 functions to connect the negative talking conductor of the trunk 675 to a source of ground pulses. These ground pulses are applied to the negative side of the trunk 675 at a rate of approximately 120 pulses per minute. Each time a ground pulse is applied to this conductor, the upper winding of the battery supply relay R550 is energized over a circuit including the wiper 511, C376, the contacts 343, the winding 313, the upper winding of R350 and the filament 319 of the lamp 317 to battery. Thus, the relay R350 is caused intermittently to operate at a rate corresponding to the rate at which the ground pulses are applied to the negative side of the trunk 675. Each time the relay R350 operates, it completes, at its contacts 351, an obvious circuit for energizing the tone relay R355. Thus, the relay R355 also follows the ground pulses applied to the negative side of the trunk 675. The relay R355, in operating, closes its contacts 358 to complete an obvious path for impressing ground potential upon the supervisory lead C454. The ground pulses thus applied to the supervisory lead C454 result in the flashing of the supervisory lamp associated with the connection at the operator's position 441 in the manner explained above. This flash busy signal indicates to the operator attending the position 441 that all of the toll connectors having access to the desired subscriber line are busy and hence the desired connection cannot immediately be obtained. The manner in which the partially established connection is released is explained in detail in a following portion of the specification.

Assuming, for example, that the toll connector 681 is the first idler connector of the selected group, the trunk-hunting operation of the selector 676 is arrested when the wipers of this selector are operated into engagement with the contacts terminating the conductors of the trunk 680. At this time the control equipment of the selector 676 operates in the usual manner to extend the loop circuit over the trunk 680 to the toll connector 681. In response to this operation the line and hold relays of the connector 681 operate in the usual manner, whereby the control equipment of this connector is conditioned to respond to the impulses comprising the third digit of the directory number designating the desired line 691. The toll connector 681 responds to the impulses of the second and third digits of the directory number designating the line 691 by operating its wipers into engagement with the bank contacts terminating the conductors of this line

in the usual manner. As the beginning of the first series of impulses transmitted to the toll connector 681, the ring cut-off relay conventionally embodied in this switch operates and locks to ground over a circuit including the connected extra control conductors of the trunks 675 and 680, and the grounded extra control wiper 514 of the toll transmission selector 300. With this relay operated, a point is opened in the circuit for transmitting ringing current over the desired line to signal the desired substation. At the end of the second series of impulses transmitted to the toll connector 681, the line 691 is tested to determine the idle or busy condition thereof in the usual manner. Immediately after the line 691 is selected in the manner pointed out above, the toll relay conventionally embodied in the toll connector 681 operates to disconnect the negative and positive terminals of the exchange battery from the line wipers 511 and 512 of the toll transmission selector 300. This operation occurs regardless of the idle or busy condition of the selected line 691. In response to this operation, the relay R370 is deenergized and restores. In releasing, the relay R370 opens its contacts 371 to interrupt the previously traced operating circuit for the relay R530. At its contacts 373, the relay R370 completes the operating circuit for the switching-through relay R340. At its contacts 372, the relay R370 opens the previously traced path for impressing ground potential upon the extra control wiper 514. In the event the selected line 691 is idle at the time it is tested by the toll connector 581, the removal of ground potential from the extra control wiper 514 results in the deenergization and release of the ring cut-off relay embodied in the toll connector. In restoring, this ring cut-off relay completes the prepared circuit for transmitting ringing current over the line 691 to energize the ringer conventionally provided at the substation T1. Thus, the ringing operation is started.

In operating, the relay R340 locks to ground over a path including the contacts 348, the normal post springs 396, C389, the contacts 557 and the off-normal springs 525. After this locking circuit is completed, the relay R340 opens its contacts 349 to interrupt the locking circuits for the relays R360 and R530, and to open a point in the circuit for energizing the lower winding of the control relay R370. At its contacts 349', the relay R340 opens another point in the prepared operating circuit for the release magnet 523. At its contacts 343, 344 and 345, the relay R340 prepares a battery feed circuit to the called end of the connection, one branch of this circuit extending by way of the negative side of the trunk 680, the negative side of the trunk 675, the wiper 511, C376, the contacts 343, the repeating coil winding 313, the upper winding of the supervisory relay R350 and the filament 319 of the lamp 317 to the negative terminal of the exchange battery. The other side of this battery feed circuit extends by way of the positive conductor of the trunk 680, the positive side of the trunk 675, the wiper 512, C378, the contacts 345, the upper winding of the answer relay R330, the repeater winding 314, the contacts 344, the lower winding of R350 and the filament 318 of the lamp 317 to the positive terminal of the exchange battery. As its contacts 341 and 346, the relay R340 opens two points in the previously traced circuit for energizing the upper winding of the control relay R370.

The relay R360, in restoring, opens its con-

tacts 361 and 362 to open two additional points in the circuit for energizing the upper winding of the control relay R370. At its contacts 363 and 364, the relay R360 opens the above-traced alternative circuit for energizing the lower winding of the relay R370, and reprepares the initially completed circuit for energizing the lower winding of this relay. At its contacts 365, the relay R360 opens a further point in the above-traced locking circuits for itself and the relay R530. At its contacts 366, the relay R360 opens a point in the operating circuit for the relay R340. The relay R530 also restores a short time interval following the release of the relay R370. Upon restoring, the relay R530 opens its contacts 531 to interrupt the path for grounding the supervisory lead C505. At its contacts 532, the relay R530 recompletes the previously traced path for impressing ground potential upon the extra control wiper 514, thereby to reprepare the locking circuit for the ring cut-off relay embodied in the toll connector 681. Following the operations just described, no further operation of the apparatus included in the switches of the switch train occurs until the call is answered at the called substation T1 or is abandoned at the operator's position 441 in the remote exchange 30.

Assuming that the call is answered at the called substation, a direct current bridge is connected across the talking conductors of the line 691 when the answering party removes the receiver provided at the substation T1 from its supporting hook or cradle. When this bridge is completed the ring cut-off relay embodied in the toll connector 681 operates and locks to the grounded extra control wiper 514. In operating, this relay also arrests the ringing operation and connects the answering bridge across the line wiper 511 and 512 over paths including the conductors of the line 691, the talking conductors of the toll connector 681, the talking conductors of the trunk 680, the talking conductors of the toll second selector 676, and the talking conductors of the trunk 675. When this bridging path is completed, the two windings of the battery supply relay R350 are energized in series with the upper winding of the answer relay R330 over the battery feed circuit as traced above. The two-step answer relay R330 now operates to close its preliminary make contacts 331 only, thereby to prepare a circuit for energizing its lower winding. The relay R350 also operates when its two windings are energized in the battery feed circuit. In operating, the relay R350 completes, at its contacts 351, an obvious circuit for energizing the tone relay R355. The relay R355, upon operating, completes, at its contacts 358, an obvious path for impressing ground potential upon the supervisory lead C434, whereby the supervisory signal lamp in use at the toll operator's position 441 is energized or deenergized to indicate to the operator attending this position that the call routed over the trunk 440 to the line 691 has been answered. This type of supervisory signal is commonly known as an off-hook supervisory signal and will be referred to as such in the following portion of the specification. At its contacts 351, the relay R350 opens a point in the circuit traced hereinafter for transmitting a call intercepting tone signal over an established connection including the trunk 440 to inform the operator attending the position 441 that the call routed to a called subscriber line 75 has been intercepted. At its contacts 356, the

relay R350 completes the prepared circuit for energizing the lower winding of the answer relay R330, this circuit extending from ground by way of the contacts 356, the resistor 307, the contacts 331 and the lower winding of R330 to battery. When this circuit is completed, the relay R330 completes its operation. At its contacts 332, the relay R330 completes an obvious path for short-circuiting its upper winding, thereby to render its self slow to release and to lower the 10 resistance of the battery feed circuit to the transmitter provided at the called substation T1. At its contacts 331', the relay R330 disconnects the balancing network comprising the resistor 333 and the condenser 334 from across 15 the repeater windings 313 and 314.

As indicated above, current for energizing the transmitter provided at the called substation T1 is supplied to the loop extending to this substation through the two filaments of the lamp 20 317. It is well known that each filament of a lamp of this character possesses a substantial current coefficient of resistance such that the resistance of each filament varies directly in accordance with the current flow therethrough. 25 Accordingly, if the line 691 extending to the called substation T1 is a short line having a low loop resistance, the current traversing the two filaments 318 and 319 of the lamp 317 tends to assume a substantial magnitude. As the current tends to rise, however, the resistance of the two filaments 318 and 319 increases, so that the current is correspondingly reduced. Thus, the current traversing the loop extending to the called substation is prevented from exceeding a predetermined value. On the other hand, if the line 691 is a relatively long line having a high loop resistance, the current traversing the loop and the two filaments 318 and 319 is of relatively low magnitude. Accordingly, the resistance of the two filaments 318 and 319 is maintained at a 40 relatively low value so that the presence of these filaments in the battery feed circuit does not materially reduce the current traversing the transmitter provided at the called substation. It is further noted that the two filaments 318 and 319, 45 being enclosed within a single envelope, are positioned in close proximity to each other so that the ready transfer of heat therebetween may occur. Thus, these filaments are maintained at substantially the same temperature and, accordingly, the resistance values thereof are maintained substantially equal regardless of the current flow therethrough. As a result, the line balance is maintained regardless of any differences in current flow through the two lamp filaments. Preferably, the lamp 317 is of the tungsten filament type, having its filament resistances so proportioned that the total filament resistance is approximately 165 ohms when current is conducted through the filaments to a line loop of zero resistance, and the total resistance is approximately 30 ohms when current is conducted through the filaments to a line loop having a resistance of 500 ohms or over. From the above 50 explanation it will be apparent that the twin filament lamp 317 functions as a current regulating device to maintain substantially constant the current transmitted to a transmitter provided at a called substation regardless of the length of the 55 line serving the substation.

After the connection to the called substation is established in the manner explained above, the answering party may recall the operator handling the call at the operator's position 441 by op-

erating the switchhook provided at the substation T1 up and down for the purpose of flashing the supervisory signal device associated with the connection at the operator's position 441. Each time the switchhook provided at the substation T1 is operated to open the bridge across the talking conductors of the line 691, the relays R350, R355 and R330 are caused sequentially to restore in an obvious manner. The relay R355, in releasing, disconnects the supervisory lead C454 from ground, whereby a signal control pulse is transmitted over the trunk 440 to cause the energization or deenergization of the supervisory signal device associated with the connection at the operator's position 441. Conversely, each time the hook switch provided at the called substation T1 is operated to reconnect the answering bridge across the talking conductors of the line 691, the relays R350, R355 and R330 are caused sequentially to reoperate in the order named and in the exact manner described above. The relay R355, in reoperating, again connects the supervisory lead C454 to ground with the result that the signal device associated with the connection at the operator's position 441 is again energized or deenergized. These operations are repeated each time the switchhook provided at the called substation T1 is operated between its normal and off-normal positions. The resulting intermittent energization of the signal device provided at the operator's position 441 in association with the connection serves to inform the operator handling the call at this position that she is being recalled by the called subscriber, whereupon she may reenter the connection and ascertain the service desired.

If the called subscriber line 691 is busy at the time it is selected by the toll connector 681 in the manner explained above, the line-switching relay embodied in the toll connector is prevented from operating due to the operation of the busy test relay of the connector. This busy test relay, in operating, also functions to complete a locking circuit for the associated ring cut-off relay, whereby the ring cut-off relay is prevented from releasing in response to the release of the relay R370 and the resulting removal of ground potential from the extra control wiper 514. The busy test relay of the connector in operating, also connects the negative side of the trunk 680 to a source of ground pulses. These pulses are impressed upon the negative talking conductor of the trunk 680 at the rate of approximately 60 pulses per minute. In addition, the control equipment of the toll connector 681 operates in the manner explained above to interrupt the circuit for energizing the upper winding of the relay R370. As a consequence, the relay R370 restores to cause the operation of the relay R340 followed by the release of the relays R360 and R530. The relay R340, upon operating, completes a circuit for energizing the battery supply relay R350 in accordance with the ground pulses being applied to the negative side of the trunk 680. This circuit extends from ground through the contacts of the pulse generator and by way of the negative conductor of the trunk 680, the negative talking conductors of the toll selector 676, the negative side of the trunk 675, the line wiper 511, C376, the contacts 343, the winding 313, the upper winding of R350 and the filament 319 to battery. After this circuit is completed, the relay R350 follows the ground pulses applied to the negative conductor of the trunk 680 and repeats these pulses to the tone

relay R355. Under the conditions stated, no bridging path is established between the talking conductors of the trunk 680 and, accordingly, the upper winding of the answer relay R330 is not energized. The tone relay R355, in following the ground pulses repeated thereto by the battery supply relay R350, intermittently closes its contacts 358 to impress ground pulses upon the supervisory lead 454. These pulses, as repeated over the trunk 440 to the trunk circuit terminating this trunk at the operator's position 441, cause the intermittent energization of the signal lamp associated with the connection at this operator's position, with the result that a flash busy signal is produced. The flashing rate of this signal is different from the rate of the flash busy signal which occurs when an all-trunks-busy condition prevails, and indicates to the operator handling the call that the called subscriber line is busy.

The busy test relay of the toll connector 681, in operating, also completes a path for impressing the usual busy tone signal voltage upon the talking conductors of the trunk 680. This voltage is transmitted through the toll second selector 676, the repeating coil 310 of the toll transmission selector 300, and over the trunk 440 to the cord circuit in use at the operator's position 441. By virtue of this arrangement, the operator handling the call at this position may, upon receiving the flash busy signal, reenter the connection, providing she has disconnected from the connection after dialing the digits of the directory number designating the desired line, and listen to the busy signal to verify the busy condition of the called line. After receiving the busy signals just described, the operator may release the connection in the manner pointed out hereinafter.

Call interception

In the event the substation T1 is taken out of service or, for some other reason, certain or all of the calls routed to the line 691 are to be intercepted, the line multiple terminating the conductors of this line in the central exchange is cross connected to the trunk conductors of a call intercepting circuit 693. If, with this wiring arrangement, a call is routed from the toll operator's position 441 through the automatic switches 300, 676 and 681 to the line 691, the ringing current transmitted from the toll connector 681 over the trunk 691 following seizure of this line causes the operation of the call intercepting circuit 693. This circuit functions in a well-known manner to forward the call over the trunk 695 to the intercepting operator's position 1151. When the call is extended to this operator's position, a signal lamp or drop individual to the trunk 695 is energized, indicating to the operator attending this position that a call has been intercepted which should be answered. When the intercepting operator answers the call, the negative and positive conductors of the line 691 are each connected to ground through approximately 1200 ohms resistance. This resistance bridge approximately 2400 ohms results in the operation of the ring cut-off relay provided in the toll connector 681. The ring cut-off relay, in operating, locks to the grounded extra control wiper 514, opens the ringing current circuit, and extends the loop from the repeating coil 310 through the call intercepting circuit 693 to the call intercepting operator's position 1151. The resistance of this loop is

such that the relay R330 operates to close its preliminary make contacts only, and the battery supply relay R350 is insufficiently energized to operate. With the relay R330 partially operated and the relays R350 and R355 restored, a circuit is completed for conducting intercepting tone signal current through the lower winding of the relay R330, this circuit extending from one terminal of the intercepting tone current source by way of C305, the condenser 306, the contacts 357, the resistor 307, the contacts 331, the lower winding of R330 and the exchange battery to the opposite terminal of the current source. The current traversing the lower winding of R330 causes a corresponding induced voltage to be developed across the upper winding of this relay. This voltage is transmitted through the repeating coil 310 and over the trunk 450 to the operator's cord circuit provided at the operator's position 441, and serves to energize the receiver in use by the operator handling the call at this position. The signal thus transmitted to the operator serves to inform the operator that the call has been intercepted. The signal voltage is also transmitted over the called end of the connection to energize the receiver provided at the intercepting operator's position 1151 and when reproduced by this receiver serves to inform the intercepting operator that the answered call is a toll call. Provisions are made at the intercepting operator's position 1151 for reducing the resistance of the previously described loop circuit extending through the call intercepting circuit 693 and the windings of the relays R330 and R350, thereby to cause the complete operation of both of these relays. In operating, these two relays perform the functions described above with reference to the call routed to the substation T1, two of these functions being the opening of the intercepting tone circuit and the transmission of an off-hook supervisory signal to the operator's position 441.

If the intercepting operator wishes to recall the operator attending the position 441, she may do so by intermittently changing the resistance of the loop extending through the call intercepting circuit 693 and the windings of the relays R330 and R350, thereby to cause the production of the flashing recall signal at the operator's position 441 in the manner described above.

Release

The release of the connection, regardless of whether it is routed to the substation T1 or the intercepting operator's position 1151, is under the control of the calling operator attending the position 441 in the remote exchange 30. Thus, if the call is routed to the substation T1, the relays R350, R330 and R355 are caused to restore in the manner explained above when the connection is released at this substation. The relay R355, upon restoring, opens its contacts 358 to disconnect the supervisory lead C454 from ground, whereby the usual disconnect or on-hook supervisory signal is produced at the operator's position 441. This signal indicates to the operator handling the connection at this operator's position that the connection has been cleared out at the called substation and is ready to be released. In a similar manner, if the call is routed to the intercepting operator's position 1151, a disconnect signal is, through the release of the relays R330, R350 and R355, transmitted to the calling operator's position 441 when the connection is cleared out at the intercepting operator's

at 500 ohms at voltage 66801 when the unit finds the position. Following the release of the three enumerated relays, only the relays R535, R545, R550, R540 and R340 are operated in the toll transmission selector 300. When the operator attending the position 441 clears out the connection, the toll line circuit 442 is released. During the release of this unit, the relays R1300, R1340, R1320 and R1350, and the relay R1330, if operated, are all deenergized and restored in the order named. The relay R1300, in releasing, disconnects the two trunk conductors C451 and C452 from ground to deenergize the line relay R535. The relay R1350, in releasing, opens one of the paths over which ground potential is impressed upon the control conductor C453. The relay R535, upon restoring, opens the operating circuit for the relay R545. The relay R545, in turn, releases to open the holding circuit for the relay R550. The relay R550 now restores to open its contacts 557 and thus interrupt the locking circuit for the relay R340 which also restores. The relay R545, upon restoring, also disconnects the private or control conductor 513 from ground. The relay R550, upon restoring, also disconnects the extra control wiper 514 from ground and opens its contacts 551 and 552 to interrupt the loop circuit extending through the second selector 676 to the toll connector 681. In response to these circuit changes, the toll connector 681 and the second selector 676 are automatically released in a manner well understood in the art. During the release of the toll connector 681, ground potential is removed from the private conductor of the line 691, whereby the operated cut-off relay of the line circuit 692 is released and the line 691 is marked as idle in the bank contacts of the connector switches having access thereto. The relays R535 and R545, upon restoring, also complete the prepared operating circuit for the release magnet 523, this circuit extending from ground by way of the contacts 538 and 548, C387, the contacts 349 and 325, the off-normal springs 392, C385 and the winding of the magnet 523 to battery. The release magnet 523 now operates to attract its holding pawl and thus permit the wipers 511 to 514, inclusive, to be restored to rotary and vertical normal in the usual manner. When these wipers are returned to their respective normal positions, the off-normal springs 391, 392 and 393 are respectively disengaged. The normal post springs 397, 395 and 396, and the off-normal springs 525, if operated, are restored to their respective normal positions at this time. When the off-normal springs 391 are disengaged, the operating circuit for the supervisory relay R540 is interrupted in an obvious manner, causing this relay to restore. When the off-normal springs 392 are disengaged, the above-traced circuit for energizing the release magnet 523 is interrupted. At the off-normal springs 393, a point is opened in the previously traced operating circuit for the stepping relay R570. Following the operations just described, the toll transmission selector 300 is fully restored to normal.

The manner in which the toll transmission selector 300 and the following operated numerical switches are released when a connection is not successfully completed, due to an all-trunks-busy condition at an intermediate switching stage or to the busy condition of the called line 691, is substantially similar to the release of the connection as described above, and will be clearly apparent from the explanation pertaining thereto. If the above-described connection is successfully completed and is cleared out at the calling op-

er's position 441 in the remote exchange 30, the relays R330, R350 and R365 of the toll transmission selector 300 are operated at the time the release of the connection is initiated. It will be apparent that these three relays are deenergized and restored in response to the release of the relay R550 to interrupt the loop circuit extending from this selector through the toll selector 676 to the toll connector 681. Aside from the release of these relays, the release of the operated switch train is accomplished in the manner described above.

CALL FROM THE REMOTE EXCHANGE 30 TO A SUB-STATION SERVED BY THE C. A. X 50

If the above-described call originating on a line terminating at the remote exchange 30 and routed to the toll operator's position 441 is intended for the substation T2, for example, served by the automatic switching equipment 403 of the C. A. X 50, the call may be routed over the trunk 440 through the toll line circuit 442, the toll transmission selector 300, the toll second selector 676, the repeater 600, the toll incoming selector 460, the trunk circuit 404 and the automatic switching equipment 403 to the desired line. In such case, the toll transmission selector 300 operates to seize the toll second selector 676 in the manner explained above with reference to the call routed to the substation T1. Following seizure of this second selector, the operator handling the call at the position 441 dials a second digit designating the group of repeaters including the repeater 600. Assuming that the repeater 600 is the first idle repeater of the selected group, the toll second selector 676, during its trunk-hunting operation, functions to seize the trunk 670 and to establish a loop circuit, including the talking conductors of this trunk, which extends from the repeating coil 310 to the repeating coil 610. More specifically, when the toll second selector 676 switches through in the usual manner, ground potential is impressed upon the control conductor C673 and a circuit is completed for energizing the relay R650 in series with the upper winding of R370. This circuit extends from ground by way of the contacts 664, C671, the positive talking conductors of the second selector 676, the wiper 512, the contacts 552, C380, the contacts 346 and 362, the upper winding of R370, C379, the contacts 536, C375, the contacts 361 and 341, C374, the contacts 551, the wiper 511, the negative talking conductors of the second selector 676, C672, the contacts 666, and the winding of R650 to battery. When energized over this circuit, the relay R370 remains in its operated position, having previously been energized in series with the line relay of the second selector 676. The operated switching-through relay of the toll second selector 676 is locked up over a holding circuit including the grounded control wiper 513, in the usual manner. In operating, the relay R650 completes a circuit including the contacts 652 and 661 for energizing the slow-to-operate relay R640. At its contacts 651, the relay R650 opens a point in the operating circuit for the slow-acting digit counting relay R630. At its contacts 653, the relay R650 prepares a loop circuit to its associated toll incoming selector 460. The relay R640, upon operating, closes its contacts 647 to impress ground potential upon the control conductor C474. At its contacts 641, the relay R640 completes an obvious path for impressing ground potential upon the supervisory lead C626. At its contacts 642,

the relay R640 opens a point in the operating circuit for the release magnet 624. At its contacts 643, the relay R640 prepares the operating circuit for the magnet 623 of the digit counting switch 620. At its contacts 644, the relay R640 prepares the operating circuit for the digit counting relay R630. At its contacts 645, the relay R640 locks to the grounded control conductor C673 which is now connected through the toll selectors 676 and 300 to the grounded private conductor C454 of the trunk 405. At its contacts 646, the relay R640 completes the prepared loop between the repeating coil 610 and the toll incoming selector 460, this loop extending by way of the positive trunk conductor C471 and the contacts 668, 653 and 646 to the negative trunk conductor C472. In response to the completion of this loop circuit and the grounding of the control conductor C474, certain of the relays embodied in the toll incoming selector 460 operate to mark the trunk 422 as busy and thus render this selector inaccessible to the toll switching apparatus 420. The relays of the toll incoming selector 460, in operating, also condition this selector to respond to impulses transmitted thereto from the calling operator's position 441.

Following seizure of the toll incoming selector 460 in the manner explained above, the calling operator at the position 441 dials the remaining digits of the directory number designating the desired line 401. During the dialing of these digits, the relay R535 in the toll transmission selector 300 repeats the impulses through the toll second selector 676 to the repeater 600. The pulsing or line relay R650, in turn, repeats the impulses to the toll incoming selector 460. Thus, each time the loop extending from the toll transmission selector 300 to the repeater 600 is opened by the pulsing relay R535, the relay R650 is de-energized and restores. At its contacts 653, the relay R650 opens the loop extending to the toll incoming selector 460. At its contacts 651, the relay R650 completes the prepared operating circuit for the digit counting relay R630. This circuit extends from ground by way of the contacts 661, 651 and 644, and the winding of R630 to battery. At its contacts 652, the relay R650 opens the operating circuit for the relay R640, but the latter relay is held operated over its holding circuit as traced above. It will be apparent that the relay R630 is energized at the beginning of the first impulse of the first series of impulses transmitted to the repeater 600. This relay, upon operating, opens its contacts 631 to open a point in the circuit for energizing the polarizing winding of the relay R655 and the winding of the relay R660 in parallel. At its contacts 632, the relay R630 completes a circuit including the contacts 643 for energizing the operating magnet 623 of the digit counting switch 620. When thus energized, the magnet 623 functions to advance its wiper 621 one step. When the wiper 621 is thus moved off normal, the off-normal springs 625 are operated into engagement to prepare the operating circuit for the release magnet 624. The relay R630, due to its slow-to-release characteristic, remains operated during each series of impulses transmitted to the repeater, and restores shortly after the impulse series is ended. At the end of the first series of impulses transmitted to the repeater 600, and repeated by the relay R650 to the toll incoming selector 460, the wipers of this selector are positioned opposite the level of contacts terminating the group of trunks including the trunk 405. 75

The line or pulsing relay R650 remains in its operated position. Accordingly, the digit counting relay R630 is deenergized and restores to open the operating circuit for the magnet 623. 5 Thus, the digit counting switch 620 is conditioned to take another step. Shortly following the end of the digit, the toll incoming selector 460 operates automatically to seize the first idle trunk of the selected group. Assuming that the trunk 405 is the first available trunk in the group, this trunk is seized and the trunk-hunting operation of the selector 460 is arrested when the wipers of this selector are positioned on the contacts terminating the conductors of this trunk. In response to this operation, the established loop circuit connecting the repeater 600 and the toll incoming selector 460 is extended through this selector and over the trunk 405 to the trunk circuit 404. At this time certain of the control relays embodied in the trunk circuit 404 operate to mark the trunk 405 as busy in the access contacts of the toll switching apparatus 420. These relays, in operating, also function to establish a calling simplex or loop circuit to certain of the automatic switching equipment 403 provided in the distant exchange 50, and to condition the trunk circuit control equipment to repeat to the seized switching equipment in the distant C. A. X impulses transmitted thereto from the repeater 600. Following the operations just described, the two pulsing relays R535 and R650, in cooperation with the pulse repeating equipment of the trunk circuit 404, function to repeat the impulses of the fourth, fifth and any required additional digits to the seized automatic switching equipment in the distant C. A. X 50, whereby the connection is extended to the desired line 401. During each of these additional digits, the digit counting relay R630 functions to transmit a current pulse to the operating magnet 623 of the digit counting switch 620. Accordingly, at the end of the calling operation, the wiper 621 is positioned in engagement with the contact of its associated contact bank which forms a part of the circuit for energizing the polarizing winding of the relay R655 and the relay R660 in parallel. Thus, if three digits are required by the seized portion of the automatic switching equipment 403 in order to route the connection to the desired line and to select the ringing code corresponding to the desired substation, the wiper 621 will be operated into engagement with its associated fourth contact at the end of the calling operation. Shortly after the calling operation is ended, the relay R630 restores to complete the above-mentioned circuit for energizing the relay R660 in parallel with the polarizing winding of the relay R655. This circuit extends from ground by way of the contacts 643 and 631 to the wiper 621 where it divides, one branch extending through the fourth contact of the contact set 622 and the polarizing winding of the relay R655 to battery, and the other branch extending through the fourth contact of the contact set 622 and the winding of R660 to battery. When thus energized, the relay R660 operates and locks to the grounded control conductor C473 through its contacts 662. At the contacts 662, the relay R660 also completes an obvious multiple circuit for energizing the polarizing winding of the relay R655. At its preliminary make contacts 669, the relay R660 completes an obvious multiple path for impressing ground potential upon the control conductor C474. At its contacts 661 and 663, the relay R660 opens the

operating and locking circuits for the relays R640 and R630. At its contacts 664 and 666, the relay R660 opens two points in the previously traced circuit for energizing the relay R650 in series with the upper winding of the relay R370. At its contacts 665, the relay R660 prepares a circuit for energizing the upper winding of the answer relay R330 in series with the two windings of the battery supply relay R350. At its contacts 667, the relay R660 completes an obvious path in shunt with the contacts 646 and 653 of the relays R640 and R650, respectively, thereby to prevent interruption of the loop circuit extending through the toll incoming selector 460 to the trunk circuit 404 when the relays R640 and R650 subsequently restore. At its contacts 668, the relay R660 opens a point in the path normally short-circuiting the series network including the repeating coil windings 611 and 612 and the operating winding of the polarized relay R655, thereby to include this network in the loop circuit extending to the trunk circuit 404. At this time, the direction of current flow over the loop extending between the repeater 600 and the trunk circuit 404 is such that the relay R655 does not operate.

As indicated above, the two relays R650 and R640 are deenergized and restore in response to the operation of the relay R660. The relay R640, upon restoring, opens its contacts 643 to interrupt the initially completed circuit for energizing the relay R660 in parallel with the polarizing winding of the relay R655. At its contacts 642, the relay R640 completes the prepared operating circuit for the release magnet 624. The latter circuit extends from ground by way of the contacts 642, the off-normal springs 625 and the winding of the magnet 624 to battery. When thus energized, the release magnet 624 functions in the usual manner to release the wiper 621, whereby this wiper is restored to its normal position. When the wiper 621 is returned to normal, the off-normal springs 625 are opened to interrupt the circuit for energizing the release magnet 624.

When the relay R660 operates to open the circuit serially including the winding of the relay R650 and the upper winding of the relay R370, the latter relay is deenergized and restores to complete the prepared operating circuit for the relay R340. Thus, the relay R340 is caused to operate further to prepare the circuit for energizing the two windings of the battery supply relay R350 in series with the upper winding of the answer relay R330. The relay R340, upon operating, also initiates the release of the relays R360 and R530 in the manner previously explained.

In the event the called line 401 is busy at the time it is selected by the seized switch train of the automatic switching equipment 403, the control relays of the final numerical switch through which the connection is routed to the line 401 operate to return busy tone current over the calling end of the connection in the usual manner. This busy tone current, as reproduced by the receiver in use at the operator's position 441, serves to inform the calling operator that the desired line is busy. The manner in which the operated switch train is released under the control of this operator is pointed out hereinafter. In the event the called line 401 is idle at the time it is selected, ringing current is transmitted thereover to energize the signal device provided at the called substation T2, and the usual ring-

back tone signal is transmitted over the calling end of the connection to inform the operator attending the position 441 that the called substation is being rung.

The desired conversational circuit is fully established when the call is answered at the called substation T2. In response to this operation, the direction of current flow over the loop circuit extending from the repeater 600 to the trunk circuit 404 is reversed in the usual manner. The polarized relay R655 responds to this current reversal by operating to close its contacts 656 and thus complete the prepared circuit for energizing the upper winding of the answer relay R330 in series with the two windings of the battery supply relay R350. This circuit extends from ground by way of the filament 318, the lower winding of R350, the contacts 344, the winding 314, the upper winding of R330, the contacts 347, C380, the contacts 552, the wiper 512, the positive side of the trunk 675, the positive talking conductors of the toll second selector 676, C671, the winding 613, the contacts 665, the resistor 616, the contacts 656, the winding 614, C672, the negative talking conductors of the toll second selector 676, the negative side of the trunk 675, the wiper 511, the contacts 551, C374, the contacts 342, the winding 313, the upper winding of R350 and the filament 319 to battery. When this circuit is completed, the three relays R330, R350 and R355 operate in the exact manner previously described to transmit an off-hook supervisory signal to the operator handling the call at the operator's position 441. Following the operation of these three relays, no further operation of the apparatus occurs until the connection is cleared out at the operator's position 441 or is released at the called substation T2.

In the event the called subscriber at the substation T2 desires to recall the operator attending the position 441 in the remote exchange 30, he may do so by operating the switchhook provided at the substation T2 to cause the intermittent release and reoperation of the polarized answer relay R655 in a manner well understood in the art. The relay R655, in cooperation with the three relays R330, R350 and R355, functions, in a manner clearly apparent from the preceding explanation, to transmit a flashing recall signal to the operator's position 441 in response to the intermittent operation of the switchhook provided at the called substation T2. When the connection is released at the substation T2 to cause the release of the answer relay R655, the three relays R330, R350 and R355 are released and a disconnect or on-hook supervisory signal is transmitted to the operator attending the operator's position 441.

The manner in which the toll transmission selector 300 and the toll second selector 676 are released under the control of the operator attending the position 441 is exactly the same as described above with reference to the call routed to the substation T1. During the release of these two switches, the control conductors C673 and C473 are disconnected from ground to cause the deenergization and release of the relays R660 and R655, these two relays being the only operated relays in the repeater 600. Incident to the release of the relay R660, the loop extending from the repeater 600 to the trunk circuit 404 is interrupted. When this loop is opened and ground potential is removed from the control conductor C473, the trunk circuit 404 and the toll incoming selector 460 are restored to normal in a manner

well understood in the art. During the release of the trunk circuit 404, the calling loop or simplex circuit extending over the trunk 405 to the operated switch train in the C. A. X 50 is opened to initiate the release of the latter equipment. Thus, the apparatus utilized in forwarding the connection to the called substation T2 is fully restored to normal. When the trunk circuit 404 releases, the trunk 405 is marked as idle in the access contacts of the toll switching apparatus 420 and in the bank contacts of the toll incoming selectors having access thereto. Similarly, when ground potential is removed from the control conductor C473, the toll incoming selector 460 is marked as idle in the access contacts of the toll switching apparatus 420. Thus, all of the equipment utilized in setting up the connection is rendered available for further use.

CALL FROM THE REMOTE EXCHANGE 30 TO A SUB-STATION SERVED BY THE C. A. X 60

In the event the above-described call routed by way of the operator's position 441 in the remote exchange 30 and extended to the toll transmission selector 300 is intended for a substation, such, for example, as the substation T3, served by the automatic switching equipment 413 of the C. A. X 60, the calling operator after initiating the call dials a first digit designating the group of toll switching selectors including the selector 700. In response to the impulses of this digit, the wipers 511 to 514, inclusive, of the toll transmission selector 300 are elevated to a position opposite the level of bank contacts at which are terminated the trunks incoming to the toll switching selectors of the indicated group. It will be observed that this selector, like the other selectors of the same group, is arranged for simplex control of the line relay R760 embodied therein. Accordingly, the normal post springs 396 of the switching mechanism 510 are disengaged to open a point in the operating and locking circuits for the relays R370, R360, R530 and R340, and the springs 395 are operated into engagement to prepare a circuit for energizing the simplex relay R320. This normal post switching operation occurs when the wipers of the switching mechanism 510 are positioned opposite the level of contacts in which the trunks of the desired group are terminated. At the end of the digit, the previously described automatic trunk hunting on the part of the toll transmission selector 300 is initiated with the result that the first idle toll switching selector of the selected group is seized. Assuming that the toll switching selector 700 is the first idle switch of this group, the trunk-hunting operation of the preceding toll transmission selector 300 is arrested when the wipers 511 to 514, inclusive, are operated into engagement with the bank contacts terminating the conductors of the trunk 705. When the trunk 705 is seized, the rotary movement of the wipers 511 to 514, inclusive, is arrested and the relay R550 operates to complete the prepared operating circuit for the simplex relay R320. This circuit extends from ground by way of the off-normal springs 525, the contacts 551, C389, the normal post springs 395 and the winding of R320 to battery. When energized over this circuit, the relay R320 operates and opens, at its contacts 325, a further point in the prepared operating circuit for the release magnet 523. At its contacts 326, the relay R320 connects the supervisory lead C454 to the extra control wiper 514. At its contacts 327, the relay R320 opens a

point in the previously traced path for impressing ground potential upon this wiper. At its contacts 321 and 323, the relay R320 opens two points in the previously traced simplex operating circuit for the line relay R535 of the toll transmission selector 300. At its contacts 322 and 324, the relay R320 connects the negative and positive trunk conductors C451 and C452 by way of the switch-through conductors C374 and C380, and the line wipers 511 and 512 to the talking conductors C706 and C707 of the trunk 705. Thus, the established simplex circuit originating in the toll line circuit 442 is extended through the toll transmission selector 300 to the toll switching selector 700. In response to this operation, the line relay R760 is energized and operates. More specifically, one branch of the simplex circuit, over which the relay R760 is energized following the switching-through operation of the toll transmission selector 300, extends by way of the grounded trunk conductor C451, the contacts 322, C374, the contacts 551, the wiper 511, C706, the contacts 751, the resistors 701 and 703, the contacts 755, the winding of R760 and the contacts 721 to battery. The other branch of this circuit extends by way of the grounded trunk conductor C452, the contacts 324, C380, the contacts 552, the wiper 512, C707, the contacts 753, the resistors 702 and 703, the contacts 755, the winding of R760 and the contacts 721 to battery.

It will be observed that the relay R320, in operating to complete the simplex operating circuit for the relay R760, in effect extends two arms of the previously described resistance bridge through the toll transmission selector 300 to include the talking conductors C706 and C707, respectively, of the trunk 705 and the resistors 701 and 702, respectively. These resistors have substantially the same resistance values and accordingly the balance of the bridge is maintained. Thus, the pad control relay R1330 is prevented from operating.

When energized over the above-traced simplex circuit, the relay R760 operates to complete, at its contacts 762, an obvious circuit for energizing the slow-acting hold relay R765. At its contacts 761, the relay R760 opens a point in the common portion of the operating circuits for the vertical and release magnets 715 and 720, respectively. At its contact 763, the relay R760 prepares a circuit for energizing the operating magnet 743 of the timing switch 740. The hold relay R765, upon operating, completes, at its contacts 766, an obvious multiple path for impressing ground potential upon the control conductor C707, thereby to complete a multiple holding circuit for the relay R550, and a multiple path for marking the trunk 705 as busy in the bank contacts of the toll transmission selectors having access thereto. More specifically, the multiple holding circuit for the relay R550 extends from ground by way of the contacts 766, C707, the wiper 513, the contacts 553, the winding of R550, the contacts 522, the winding of R570, C388, the off-normal springs 393, C384, and the contacts 524 to battery. At its contacts 761, the hold relay R765 prepares a path for impressing ground potential upon the supervisory lead C708. This supervisory lead is now connected by means of the wiper 514, the contacts 558, C501 and the contacts 326 to the supervisory lead C454 incoming to the toll transmission selector 300. At its contacts 768, the relay R765 opens a point in the operating circuit for the release magnet 720. At its contacts 769, the relay

R765 prepares the operating circuit for the vertical magnet 715 and a holding circuit for the relay R770. At its contacts 769', the relay R765 completes a circuit including the vertical off-normal springs 722 for energizing the lower winding of the slow-acting transfer relay R770. The relay R770, in turn, operates further to prepare, at its contacts 773, the operating circuit for the vertical magnet 713 and the holding circuit for itself. At its contacts 771, the relay R770 opens a point in one of the paths for impressing ground potential upon the supervisory lead C708. At its contacts 772, the relay R770 completes a path including the engaged cam or off-normal springs 729 for impressing ground potential upon the permanent supervisory lead C733. At its contacts 774, the relay R770 prepares the operating circuit for the automatic cut-in or test relay R780. At its contacts 775, the relay R770 opens a point in the operating circuit for the rotary magnet 718. Following the operation of the three relays R760, R765 and R770, the toll switching selector 700 is conditioned to respond to the impulses of the next digit dialed at the calling operator's position 441 in the remote exchange 30.

As indicated above, the relay R320, upon operating, opens two points in the previously traced circuit for energizing the line relay R535 of the toll transmission selector 300. In releasing, the relay R535 opens its contacts 537 to interrupt the operating circuit for the hold relay R545, and closes its contacts 538 further to prepare the operating circuit for the release magnet 523. The relay R545, upon restoring, opens its contacts 546 to interrupt the initially completed operating circuit for the relay R550, and to open a point in the common portion of the paths for impressing ground potential upon the permanent supervisory lead C231 and the control conductor C453 of the trunk 450. It will be noted that the relay R550 is held energized over the previously traced holding circuits which extend to ground through the operated contacts 766 of the hold relay R765 embodied in the toll switching selector 700 and through the operated contacts 1351 of the operated relay R1350 embodied in the toll line circuit 442. With the relay R550 operated, the simplex relay R320 is held energized.

The impulses of the second digit dialed at the calling toll operator's position 441 are utilized in the toll switching selector 700 for the purpose of elevating the wipers of this switch to a position opposite the level of bank contacts terminating the group of trunks in which the trunk 685 is included. These impulses are repeated to the line relay R760 of the toll switching selector 700 through the toll transmission selector 300 from the toll line circuit 442. More specifically, at the beginning of the open-circuit period of each impulse of the second digit, the above-traced simplex operating circuit for the line relay R760 is interrupted. This circuit is recompleted at the beginning of the closed-circuit period of each impulse and at the end of the digit. Upon restoring at the beginning of the open-circuit period of the first impulse transmitted thereto, the relay R760 completes the prepared operating circuit for the vertical magnet 715, this circuit extending from ground by way of the contacts 751', 761, 769 and 773, and the winding of the magnet 715 to battery. It will be noted that a branch of this circuit extends through the upper winding of the relay R770.

Accordingly, the relay R770 is energized in parallel with the vertical magnet 715 during the open-circuit period of each impulse transmitted to the toll switching selector 700. The vertical magnet 715, upon operating, elevates the wipers 711 to 714, inclusive, one step in response to each impulse repeated thereto by the line relay R760. When these wipers are moved to the first vertical off-normal position, the off-normal springs 722 are opened to interrupt the initially traced operating circuit for the relay R770; the off-normal springs 723 are closed to complete the operating circuit for the stepping or automatic cut-in relay R780; and the off-normal springs 724 are closed to prepare the operating circuit for the release magnet 720. The circuit for energizing the relay R780 extends from ground by way of the contacts 769' and 774, the off-normal springs 723, the winding of R780 and the contacts 721 to battery. When thus energized, the relay R780 operates to complete a locking circuit for itself which extends from ground by way of the contacts 751', 781 and 719, the off-normal springs 723, the winding of R780 and the contacts 721 to battery. At its contacts 782, the relay R780 further prepares the operating circuit for the rotary magnet 718. At its contacts 781, the relay R780 also completes a path for short-circuiting the test or switching-through relay R750, this path extending from ground by way of the contacts 751' and 781, the winding of R750, the off-normal springs 732 and the contacts 766 back to ground. Thus, the test relay R750 is prevented from operating when the transfer relay R770 subsequently releases. Due to the slow-to-release characteristics thereof, the relays R765 and R770 do not restore during impulsion.

When the wipers of the switching mechanism 710 are operated to a position opposite the level of bank contacts in which the trunk 685 is terminated, the normal post springs 727 are disengaged to open a point in the operating circuit for the ring-down relay R790 and the normal post springs 726 are moved into engagement to prepare one of the paths for impressing ground potential upon the supervisory lead C708. In the arrangement illustrated, the described normal post spring switching operations only occur when the wipers 711 to 714, inclusive, are elevated to a position opposite the level of bank contacts to which the trunk 685 and the other trunks of the same group extend.

Shortly following the end of the digit and with the line relay R760 occupying its operated position, the transfer relay R770 restores. Upon restoring, this relay disconnects the permanent supervisory lead C733 from ground and closes its contacts 771 to complete the above-mentioned path for impressing ground potential upon the supervisory lead C708. This path extends from ground by way of the contact springs 729, the contacts 771, the normal post springs 726, the contacts 767 and the contact springs 731 to the lead C708. When this lead is grounded, the supervisory relay R1310 operates to change the condition of the supervisory lamp provided at the operator's position 441 in association with the connection. At its contacts 773, the relay R770 opens a point in the above-traced circuit for transmitting impulses to its upper winding and the vertical magnet 715 in parallel. At its contacts 774, the relay R770 opens a point in the operating circuit for the stepping relay R780. At its contacts 775, the relay R770 completes the

prepared operating circuit for the rotary magnet 718, this circuit extending from ground by way of the contacts 768' and 775, the winding of the magnet 718 and the contacts 782 to battery.

When thus energized, the magnet 718 operates to rotate the wipers 711 to 714, inclusive, into engagement with the first set of contacts of the selected level, and opens its contacts 719 to interrupt the previously traced locking circuit for the relay R780. The operations which now occur depend upon whether the first trunk of the selected group is idle or busy. If this trunk is busy, ground potential is present upon the control conductor thereof, so that the test relay R750 is short-circuited over an alternative path, and an alternative path is prepared for energizing the stepping relay R780. In this regard it will be noted that the transfer relay R780, upon restoring, opens its contacts 782 to interrupt the circuit for energizing the rotary magnet 718. The above-mentioned alternative short-circuiting path may be traced as extending by way of the grounded wiper 713, the contacts 751, the winding of R750, the contact springs 732 and the contacts 766 back to ground. With the wiper 713 connected to ground, the relay R780 is energized over a circuit including this wiper and the contacts 757 and 719 in response to the release of the rotary magnet 718. Upon reoperating, the relay R780 recompletes the circuit for energizing the rotary magnet 718. The rotary magnet now functions to step the wipers 711 to 714, inclusive, into engagement with the bank contacts terminating the conductors of the second trunk in the selected group, and to again open the circuit for energizing the stepping relay R780. Thus, this relay and the rotary magnet 718 are sequentially deenergized coincident with the second step of the wipers 711 to 714, inclusive. In the event the second trunk is also busy, the operations just described are repeated. More specifically, the automatic trunk-hunting operation on the part of the wipers 711 to 714, inclusive, continues until an idle trunk of the selected group is found, or all of the trunks are tested and found to be in a busy condition.

Assuming that all of the trunks of the selected group are busy, the wipers of the switching mechanism 710 are rotated into their respective eleventh rotary off-normal positions, at which time the contact springs 729, 731 and 732 are respectively operated out of engagement and the contact springs 730 are moved into engagement. At the contact springs 732, a point is opened in the above-traced paths for short-circuiting the test relay R750. At the contact springs 729 and 731, the above-mentioned path for impressing ground potential upon the supervisory lead C708 is interrupted. When this supervisory lead is disconnected from ground the supervisory relay R1310 is deenergized and restores to again change the condition of the supervisory lamp associated with the connection at the operator's position 441. Thus, a flash signal is transmitted to the operator which informs her that she should listen for dial tone or that a flash busy-signal is to follow. At the contact springs 730, a path is completed for impressing ground pulses upon the supervisory lead C708, this path extending from the pulsing contacts of a pulsing generator, not shown, by way of the pulsing lead C734 and the contact springs 730 to the lead C708. These ground pulses, which are impressed upon the pulsing lead C734 at the approximate rate of 120 per minute, are repeated over the previously

traced path to the supervisory lead C454. As indicated previously, the application of ground pulses to this supervisory lead results in the operation of the relay R1310 to flash the supervisory lamp provided at the toll operator's position 441 in association with the trunk 440. Thus, the operator handling the call at this position is informed that an all-trunks-busy condition prevails at one of the intermediate switching stages and that the desired connection cannot be obtained until the all-trunks-busy condition is terminated. The manner in which the partially established connection is released under the control of the operator attending the position 441 is explained in detail hereinafter.

In connection with the all-trunks-busy condition considered above, it will be understood that the eleventh set of contacts in the selected level are not wired and, accordingly, when the control wiper 713 is moved into engagement with the control contact of the eleventh contact set in the selected level, no further circuit is available for energizing the stepping relay R780. Thus, the trunk-hunting operation of the toll switching selector 700 is arrested.

Assuming that the trunk 685 is the first idle trunk of the selected group, the idle condition thereof is indicated by the fact that the control conductor of the trunk is not connected to ground. Accordingly, when the wiper 713 is operated into engagement with the contact terminating the control conductor of this trunk, the path short-circuiting the winding of the test relay R750 is interrupted, permitting this relay to be energized in series with the stepping relay R780. The circuit for energizing these two relays in series extends from ground by way of the contacts 766, the contact springs 732, the winding of R750, the contacts 719, the off-normal springs 723, the winding of R780 and the contacts 721 to battery. The winding of the relay R750 is of relatively high resistance such that the relay R780 is insufficiently energized to reoperate when the circuit just traced is completed. Thus, the interrelated operation of the rotary magnet 718 and the stepping relay R780 is arrested. The relay R750 operates when energized in series with the relay R780 and opens, at its contacts 751', a point in the previously traced locking circuit for the relay R780 and a point in the initially established path for short-circuiting its own winding. At its contacts 759', the relay R750 further prepares another of the paths for impressing ground potential upon the supervisory lead C708. At its contacts 759 and 759', the relay R750 completes a connection between the supervisory lead C708 of the trunk 705 and the supervisory lead of the trunk 685 extending to the repeater 686. This connection extends from the lead C708 through the contact springs 731, the contacts 759', 786, 793 and 759, and the wiper 714 to the supervisory lead of the trunk 685. At its contacts 751, the relay R750 opens a further point in the previously traced alternative path for short-circuiting its own winding. At its contacts 758, the relay R750 connects the control conductor C707' of the trunk 705 through the control wiper 713 to the control conductor of the trunk 685, and, in so doing, completes a path including the contacts 766 for impressing ground potential upon the control conductor of the trunk 685. It will be understood that, when this conductor is grounded, the trunk 685 is marked as busy in the bank contacts of the other selector switches having access thereto. At its contacts 751 and 753,

the relay R750 opens two points in the above-traced simplex operating circuit for the relay R760.

At its contacts 752 and 754, the relay R750 extends the loop circuit over the talking conductors of the trunk 685 to the repeater 686. In response to this operation and the grounding of the control conductor of the trunk 685, the line and hold relays conventionally embodied in the repeater 686 operate to condition this repeater to respond to the impulses of additional digits dialed at the calling operator's position 441. In this regard it is pointed out that the operated relays of the two toll selector switches 700 and 300 are held energized over circuits commonly extending to ground through the contacts 1351 of the relay R1350, following the described switching-through operation of the toll switching selector 700.

As indicated above, the line relay R760 is de-energized and restores in response to operation of the test relay R750. The relay R760, in releasing, closes its contacts 761 further to prepare the operating circuit for the release magnet 720, and opens its contacts 762 to interrupt the operating circuit for the holding relay R765.

At its contacts 763, the relay R760 opens the prepared operating circuit for the operating magnet 743 of the timing switch 740. The relay R765, upon restoring, opens its contacts 769 further to interrupt the operating circuits for the relays R770 and R780 and the rotary magnet 718. At its contacts 769, the relay R765 opens a further point in the previously traced circuit for transmitting current pulses to the vertical magnet 715 in parallel with the upper winding of the relay R770. At its contacts 768, the relay R765 further prepares the operating circuit for the release magnet 720. At its contacts 766, the relay R765 opens one of the paths for grounding the control conductor C707' and the control conductor of the trunk 685. At its contacts 767, the relay R765 opens the path for impressing ground potential upon the supervisory lead C708. Thus, the relay R1310 is de-energized and restores to change the condition of the supervisory lamp associated with the connection at the operator's position 441. The single flash of this lamp produced incident to the vertical movement of the wipers 711 to 714, inclusive, and the release of the hold relay R765 informs the calling operator that she should wait for a dial tone signal before continuing the dialing operation. Following the release of the line and hold relays R760 and R765 of the toll switching selector 700, no further operation of the apparatus embodied in this selector occurs until the connection is released at the calling operator's position 441. In this regard it will be understood from the foregoing explanation that further impulses dialed at the operator's position 441 are transmitted through the operated toll selectors 300 and 700 to the repeater 686 terminating the seized trunk 685.

When the repeater 686 is seized over the trunk 685 in the manner set forth above, it functions to seize through a non-numerical switch embodied in the toll switching apparatus 430 one of the numerical switches of this apparatus. The response of the numerical equipment embodied in the toll switching apparatus 430 to the impulses repeated thereto through the repeater 686 from the calling operator's position 441 causes the connection to be routed over one of the interoffice trunks interconnecting the C. A. X. 60 with the central exchange 20 and

through the automatic switching equipment 413 to the desired line 411. For example, the trunk circuit 414 and the associated two-way trunk 415 may be utilized as the connecting link between the toll switching apparatus 430 and the automatic switching equipment 413 provided at the C. A. X. 60. When the connection is extended to the called line 411 through one of the connector switches forming a part of the automatic switching equipment 413, the line is tested to determine the idle or busy condition thereof, and, if busy, the usual busy tone signal is transmitted back over the connection to inform the calling operator attending the position 441 that the desired connection cannot be obtained. On the other hand, if the line is idle, ringing current is transmitted thereover to energize the signal device provided at the called substation T3, and the usual ring-back tone is transmitted over the calling end of the connection to signal the operator that the called substation is being rung. The desired conversational circuit between the calling line terminating at the remote exchange 20 and the called substation T3 is completed when the call is answered. In this regard it will be understood that the control relays of the repeater 686 function directly to control the supervisory relay R1310 to transmit supervisory signals to the toll operator's position 441. More specifically, these relays are arranged to impress ground potential upon the supervisory lead of the trunk 686, thereby to cause the transmission of an off-hook signal to the operator handling the call at the operator's position 441, when the call is answered at the called substation T3. These relays also function to impress ground pulses upon the supervisory lead of the trunk 685, thereby to produce a flashing recall signal at the toll operator's position 441, in response to intermittent operation of the switchhook provided at the substation T3 when the called subscriber desires to recall the operator attending the position 441. These relays also function to remove ground potential from the supervisory lead of the trunk 685, whereby a disconnect or on-hook supervisory signal is transmitted to the toll operator's position 441, when the called subscriber restores the receiver provided at the substation T3 to its supporting hook or cradle to terminate the call.

The release of the connection is entirely under the control of the operator attending the position 441. Thus, when the connection is cleared out at this operator's position, the control relays of the toll line circuit 442 are released in the manner previously explained. During the release of these relays, the loop circuit extending through the toll selectors 300 and 700 to the repeater 686 is interrupted. When this loop circuit is opened, the control equipment of the repeater 686 restores to normal. During the release of this equipment, the loop extending over the trunk 431 to the operated switches of the toll switching apparatus 430 is interrupted, causing these operated switches to restore in the usual manner. During the release of the last-mentioned switching equipment, the trunk circuit 414 is released and the operated switches of the automatic switching equipment 413 are caused to restore. When the toll line circuit 442 is released, ground potential is removed from the control conductors C453 and C707' of the toll selectors 300 and 700. When these conductors are disconnected from ground, the relay R750 of the toll switching selector 700, and the relays R320

and R550 of the toll transmission selector 300 are deenergized in an obvious manner. The relay R320, upon restoring, completes the previously traced operating circuit for the release magnet 523, whereby the toll transmission selector 300 is caused to release in the manner explained above with reference to the call routed to the substation T1.

The relay R750, upon restoring, completes the prepared operating circuit for the release magnet 720, this circuit extending from ground by way of the contacts 751', 761 and 768, the off-normal springs 724 and the winding of the magnet 720 to battery. When thus energized, the magnet 720 operates to attract its holding pawl, whereby the wipers 711 to 714, inclusive, are restored to rotary and vertical normal in the manner well understood in the art. When these wipers are restored to their respective home positions, the off-normal springs 724 are disengaged to deenergize the release magnet 720, the off-normal springs 722 are engaged to reprepare the operating circuit for the relay R770, and the off-normal springs 723 are moved out of engagement to open another point in the operating circuit for the stepping relay R780. Thus, the toll switching selector R700 is fully restored to normal.

CALL FROM THE REMOTE EXCHANGE 30 TO THE DISTANT EXCHANGE 40

In the event the above-described call originating at a line terminating at the remote exchange 30 and routed to the toll operator's position 441 requires the assistance of an operator in the distant exchange 40 in setting the desired connection, one of the group of ring-down trunks, such, for example, as the trunk 1105, is utilized in forwarding the connection from the central office to the distant exchange 40. More specifically, the call may be routed through the toll transmission selector 300 and the toll switching selector 700 to the access circuit 800 associated with the trunk 1105 in the exact manner described above with reference to the call routed to the C. A. X. 60. It is noted, however, that when the wipers of the toll switching selector 700 are elevated to a position opposite the level of bank contacts terminating the trunks extending to the group of access circuits including the circuit 800, the normal post springs 728 are operated into engagement to prepare a circuit for energizing the ring-down relay R790. In this case the normal post springs 727 and 726 remain in the positions illustrated in the drawings. The prepared operating circuit for the relay R790 is completed when the relay R770 releases shortly following the end of the series of impulses transmitted to the toll switching selector 700. This circuit extends from ground by way of the contact springs 729, the contacts 771, the normal post springs 727 and 728, and the winding of R790 to battery. Upon operating, the relay R790 closes its contacts 791 to prepare a simplex operating circuit for the timer reset relay R720. At its contacts 792, the relay R790 prepares a path for impressing ground potential upon the supervisory lead C708. At its contacts 793, the relay R790 opens a point in the above-traced connection between the supervisory wiper 714 and the supervisory lead C708. At its contacts 794, the relay R790 prepares a circuit for energizing the relay R785. Assuming that the access circuit 800 is idle and that this circuit is seized over the trunk 820 by the toll switching selector 700, the test relay R750

operates in the manner previously explained when the wipers 711 to 714, inclusive, are operated into engagement with the contacts terminating the conductors of the trunk 820. In operating, the relay R750 closes its contacts 752 and 754 to complete the prepared simplex operating circuit for the timer reset relay R720, and a paralleling simplex operating circuit for energizing the line relay R840 of the access circuit 800. One branch of this circuit extends by way of the grounded trunk conductor C451, the contacts 322, C314, the contacts 551, the wiper 511, C706 and the contacts 752 to C730 where it divides, one branch extending through the right winding of the retard coil 704, the resistor 738, the contacts 791 and the winding of R720 to battery, and the other branch extending by way of the wiper 711, the trunk conductor C821, the winding 811, the resistors 817 and 818, C825, the resistor 801 and the winding of R840 to battery. The second branch of the simplex circuit extends by way of the grounded trunk conductor C452, the contacts 324, C380, the contacts 552, the wiper 512, C707, and the contacts 754 to C731 where it divides, one branch extending by way of the left winding of the retard coil 704, the resistor 739, the contacts 791 and the winding of R720 to battery, and the other branch extending by way of the wiper 712, C822, the winding 812, the resistors 819 and 818, C825, the resistor 801 and the winding of R840 to battery. It is noted that the resistance values of the resistors 738, 739, 817 and 819 are so proportioned that the balance of the previously described resistance bridge is maintained when the two variable arms thereof are extended to include these resistors and the other enumerated circuit elements. Thus, the pad control relay R1330 is prevented from operating. When the relays R720 and R840 are energized over the above-traced simplex circuit they both operate.

The test relay R750, in operating, also prepares, at its contacts 759, a circuit for energizing the ringing relay R870 of the access circuit 800. At its contacts 751, 753 and 755, the relay R750 opens the previously traced operating circuit for the relay R760, thereby to cause the sequential release of the relays R760 and R785 in the manner previously explained. Following the release of these relays, the operated relays R750 and R550 are locked up over circuits commonly extending to ground through the contacts 1351 of the relay R1350. At its contacts 756, the relay R750 prepares a pulsing circuit to the relay R760. At its contacts 758, the relay R750 connects the control conductor C707 to the control wiper 713 which is now connected to the control conductor C823. At its contacts 759', the relay R750 completes a path including the contacts 792 and 786 for impressing ground potential upon the supervisory lead C708. This lead is now connected by way of the wiper 514, the contacts 558, the conductor C501 and the contacts 326 to the supervisory lead C454. The grounding of the lead C454 results in the transmission of an off-hook supervisory signal to the operator handling the call at the operator's position 441 in the manner previously explained.

The relay R720, upon operating, closes its contacts 721' to complete a circuit for energizing the relay R710, this circuit extending from ground by way of the contacts 716', the off-normal springs 746, the contacts 721' and the winding of R710 to battery. Upon operating, the relay R710 locks to ground over a path including the

contacts 721' and 711'. At its contacts 715', the relay R710 prepares a circuit for energizing the slow-to-operate timing control relay R795. At its contacts 716', the relay R710 opens a point in the circuit for energizing the release magnet 744. At its contacts 718', the relay R710 prepares the operating circuit for the magnet 743 of the timing switch 740. At its contacts 711', the relay R710 impresses ringing voltage upon the negative side of the connection extending to the calling operator's position 441 over a path which includes the ringing lead C736, the condenser 737 and the contacts 796. The current transmitted over this path to the calling end of the connection serves to signal the operator handling the call at the toll operator's position 441 that the called operator's position is being rung. At its contacts 713', the relay R710 opens a point in the operating circuit for the recall relay R785. At its contacts 712', the relay R710 completes the above-mentioned circuit for transmitting ground pulses to the line relay R760, this circuit extending from the pulse generator, not shown, by way of the pulsing lead C734, the contacts 797, 712' and 756, the winding of R760 and the contacts 721 to battery. These pulses, which are transmitted at a rate of approximately 120 per minute, are repeated by the line relay R760 to the operating magnet 743 of the timing switch 740 over a circuit including the contacts 763 and 718'. Thus, the stepping operation of the switch wiper 741 is initiated. When this switch wiper is moved off normal from the position illustrated in the drawings, the off-normal springs 746 are disengaged to open a point in the above-traced operating circuit for the relay R710, and the contacts 747 are moved into engagement to prepare the operating circuit for the release magnet 744.

The relay R710, in operating, also completes the above-mentioned circuit for energizing the ringing relay R870, this circuit extending from ground by way of the winding of R870, the contacts 856, C824, the wiper 714, the contacts 759, 794, 714' and 798, and the resistor 735 to battery.

As indicated above, the relay R840 is energized in response to operation of the test relay R750 to extend the simplex operating circuit to the access circuit 800. In operating, the relay R840 closes its contacts 841 to complete a circuit extending through the contacts 886 for energizing the lower winding of the line switching relay R880. When thus energized, the relay R880 locks to the grounded control conductor C823 through its preliminary make contacts 884, and then opens its contacts 886 to interrupt its operating circuit. At its contacts 885, the relay R880 completes an obvious path for impressing ground potential upon the supervisory lead C807. At its contacts 881 and 883, the relay R880 disconnects the line-balancing network comprising the condenser 806 and the resistor 805 from the repeating coil windings 813 and 814. At its contacts 882 and 884, the relay R880 connects the line terminals of the repeating coil windings 813 and 814 to the talking conductors C831 and C832 of the trunk 830 extending to the toll line circuit 1101.

When energized over the above-traced circuit, the ringing relay R870 operates to complete, at its contacts 871, a path including the contacts 882 for impressing ground potential upon the trunk conductor C831. At its contacts 873, the relay R870 connects the trunk conductor C832 to the negative terminal of the exchange battery over a path including the contacts 884 and the resistor 75

803. When ground and negative potentials are thus respectively impressed upon the trunk conductors C831 and C832, the ringing relay of the toll line circuit 1101 operates in a well-known manner to transmit ringing current over the trunk 1105 for the purpose of energizing the drop conventionally provided at the operator's position 1160 in association with this trunk. Thus, the operator attending the position 1160 is informed that a call is present on the trunk 1105 which should be answered.

As indicated above, the operating magnet 743 of the timing switch 740 is intermittently energized in response to the ground pulses repeated thereto by the relay R760. After four pulses are transmitted to this operating magnet, the wiper 741 is operated into engagement with its associated fourth contact to complete a circuit including the contacts 715' for energizing the slow-to-operate timing relay R795. When thus energized, the relay R795 opens its contacts 797 to interrupt the above-traced circuit for transmitting ground pulses to the line or pulsing relay R760. Thus, the stepping operation of the timing switch 740 is arrested. At its contacts 796, the relay R795 opens the previously traced path for impressing ringing voltage upon the negative side of the calling end of the connection, thereby to terminate the ring-back tone signal being transmitted to the operator handling the call at the toll operator's position 441. At its contacts 798, the relay R795 opens the previously traced circuit for energizing the ringing relay R870. At its contacts 799, the relay R795 further prepares the circuit for energizing the recall relay R785. The ringing relay R870, when deenergized in response to operation of the timing relay R795, restores to open its contacts 871 and 873 and thus disconnects the trunk conductors C831 and C832 from the positive and negative terminals of the exchange battery, respectively. In response to this operation, the ringing control relay of the toll line circuit 1101 restores to remove ringing voltage from the conductors of the trunk 1105, thereby to terminate the signal being transmitted to the toll operator's position 1160 in the distant exchange 40. In releasing, the ringing relay R870 also closes its contacts 872 to prepare the operating circuit for the alternating current recall relay R860. From the above explanation it will be apparent that a signal of limited duration is transmitted over the trunk 1105 to the toll operator's position 1160 in response to the operation of the toll switching selector 700 to seize the access circuit 800.

If the calling operator attending the position 441 in the remote exchange 30 desired to resign the called operator attending the position 1160 in the distant exchange 40, she may do so by momentarily opening the circuit including the trunk 440 over which dial pulses are transmitted to the toll line circuit 442. In response to this operation, the relay R1300 momentarily restores to open the previously traced simplex circuit over which the reset relay R720 is being held energized for a period equivalent in length to the open-circuit period of a dial pulse. The reset relay R720 and the simplex relay R840 are thus caused momentarily to restore. In releasing, the relay R720 opens its contacts 721' to interrupt the locking circuit for the relay R710. The release of the relay R840 is without effect. The relay R710, upon restoring, opens its contacts 715' to interrupt the operating circuit for the timing relay R795. The relay R795, upon re-

storing, closes its contacts 796 to reprepare the path for impressing ringing voltage upon the calling end of the connection; closes its contacts 797 to reprepare the circuit for transmitting ground pulses to the line relay R760; and closes its contacts 798 to reprepare the previously traced operating circuit for the ringing relay R870. At its contacts 716', the relay R710 completes the prepared operating circuit for the release magnet 744, this circuit extending from ground by way of the contacts 716', the off-normal springs 747, and the winding of the magnet 744 to battery. When energized over this circuit, the release magnet 744 attracts its holding pawl, permitting the wiper 741 to be returned to its normal or home position, at which time the off-normal springs 747 are disengaged to deenergize the release magnet 744 and the off-normal springs 746 are again operated into engagement. During the return movement of the wiper 741, a further point is opened in the operating circuit for the timing relay R795. By the time the wiper 741 is returned to normal, the reset relay R720 is again energized so that the operating circuit for the relay R710 is reprepared at the contacts 721'. Accordingly, when the off-normal springs 746 are moved into engagement, the previously traced operating circuit for the relay R710 is completed. The relay R710, upon operating, closes its contacts 711' to recomplete the path for impressing ringing voltage upon the calling end of the connection; closes its contacts 712' to recomplete the above-traced circuit for transmitting ground pulses to the line relay R760; closes its contacts 714' to recomplete the operating circuit for the ringing relay R870; closes its contacts 715' to reprepare the operating circuit for the timing relay R795; opens its contacts 716', thereby further to interrupt the circuit for energizing the release magnet 744; locks to ground through its contacts 717'; and closes its contacts 718' to recomplete the pulsing circuit to the operating magnet 743. Thus, a second timing operation on the part of the timing switch 740 is initiated. The ringing relay R870, upon reoperating, again impresses positive and negative battery potentials upon the trunk conductors C831 and C832, respectively. When these potentials are reapplied to the talking conductors of the trunk 830, the ringing control relay embodied in the toll line circuit 1101 again operates to impress ringing voltage upon the conductors of the trunk 1105. Thus, a second signal is transmitted over this trunk to the toll operator's position 1160. At the end of the timing operation of the timing switch 740, the relay R795 is caused to operate to interrupt the circuit for energizing the ringing relay R870 and to arrest the operation of the timing switch 740 in the manner explained above. The relay R870, in releasing, opens the circuit for energizing the ringing control relay of the toll line circuit 1101, causing the latter relay to restore and disconnect ringing voltage from the conductors of the trunk 1105. From the above explanation it will be apparent that the calling operator attending the position 441 may resignal the called operator attending the position 1160 at will by the simple expedient of momentarily opening the dial pulse circuit extending over the trunk 440 to the toll line circuit 442. The manner in which the ringing control equipment embodied in the toll switching selector 700, the access circuit 800 and the toll line circuit 1101 responds to each momentary interruption of the dial pulse circuit

extending from the operator's position 441 over the trunk 440 to the toll line circuit 442 is exactly the same as set forth above.

After the call as extended to the toll operator's position 1160 in the distant exchange 40 is answered by the operator attending this position, it may be extended to the desired subscriber line in the manner usually followed in manual office practice. It will be understood that after the connection is established in the manner explained above between these two operators' positions, it may be held for an extended period of time and used in setting up a large number of toll connections between subscriber lines respectively terminating at the exchanges 30 and 40. It is desirable, therefore, that the above-described facilities be provided whereby the operator attending the position 441 may resignal the operator attending the position 1160. It is also desirable to provide facilities whereby the called operator attending the position 1160 may resignal the calling operator attending the operator's position 441. In the arrangement illustrated, the operator attending the position 1160 may resignal the calling operator attending the position 441 by operating the ringing key of the cord circuit in use at the operator's position 1160 to transmit ringing current over the trunk 1105, through the toll line circuit 1101, over the trunk 830 and through the winding of the alternating current relay R860. In this regard it will be noted that the winding of this relay is normally bridged across the talking conductors C831 and C832 of the trunk 830 in series with the condenser 802 and the contacts 882, 884 and 872. When energized by ringing current transmitted thereto over the called end of the connection, the relay R860 operates to complete, at its contacts 861, an obvious circuit for energizing the slow-acting cut-off relay R850. Upon operating, the relay R850 disconnects the line terminals of the repeating coil windings 813 and 814 from the trunk conductors C831 and C832 to interrupt the established communication connection. At the contacts 852 and 854, the balancing network comprising the condenser 806 and the resistor 805, and which in effect constitutes an artificial line, is bridged across the series connected repeating coil windings 813 and 814 to prevent the unbalancing of the vacuum tube repeaters associated with the trunk 440. At its contacts 856, the relay R850 opens a point in the previously traced operating circuit for the ringing relay R870. At its contacts 855, the relay R850 completes the above-mentioned circuit for energizing the recall relay R785 of the toll switching selector 700. This circuit extends from ground by way of the winding of R785, the contacts 799, 714', 794 and 759, the supervisory wiper 714, C824, the contacts 855 and the resistor 804 to battery. The relay R785, upon operating, opens its contacts 786 to interrupt the previously traced path for impressing ground potential upon the supervisory lead C708. When this supervisory lead is disconnected from ground, an on-hook supervisory signal is transmitted to the toll operator's position 441 in the manner previously explained. It will be understood from the above explanation that when the called operator attending the position 1160 restores her ringing key to normal to remove ringing voltage from the conductors of the trunk 1105, the recall relay R860 is deenergized and restores to open the operating circuit for the relay R850. The relay R850, upon restoring, disconnects the repeating coil windings

813 and 814 from the line balancing network comprising the condenser 806 and the resistor 805, and reconnects these windings to the talking conductors of the trunk 830, thereby to recomplete the communication connection between the calling and called operators' positions. At its contacts 855, the relay R850 opens the above-traced operating circuit for the recall relay R785. The relay R785, upon restoring, recompletes the above-traced path for impressing ground potential upon the supervisory lead C708, whereby an off-hook supervisory signal is transmitted to the operator's position 441. In view of the above explanation it will be apparent that the relays R860, R850 and R785 function to flash the supervisory lamp associated with the trunk 440 at the operator's position 441 each time the ringing key of the operator's cord circuit in use at the toll operator's position 1160 is operated to the ringing position and then restored to normal. This flashing signal serves to inform the operator attending the position 441 that she is being recalled from the called operator's position 1160 in the distant exchange 40.

As indicated above, the release of the operated switching equipment in the central exchange 20 is under the control of the operator attending the position 441 in the remote exchange 30. Thus, when the connection is cleared out at the operator's position 441 in the remote exchange 30, the toll line circuit 442 is restored to normal. During the release of this circuit ground potential is removed from the connected control conductors C453, C707' and C823 and the simplex circuit over which the relays R720 and R840 are being held energized is interrupted. The relay R720, in restoring, causes the release of the timing equipment comprising the rotary switch 740, the relay R710 and the relay R795 in the manner explained above. The release of the simplex relay R840 included in the access circuit is without effect. When the control conductors C453 and C707' are disconnected from ground the release of the toll selectors 300 and 700 is initiated in the manner previously described. When ground potential is removed from the conductor C823, the relay R880 is deenergized and restores. Following the release of the relay R880, the access circuit 800 is fully restored to normal. The removal of ground potential from the control conductor C823 serves to mark the circuit 800 as idle in the bank contacts of the selectors having access thereto. During the release of the toll selector 700 and when wipers of the switching mechanism 710 are returned to their respective normal positions, the vertical off-normal springs 724 are disengaged to interrupt the operating circuit for the release magnet 710; the off-normal springs 722 are engaged to reprepare the operating circuit for the transfer relay R770; and the off-normal springs 723 are moved out of engagement to open a point in the operating circuit for the stepping relay R780. In addition, the normal post springs 728 are disengaged to cause the deenergization and release of the ring-down relay R790. Following the release of this relay, the toll switching selector 700 is fully restored to normal. In this regard it will be noted that with the switching mechanism 710 and all of the control relays of the selector 700 at normal, the control lead C707' is disconnected from ground, thereby to identify this selector as idle in the bank contacts of the toll transmission selectors having access thereto. The manner in which the toll transmission selec-

tor 300 is released in response to the deenergization and release of the line-switching relay R550 is exactly the same as described previously with reference to the call routed to the substation T2.

5 CALL FROM THE REMOTE EXCHANGE 30 TO THE INFORMATION OPERATOR'S POSITION 1153

If the above-described call, originating on a line served by the remote exchange 30 and routed by way of the toll operator's position 441, the trunk 440, the toll line circuit 442 and the toll transmission selector 300 to the toll switching selector 700, is intended for the information operator's position 1153, the calling operator attending the position 441 in the remote exchange 30 will dial a second digit designating the group of access circuits which includes the circuit 900. Assuming that the access circuit 900 is the first idle circuit of the selected group, this circuit is seized by the toll switching selector 700 and the trunk-hunting operation of the selector is arrested when the wipers 711 to 714, inclusive, are positioned in engagement with the contacts terminating the conductors of the trunk 920. Incident to the seizure of the access circuit 900, the toll switching selector 700 switches through in the manner previously described and extends the simplex circuit branches to the talking conductors C921 and C922 of the trunk 920, thereby to energize the simplex relay R960. One branch of the simplex operating circuit for this relay may be traced as extending from the grounded trunk conductor C451 by way of the contacts 322, C374, the contacts 551, the wiper 511, C706, the contacts 752, C730, the wiper 711, C921, the contacts 951, the winding 911, the resistors 917, 918 and 926, and the winding of R860 to battery. The other branch of this circuit extends by way of the grounded trunk conductor C452, the contacts 324, C380, the contacts 552, the wiper 512, C707, the contacts 754, C731, the wiper 712, C922, the contacts 953, the winding 912, the resistors 919, 918 and 926, and the winding of R960 to battery. The resistance values of the resistors 917, 918 and 919 are so proportioned that the balance of the above-described resistance bridge is maintained, thereby to prevent the pad control relay R1330 embodied in the toll line circuit 442 from operating. Following the operation of the test relay R750, this relay and the relay 50 R550 of the toll selector 300 are held energized over circuits commonly extending to ground through the contacts 1351 of the relay R1350. Thus, the toll selectors 300 and 700 are prevented from releasing and ground potential is maintained on the connected control conductors C453, C707' and C923.

The relay R960, upon operating, closes its contacts 961 to complete a circuit including the contacts 974 for energizing the lower winding of the slow-to-operate relay R970 and a parallel circuit including the contacts 975 for energizing the lower winding of the relay R980. As indicated above, incident to the seizure of the access circuit 900, ground potential is impressed upon the control conductor C923 through operation of the switch-through or test relay R750 embodied in the toll switching selector 700. This ground is forwarded through the contacts 955 and 993 to the control conductor C943 of the trunk 940 and serves to energize the base lamp 1207 provided at the information operator's position 1153 in association with the trunk 940. The application of ground potential to the control conductor 75 C923 also serves to guard the access circuit 900.

against seizure by the other toll switching selectors having access thereto.

The digit absorbing relay R980, upon operating, locks to ground over a path including its preliminary make contacts 983 and closes its contacts 982 to complete an obvious circuit for energizing the slow-acting control relay R930. At its contacts 981, the relay R980 opens a point in the circuit for energizing its own upper winding. At its contacts 984, the relay R980 opens a point in the circuit for energizing the answer lamp 1206 in series with the signal control relay R1200. At its contacts 985, the relay R980 opens a point in an alternative circuit for energizing the answer lamp 1206.

The slow-to-operate relay R970, upon operating, first locks to the grounded control conductor C923 over a circuit including its upper winding, the preliminary make contacts 973 and the contacts 955. After this locking circuit is completed, the relay R970 opens its contacts 974 to interrupt its initially completed operating circuit. At its contacts 975, the relay R970 opens a point in the above-traced operating circuit for the digit absorbing relay R980. At its contacts 978, the relay R970 prepares the above-mentioned alternative circuit for energizing the answer lamp 1206. At its contacts 971, the relay R970 prepares a path for impressing ringing voltage upon the calling end of the connection. At its contacts 977, the relay R970 opens a point in the operating circuit for the night transfer relay R950. At its contacts 976, the relay R970 completes an obvious circuit for energizing the slow-to-operate switching relay R990. At its contacts 972, the relay R970 completes a circuit for energizing the ring-back relay R965, this circuit extending from ground by way of the contact springs 1219 and 1218, C944, the winding of R965 and the contacts 972 to battery. The relay R965, upon operating, opens, at its contacts 967, a point in the path for impressing ground potential upon the supervisory lead C924. At its contacts 968, the relay R965 further prepares the above-mentioned path for impressing ringing voltage upon the calling end of the connection. At its contacts 969, the relay R965 opens another point in the above-mentioned alternative circuit for energizing the answer lamp 1206. The slow-to-operate switching relay R990, upon operating, closes its contacts 991 and 992 to connect the line terminals of the repeating coil windings 913 and 914 to the talking conductors C941 and C942 of the trunk extending to the information operator's position 1153. At its contacts 993 and 994, the relay R990 disconnects the control lead C943 from the control conductor C923 and connects this lead to ground, thus completing an alternative circuit for energizing the busy lamp 1201. At its contacts 995, the relay R990 prepares the above-mentioned path for impressing ground potential upon the supervisory lead C924. At its contacts 996, the relay R990 prepares the above-mentioned circuit for energizing the upper winding of the digit absorbing relay R980. The slow-acting relay R930, in operating, opens, at its contacts 931, a further point in the circuit for energizing the upper winding of the relay R980.

As indicated by the above explanation, provisions are made in the access circuit 900 for absorbing any excess digits dialed at the calling operator's position and not required in order to

route a connection to the information operator's position 1153. Thus, in the case under consideration, if the calling operator attending the position 441 in the remote exchange 30 dials an additional digit following the seizure of the access circuit 900 in the manner explained above, the simplex relay R960 follows the impulses. The control equipment of the access circuit 900 responds to the impulse or impulses of this digit by operating to complete the circuit for energizing the answer lamp 1206. More specifically, when the relay R960 restores at the beginning of the open-circuit period of the first impulse transmitted to the access circuit 900, the above-traced locking circuit for the digit absorbing relay R980 is interrupted at the contacts 961. The relay R980, upon restoring, further opens its locking circuit at the contacts 983. At its contacts 981, the relay R980 further prepares the above-mentioned circuit for energizing its upper winding. At its contacts 982, the relay R980 opens the operating circuit for the control relay R930. At its contacts 985, the relay R980 further prepares the above-mentioned alternative circuit for energizing the answer lamp 1206. At its contacts 984, the relay R980 completes the prepared circuit for energizing the signal control relay R1200 in series with the answer lamp 1206. This circuit extends from ground by way of the contacts 994, C943, the contact springs 1214, C946, the contacts 984, C945, the filament of the lamp 1206, the contact springs 1215 and the two windings of R1200 in series to battery. At its contacts 981', the relay R980 completes the above-mentioned path for impressing ringing voltage upon the calling end of the connection. This path may partially be traced as extending from one terminal of the ringing current generator by way of the conductor C902, the condenser 903, and the contacts 966, 981', 971 and 951 to the negative side of the partially completed connection. This voltage is reproduced by the receiver provided in the operator's cord circuit in use at the operator's position 441, and the resulting tone serves to inform the calling operator that the called operator is being signaled. It will be observed that following the release of the digit absorbing relay R980, further operation of the simplex relay R960 in response to further impulses dialed at the calling operator's position 441 is without effect. The relay R930, upon restoring, recloses its contacts 931 to reprepare the circuit for energizing the upper winding of the relay R980.

The relay R1200, upon operating, closes its contacts 1201 to complete an obvious path for short-circuiting its high resistance, lower winding, thereby to increase the energization of the answer lamp 1206. At its contacts 1202, the relay R1200 completes an obvious circuit for energizing the buzzer 1203, providing the key 1204 occupies its normal position. The audible signal produced by the buzzer 1203 and the illuminated condition of the lamp 1206 serve to inform the operator attending the position 1153 that a call is present upon the trunk 940 which should be answered. In order to terminate the operation of the buzzer 1203, the operator may actuate the key 1204 to its off-normal position to interrupt the operating circuit for this buzzer in an obvious manner. In order operatively to associate the telephone set 1210 with the trunk 940, the operator attending the position 1153 may actuate the talk and hold key 1211

to its talk position. In response to this operation of the key 1211, the contact springs 1212 and 1213 are respectively operated into engagement to bridge the operator's telephone set 1210 across the talking conductors C941 and C942 of the trunk 940 in series with the condensers 1208 and 1209. Thus, a communication connection is established between the operator's telephone set 1210 and the telephone set in use by the calling operator attending the position 441. When the key 1211 is thrown to the talk position, the contact springs 1214 are disengaged to open the above-traced circuit for energizing the answer lamp 1206 in series with the signal control relay R1200. These two elements are thus deenergized. The relay R1200, upon restoring, opens its contacts 1201 to interrupt the path short-circuiting its lower winding, and opens its contacts 1202 to interrupt the above-traced operating circuit for the buzzer 1203. The contact springs 1216 are operated into engagement and the contact springs 1218 are disengaged when the key 1211 is operated to its talk position. At the contact springs 1216, an obvious alternative circuit is completed for energizing the busy lamp 1207. At the contact springs 1218, the previously traced operating circuit for the ring-back relay R965 is interrupted. The relay R965 now restores to open its contacts 966 and thus interrupt the above-traced path for impressing ringing voltage upon the calling end of the connection. At its contacts 968, the relay R965 completes the above-mentioned alternative circuit for energizing the relay R980, this circuit extending from ground by way of the contacts 981, 968, 996 and 931, and the upper winding of R980 to battery. At its contacts 969, the relay R965 reprepares the above-mentioned alternative circuit for energizing the answer lamp 1206. At its contacts 967, the relay R965 completes the above-mentioned path for impressing ground potential upon the supervisory lead C924. When this lead is grounded, the supervisory relay R1310 of the toll line circuit 442 is energized over a circuit which may be traced as extending from this lead by way of the wiper 714, the contacts 759, 793, 786 and 759', the contact springs 731, C708, the wiper 514, the contacts 558, C501, the contacts 326, C454 and the winding of R1310 to battery. Upon operating, the relay R1310 transmits an off-hook supervisory signal to the operator's position 441 in the manner previously explained.

As indicated above, the absorbing relay R980 is energized in response to the release of the ring-back relay R965. In operating, the relay R980 again locks to ground through its contacts 983 and the operated contacts 981, following which it opens its contacts 981 to interrupt the above-traced circuit for energizing its upper winding. At its contacts 982, the relay R980 recompletes the operating circuit for the control relay R930, which latter relay, in operating, opens a further point in the circuit for energizing the upper winding of the relay R980. At its contacts 984, the relay R980 opens a further point in the circuit for energizing the answer lamp 1206 in series with the windings of the relay R1200. At its contacts 985, the relay R980 opens a point in the alternative circuit for energizing the answer lamp 1206. At its contacts 981', the relay R980 opens a further point in the above-traced path for impressing ringing voltage upon the negative side of the connection extending to the call-

ing operator's position. Following the operations just described, the calling operator attending the position 441 may converse with the information operator attending the position 1153 and obtain the desired information. In this regard it will be understood that current for energizing the transmitter embodied in the operator's telephone set 1210 is supplied through the windings of the battery feed coil 1205.

10 If the operator attending the position 1153 desires to hold the call while disposing of other duties, she may operate the key 1211 to the hold position wherein the contact springs 1215, 1212, 1213, 1216 and 1219 are respectively disengaged, and the contact springs 1214, 1218 and 1220 are operated into engagement. At the contact springs 1220, an obvious alternative circuit is completed for energizing the busy lamp 1207, whereby the operator attending the position 1153 is continuously reminded that an unanswered or undisposed-of-call is present on the trunk 940. At the contact springs 1215, the previously traced circuit for energizing the answer lamp 1206 in series with the relay R1200 is interrupted to cause the deenergization of these circuit elements, if energized. At the contact springs 1219, a point is opened in the previously traced circuit for energizing the ring-back relay R965, thereby to cause the release of this relay, if operated.

20 If the key 1211 is operated to the hold position after the call has been answered, the opening of the contacts 1215 and 1219 is without effect since the functions normally accomplished by the engagement of these contact springs have already occurred in response to operation of the key 1211 to the talk position. On the other hand, if the key 1211 is operated to the hold position immediately the call is received and before it is acknowledged, the relay R965 is deenergized to

30 perform the functions previously described, among which are the termination of the ring-back tone signal being transmitted to the calling operator's position, and the transmission of a supervisory signal to the calling operator's position indicating that the call has been received.

40 45 If the operator attending the position 441 desires to recall the information operator at the position 1153, she may do so by momentarily opening the dialing circuit, thereby to transmit a pulse to the line relay R1300. This pulse is repeated by the line relay R1300 over the simplex circuit extending through the selectors 300 and 700 to the simplex relay R960. The relay R960 restores and reoperates in response to this impulse. Upon restoring, the relay R960 opens the locking circuit for the relay R980. The relay R980, in turn, releases to open its contacts 983, thereby further to interrupt its locking circuit. Thus, the relay R980 remains in its restored position following the reoperation of the simplex relay R960. In restoring, the relay R980 also completes one of the two available circuits for energizing the answer lamp 1206, and opens the circuit for energizing the control relay R930.

50 55 If the key 1211 occupies its hold position at the time the relay R980 restores, the above-mentioned alternative circuit for energizing the answer lamp 1206 is completed, this circuit extending from ground by way of the contacts 994, C943, the contact springs 1214, C946, the contacts 984, C945, the filament of the lamp 1206, C947, the contacts 989, 985 and 978, C948 and the two windings of R1200 in series to battery. Thus, the lamp 1206 is energized to signal the operator attending the position 1153. Shortly

60 65 70 75

following the release of the relay R980, the slow-acting control relay R930 releases to again complete the circuit for energizing the upper winding of the relay R980. The relay R980 accordingly reoperates, locks to ground, recompletes the operating circuit for the relay R930, and opens its contacts 985 to interrupt the above-traced alternative circuit for energizing the answer lamp 1206. Thus, the lamp 1206 is momentarily flashed, this flash serving to indicate to the operator attending the position 1153 that she is being recalled. Obviously, the control operations just described are repeated each time the calling operator momentarily interrupts the dialing circuit extending to the line relay R1300 of the toll line circuit 442.

If the information operator attending the position 1153 has disconnected at the time the recall signal is transmitted by the calling operator to cause the release of the relay R980 in the manner explained above, the ring-back relay R965 occupies its operated position. Accordingly, the relay R980, upon restoring, recompletes the path for transmitting ringing current over the calling end of the connection, and recompletes the initially traced circuit for energizing the answer lamp 1206. Thus, the access circuit 900 and the information operator's position circuit equipment are restored to the condition which prevails just prior to the answering of a call routed to the position 1153.

In the event the talk and hold key 1211 occupies its talk position at the time the recall signal is transmitted to the access circuit 900 from the calling operator's position, the relays R980 and R930 cooperate momentarily to energize the answer lamp 1206 in the exact manner described above with reference to the recall signal transmitted to the access circuit 900 at a time when the key 1211 occupies its hold position.

If the information operator attending the position 1153 desires to recall the operator attending the position 441, she may do so by repeatedly operating the key 1211 between its talk and normal positions. In response to each operation of the key 1211 to its normal position, the ring-back relay R965 is energized over its operating circuit as traced above. This circuit is obviously interrupted at the contact springs 1218 each time the key 1211 is reoperated to the talk position. Thus, the relay R965 intermittently operates to complete the previously traced circuit for energizing the supervisory relay R1310 of the toll line circuit 442. The supervisory relay R1310, in following the current pulses transmitted thereto, causes the supervisory signal lamp provided at the calling operator's position 441 to flash in the manner previously pointed out. This flashing signal serves to inform the calling operator that she is being recalled from the information operator's position 1153.

The release of the connection established between the operator's position 441 and the information operator's position 1153 is entirely under the control of the calling operator. Thus, when the connection is cleared out at the operator's position 441, the toll line circuit 442 is released in the manner previously explained. During the release of this circuit, the relay R1350 is deenergized and restores to disconnect the control conductor C453 from ground. In response to this operation, the toll transmission selector 300 and the toll switching selector 700 are restored to normal in the manner previously described. During the release of the toll line circuit 442, the

two branches of the simplex operating circuit for the relay R960 are opened, thereby to cause the deenergization and release of this relay, the relay R980 and the relay R930. When ground potential is removed from the control conductor C453 and incident thereto the control conductor C923, the relay R970 is also deenergized. This relay, in restoring, opens its contacts 972 and 976 to interrupt the respective operating circuits for the relays R965 and R990. Thus, all the relays embodied in the access circuit 900 are restored to normal, and this circuit is conditioned for further use. It will be noted that if the connection is cleared out at the calling operator's position before it is released at the information operator's position 1153, ground potential is retained upon the control conductor C923 of the trunk 920 to mark this trunk as busy over a path which extends from ground by way of the contact springs 1216 or 1220, depending upon the position of the key 1211, C943 and the contacts 993 and 955. Thus, the access circuit 900 is guarded against seizure until the talk and hold key 1211 is restored to normal. It will also be observed that if the talk and hold key 1211 is restored to normal prior to the release of the connection at the calling operator's position 441, the previously traced operating circuit for the ring-back relay R965 is recompleted. This relay, in operating, opens the previously traced operating circuit for the supervisory relay R1310, whereby the previously described disconnect or on-hook supervisory signal is transmitted to the calling operator's position. After receiving the signal, the calling operator may release the connection in the manner just explained.

Night transfer

As indicated in the introductory portion of the specification, provisions are made in the access circuit 900 for transferring calls normally handled at the information operator's position 1153 to the delay operator's position 1154 or another of the delay operator's positions provided at the operator's switchboard in the central exchange 20 during those intervals when the information operator's position 1153 is not attended. To this end the operator on duty at the position 1153, before leaving this position, operates the night key 1221 to its off-normal position to complete a circuit including the conductor C901 and the contacts 977 for energizing the night transfer relay R950. The key 1221 is of the locking type, and, accordingly, remains in its off-normal position until manually restored to normal. It will be observed that in the event the access circuit 900 is occupied with a call at the time the key 1221 is thrown to its off-normal position, the operating circuit for the night transfer relay R950 is held open at the contacts 977. Thus, the information operator on duty at the position 1153 must dispose of the call present on the trunk 940 before operating the night key 1221 to its off-normal position. When energized over the above-traced circuit, the night transfer relay R950 operates and locks to the grounded lead C901 through its contacts 959. At its contacts 951 to 958, inclusive, the relay R950 disconnects the conductors of the trunk 920 from the access circuit 900, and connects these conductors to corresponding conductors of the trunk 1020 incoming to the access circuit 1000 associated with the delay operator's position 1154. Thus, so long as the night transfer relay R950 is operated, all calls routed to the trunk 920 are extended.

through the access circuit 1000 to the delay operator's position 1154. The manner in which this is accomplished is explained in a following portion of the specification.

CALL FROM THE REMOTE EXCHANGE 30 TO THE
DELAY OPERATOR'S POSITION 1154

In the event the above-described call routed to the toll switching selector 700 from the toll operator's position 441 in the remote exchange 30 is a toll call requiring the assistance of the delay operator attending the operator's position 1154 for completion, the calling operator attending the position 441 will dial a second digit designating the group of access circuits including the circuit 1000. In this case, the normal post springs 726, 727 and 728 remain in the positions illustrated in the drawings. At the end of the digit, the trunk-hunting operation of the toll switching selector 700 is initiated in the manner previously explained. Assuming that the access circuit 1000 is the first idle circuit of the selected group, the trunk-hunting operation of the toll switching selector 700 is arrested when the wipers 711 to 714, inclusive, are positioned in engagement with the bank contacts terminating the conductors of the trunk 1020. At this time, the switching-through or test relay R750 operates to extend ground potential over the line wipers 711 and 712 to the talking conductors C1021 and C1022 of the trunk 1020. In operating, the relay R750 also connects the grounded control lead C707' through the control wiper 713 to the control conductor C1023 of the trunk 1020, and completes a path for connecting the supervisory lead C1024 of the trunk 1020 back to the supervisory lead C454 of the trunk 450 incoming to the toll transmission selector 300. This path extends from the conductor C1024 by way of the wiper 714, the contacts 759, 793, 786 and 759', the contact springs 731, C708, the wiper 514, the contacts 558, C501 and the contacts 326 to the supervisory lead C454. The relay R750, in operating, also initiates the release of the relays R760 and R765 in the manner previously explained. Following the release of these two relays, the operated relays of the toll selectors 300 and 700 are held energized over circuits commonly including the engaged contacts 1351 of the relay R1350, and the connected control conductors C453, C707' and C1023 are connected to ground through these contacts.

When the talking conductors C1021 and C1022 of the trunk 1020 are connected to ground, the simplex relay R1055 is energized over a circuit, one branch of which extends from the grounded lead C1021 by way of the contacts 1031, the repeating coil winding 1011, the resistors 1017, 1018 and 1004, and the winding of R1055 to battery. The other branch of the operating circuit for the relay R1055 extends from the grounded trunk conductor C1022 by way of the contacts 1033, the repeating coil winding 1012, the resistors 1019, 1018 and 1004, and the winding of R1055 to battery. The resistance values of the resistors 1017, 1018 and 1019 are so proportioned that the balance of the previously described resistance bridge is maintained when the two variable arms thereof are extended to include these resistors and the other circuit elements enumerated above. Accordingly, the pad control relay R1330 embodied in the toll line circuit 442 is not energized.

The relay R1055, upon operating, closes its contacts 1056 to complete a circuit including the contacts 1079 for energizing the slow-to-operate

hold relay R1070, and to complete a circuit including the contacts 1079' for energizing the upper winding of the relay R1080. The relay R1080, upon operating, locks to ground over a circuit including its lower winding, the preliminary make contacts 1085 and the contacts 1056. At its contacts 1081, the relay R1080 opens a point in the path for impressing ringing voltage upon the calling end of the connection. At its contacts 1082, the relay R1080 prepares a path for impressing ground potential upon the supervisory lead C1024. At its contacts 1083 and 1084, the relay R1080 opens a point in an alternative circuit for energizing its upper winding, and prepares a circuit for energizing the upper winding of the disconnect relay R1090. At its contacts 1086, the relay R1080 opens a point in one of the operating circuits for the line lamp 1193 provided at the delay operator's position 1154. At its contacts 1087, the relay R1080 opens a point in an alternative circuit for energizing the line lamp 1193.

The slow-to-operate relay R1070, upon operating, locks to the grounded control conductor C1044 over a circuit including its preliminary make contacts 1076 and the contacts 1094. After this locking circuit is completed, the relay R1070 further locks to the grounded control conductor C1044 through its contacts 1075. At its contacts 1079, the relay R1070 opens a point in its operating circuit as traced above. At its contacts 1071, the relay R1070 prepares the above-mentioned path for impressing ringing voltage upon the calling end of the connection. At its contacts 1072 and 1073, the relay R1070 connects the line terminals of the repeating coil windings 1013 and 1014 to the talking conductors C1041 and C1042 of the trunk 1040. At its contacts 1077, the relay R1070 further prepares the above-mentioned circuit for energizing the disconnect relay R1090. At its contacts 1078, the relay R1070 opens a point in the operating circuit for the night transfer relay R1030. At its contacts 1079', the relay R1070 interrupts the previously traced operating circuit for the relay R1080.

With the wiring arrangement illustrated, any further digits dialed at the calling operator's position 441 following seizure of the access circuit 1000 in the manner explained above are absorbed. Thus, if the operator continues to dial after this circuit is seized, the simplex relay R1055 follows the impulses and alternately restores and re-operates to open and close its contacts 1056. When this relay restores at the beginning of the open-circuit period of the first additional impulse, it opens its contacts 1056 to interrupt the above-traced locking circuit for the relay R1080. The relay R1080, accordingly, restores and opens its contacts 1085 further to interrupt its locking circuit. At its contacts 1084, the relay R1080 reprepares the above-mentioned alternative operating circuit for itself. At its contacts 1082, the relay R1080 opens a point in the above-mentioned path for impressing ground potential upon the supervisory lead C1024. At its contacts 1081, the relay R1080 completes the above-mentioned path for impressing ringing voltage upon the calling end of the connection, this path extending from the ungrounded terminal of the ringing current generator by way of C1001, the condenser 1002 and the contacts 1091', 1081 and 1071 to the negative side of the connection established between the calling operator's position and the repeating coil 1010. The current thus caused to traverse the calling end of the connection is re-

produced by the receiver in use at the calling operator's position 441, thereby to signal the calling operator that the called operator is being signaled.

At its contacts 1086, the relay R1080, in releasing, prepares one of the above-mentioned circuits for energizing the line lamp 1193. At its contacts 1087, the relay R1080 completes the other of the circuits for energizing this line lamp, this latter circuit extending by way of the grounded control conductor C1044, the contacts 1123 and 1132, C1049, the contacts 1087 and 1099, C1048 and the filament of the lamp 1193 to battery. When energized over this circuit, the lamp 1193 is illuminated to signal the operator attending the position 1154 that a call is present upon the trunk 1040 which should be answered. From the above explanation it will be observed that the only function resulting from the transmission of one or more additional digits to the access circuit 1000 is that of releasing the relay R1080 to cause the energization of the line signal lamp 1193.

When the operator attending the position 1154 answers the call by operating the key 1180 to the talk position, the contact springs 1184, 1185, 1186 and 1188 are respectively operated into engagement, and the contact springs 1187 are disengaged. At the contact springs 1187, the path over which the release conductor C1047 is normally connected to ground is opened. At the contact springs 1186, a path is completed for connecting the release conductor C1047 to the normally grounded conductor C1199 extending to the operator's position equipment. At the contact springs 1188, a locking circuit including the normally grounded lead C1189 is prepared for the split relay R1110. At the contact springs 1185, a circuit is completed for energizing the series connected lower windings of the split and control relays R1110 and R1120 in parallel with the upper winding of the relay R1020. This circuit extends by way of the normally grounded lead C1198 through the contact springs 1185 to the lead C1046 where it divides, one branch extending through the series connected lower windings of the relays R1110 and R1120 to battery, and the other branch extending by way of the contacts 1077 and 1083, and the upper winding of R1080 to battery. At the contact springs 1184, a circuit including the normally grounded lead C1197 is completed for energizing the upper winding of the line switching relay R1170.

The relay R1080 operates when energized over the above-traced circuit, and locks to ground through its preliminary make contacts 1085. After this locking circuit is completed, the relay R1080 opens its contacts 1083 to interrupt its operating circuit, and closes its contacts 1084 to complete the prepared circuit including the contacts 1097 for energizing the disconnect relay R1090. At its contacts 1087, the relay R1080 opens the above-traced circuit for energizing the line lamp 1193. At its contacts 1081, the relay R1080 opens the above-traced path for impressing ringing voltage upon the calling end of the connection, thus terminating the ring-back tone signal being transmitted to the calling operator's position.

When its operating circuit is completed in the manner set forth in the preceding paragraph, the disconnect relay R1090 operates and locks to the grounded release conductor 1047 through its preliminary make contacts 1099. After this locking circuit is completed, the relay R1090

opens its contacts 1097 to interrupt its operating circuit. At its contacts 1095 and 1098, the relay R1090 simultaneously completes circuits for energizing the upper and lower windings of the slow-acting differentially wound pad switching relay R1050. The circuit for energizing the lower winding of this relay extends by way of the grounded conductor C1046, the contacts 1077, 1084, 1098, 1063' and 1055, and the lower winding of R1050 to battery. The circuit for energizing the upper winding of the relay R1050 extends by way of the grounded control conductor C1044, the contacts 1095 and 1062', the resistor 1007, the contacts 1054 and the upper winding of R1050 to battery. When these two circuits are simultaneously completed, the differentially energized relay R1050 does not operate. At its contacts 1094, the relay R1090 opens one of the above-traced locking circuits for the relay R1070. At its contacts 1092, the relay R1090 prepares an alternative path for impressing ground potential upon the control conductor C1044. At its contacts 1091, the relay R1090 prepares a circuit for energizing the lower winding of the slow-acting differentially wound supervisory relay R1045. At its contacts 1091', the relay R1090 opens another point in the above-traced path for impressing ringing voltage upon the calling end of the connection. At its contacts 1098' and 1099', the relay R1090 opens another point in the above-traced circuit for energizing the line lamp 1193, and prepares the alternative circuit for energizing this lamp. At its contacts 1093, the relay R1090 completes the above-mentioned path for impressing ground potential upon the supervisory lead C1024, this path extending from ground by way of the contacts 1046, 1093, 1082, 1066 and 1037 to the lead C1024. When this lead is grounded, the supervisory relay R1310 embodied in the toll line circuit 442 operates to transmit an off-hook supervisory signal to the operator's position 441.

The split relay R1110 and the relay R1120 both operate when the key 1080 is actuated to the talk position in the manner pointed out above. The relay R1120, upon operating, locks to the grounded release conductor C1047 through its contacts 1124. At its contacts 1123, the relay R1120 opens another point in the above-traced circuit for energizing the line signal lamp 1193. At its contacts 1124, the relay R1120 also completes a circuit including the grounded release conductor C1047 for energizing the position busy lamp 1195.

The split relay R1110, upon operating, locks to the grounded holding conductor C1189 over a path including its contacts 1118 and the contact springs 1188. At its contacts 1113 and 1116, the relay R1110 bridges the operator's telephone set embodied in the operator's position equipment 1196, across the talking conductors C1041 and C1042 of the trunk 1040, thereby to complete the desired conversational circuit between the operator's position 1154 and the calling operator's position 441. At its contacts 1111 and 1114, the relay R1110 disconnects the talking conductors of the trunk 1040 from the talking conductors of the trunk outgoing to the toll switching apparatus 1140. At its contacts 1112 and 1115, the relay R1110 prepares a dialing loop to the toll switching apparatus 1140.

The line switching relay 1170 also operates when the key 1180 is operated to the talk position. In operating, the relay R1170 locks to the grounded release conductor C1047 through its

contacts 1177. At its contacts 1173, the relay R1170 opens a point in the operating circuit for the relay R1130. At its contacts 1174, the relay R1170 connects the control conductor C1178 of the trunk extending to the toll switching apparatus 1140 to ground. At its contacts 1172 and 1176, the relay R1170 completes the dialing loop to the toll switching apparatus 1140. When this loop is completed, one of the first toll selectors embodied in the apparatus 1140 is seized in the usual manner in preparation for the extension of the call to the desired substation served by the switching equipment of the central exchange 20 or another operator's position located in a distant exchange. Following the relay operations just described, the called operator is connected with the calling operator and the toll switching apparatus 1140 is conditioned for the extension of the call.

The delay operator attending the position 1054, upon ascertaining the party desired, may extend the connection through the toll switching apparatus 1140 to the desired subscriber line or the desired operator's position in the usual manner. If the call is extended through this switching apparatus to a line which is arranged for supervision over the extra control lead C1045, this lead is connected to ground through a resistance 1133 of from 250 to 450 ohms when the called line, such, for example, as that extending to the substation T4 is seized by the final numerical switch embodied in the switching apparatus 1140 and utilized in handling the call. When the lead C1045 is connected to ground over a low resistance path of the character just described, the supervisory relay R1135 is energized over a circuit including this lead and the operated contacts 1175. The relay R1060 is also energized when this lead is connected to ground, the circuit for energizing the latter relay extending by way of C1045, the contacts 1096 and 1062, and the upper winding of R1060 to battery. Upon operating, the relay R1060 first locks to ground over a path including its preliminary make contacts 1061, the contacts 1095 and the grounded control conductor C1044. After this locking circuit is completed, the relay R1060 opens its operating circuit at its contacts 1062. At its contacts 1062' and 1063, the relay R1060 opens the two circuits traced above for energizing the upper and lower windings of the pad switching relay R1050. Thus, the two windings of the relay R1050 are deenergized. At its contacts 1061, the relay R1060 opens a point in the locking circuit for the relay R1050. It will be understood from the above explanation that when the relay R1060 is operated in response to seizure of a subscriber line, the pad control relay R1330 of the toll line circuit 442 is prevented from operating. Accordingly, the loss pads of the network 1370 are retained in the voice current transmission channel.

The supervisory relay R1135, upon operating, completes a circuit for energizing the lower winding of the supervisory relay R1045, this circuit extending from ground by way of the contacts 1136, C1043, the resistor 1006, the contacts 1091 and the lower winding of R1045 to battery. At its contacts 1136, the relay R1135 also completes an obvious circuit for energizing the supervisory lamp 1194. When its lower winding is thus energized, the relay R1045 operates and opens its contacts 1046 to interrupt the above-traced path for impressing ground potential upon the supervisory lead C1024. When this lead is

disconnected from ground, the supervisory relay R1310 of the toll line circuit 442 is deenergized and restores to transmit the previously described on-hook supervisory signal to the calling operator's position 441.

When the call as routed through the toll switching apparatus 1140 to the substation T4 is answered, the extra control conductor C1045 is disconnected from the above-described resistance ground path by the back-bridge relay of the final numerical switch of the switch train, thereby to cause the sequential deenergization and release of the supervisory relays R1135 and R1045. The relay R1135, upon restoring, also opens the circuit for energizing the supervisory lamp 1194, whereby the operator attending the position 1154 is informed that the call has been answered at the called substation. The relay R1045, upon restoring, recompletes the path for impressing ground potential upon the supervisory lead C1024, whereby the supervisory relay R1310 is caused to reoperate to transmit an off-hook supervisory signal to the calling operator's position 441. After the call is answered at the called substation T4, the operator attending the position 1154 may restore the key 1180 to its normal position, thereby to cause the disengagement of the contacts 1185, 1184, 1186 and 1188, and the engagement of the contact springs 1187. At the springs 1186 and 1187, holding ground on the release conductor C1047 is transferred from the lead C1199 directly to ground through the contact springs 1187. At the contact springs 1183, the locking circuit for the relay R1110 is interrupted. At the contact springs 1184, the operating circuit for the relay R1170 is interrupted. At the contact springs 1185, the lead C1046 is disconnected from ground. The relay R1110, upon restoring, connects the talking conductors C1041 and C1042 directly to the talking conductors of the trunk extending to the first toll selector of the operated toll switch train included in the apparatus 1140, thereby to establish the desired conversational circuit between the calling and called parties. At its contacts 1112, 1113, 1115 and 1116, the operator's telephone set embodied in the position 1186 is disconnected from the established communication connection. If, following restoration of the key 1180 to its normal position, the operator desires to monitor the connection, she may bridge her telephone set across the talking conductors of the trunk 1040 by operating the key 1180 to the monitor position wherein the contact springs 1181, 1182 and 1183 are closed. At the springs 1181 and 1182, the operator's telephone set is bridged across the talking conductors C1041 and C1042 of the trunk 1040, whereby the operator attending the position 1154 may listen to the conversation being held over the established connection. At the contact springs 1189, ground potential is applied to the lead C1139 for supervisory purposes. Obviously, when the key 1180 is restored from its monitor position to its normal position, the operator's telephone set is disconnected from the established connection.

The arrangement of the toll switching apparatus 1140 is such that if the loop circuit extending from the operated connector switch of this apparatus to the called substation T4 is opened, ground potential is again impressed upon the extra control lead C1045 through the resistor 1133. Thus, if the called subscriber repeatedly operates the switchhook provided at the substation T4 between its two operating positions, ground pulses are transmitted over the extra con-

trol conductor **C1045** to cause the intermittent operation of the supervisory relays **R1135** and **R1045**. Each time the relay **R1135** operates, it completes the circuit for energizing the supervisory lamp **1194**. Similarly, each time the supervisory relay **R1045** operates, it opens the path over which ground potential is impressed upon the supervisory lead **C1024**, thereby to cause the deenergization of the supervisory relay **R1310** embodied in the toll line circuit **442**. Thus, the relay **R1310** follows the ground pulses applied to the extra control conductor **C1045**, and functions to transmit a flashing recall signal to the calling operator's position **441**. The flashing of the lamp **1194** similarly informs the operator attending the position **1154** that the called subscriber requires the assistance of an operator.

If the operator attending the position **1154** desires to resign the calling operator attending the position **441**, she may do so by repeatedly operating the answering ring key embodied in the position equipment **1196** after having first operated the key **1180** to the talk position to cause the reoperation of the split relay **R1110**. With this relay operated, positive and negative battery potentials are impressed upon the trunk conductors **C1041** and **C1042**, respectively, through the contacts **1113** and **1116**, respectively, each time the answering ring key of the operator's position equipment is operated to the ringing position. When these potentials are applied to the trunk conductors **C1041** and **C1042**, the slow-acting relay **R1065** is obviously energized. In operating, the relay **R1065** opens its contacts **1066** to interrupt the previously traced path for grounding the supervisory lead **C1024**. Thus, the supervisory relay **R1310** of the toll line circuit **442** is deenergized and restores each time the answering ring key of the operator's position equipment **1196** is operated to the ring position, and is reenergized each time this key is restored to normal to cause the release of the relay **R1065**. The supervisory relay **R1310** thus functions to transmit a flashing recall signal to the operator handling the call at the calling operator's position **441**.

If the calling operator attending the position **441** desires to recall the delay operator attending the position **1154**, she may do so by momentarily opening the dialing circuit extending over the trunk **440** to the toll line circuit **442**. When the dialing circuit is opened, the line relay **R1300** and the simplex relay **R1055** are caused sequentially to restore in a manner clearly apparent from the preceding explanation. The operations which result from the release of the simplex relay **R1055** depend upon whether the connection has been cleared out at the delay operator's position **1154**. More specifically, if the connection is still being held at this operator's position, the relay **R1090** occupies its operated position. Accordingly, when the relay **R1080** restores in response to the release of the relay **R1055**, it completes the above-mentioned alternative circuit for energizing the line lamp **1193**, this circuit extending from ground by way of the contacts **1086** and **1098**, **C1048** and the filament of the lamp **1193** to battery. At its contacts **1082**, the relay **R1080** opens the above-traced path for impressing ground potential upon the supervisory lead **C1024**, whereby the supervisory relay **R1310** is deenergized and restores to transmit an on-hook supervisory signal to the calling operator's position **441**. When the operator attending the position **1154** answers the recall signal by again

actuating the key **1180** to the talk position, the previously traced alternative operating circuit for the relay **R1080** is recompleted. The relay **R1080**, accordingly, reoperates to again complete the path for grounding the supervisory lead **C1024**, and to open the alternative circuit for energizing the line lamp **1193**. It will be understood that when the supervisory lead **C1024** is again connected to ground, the relay **R1310** re-operates to transmit an off-hook supervisory signal to the calling operator's position **441**. In operating, the relay **R1080** also recompletes its locking circuit as traced above.

In the event the connection is released at the delay operator's position **1154** before the recall signal is transmitted to this position from the calling operator's position **441**, the relays **R1090**, **R1110**, **R1120**, **R1170**, **R1135** and **R1130** all occupy their respective restored positions at the time the simplex relay **R1055** restores in response to the recall signal transmitted from the calling operator's position. More specifically, to release the connection, the delay operator attending the position **1154** operates the release key **1191** to its off-normal position to disconnect the release conductor **C1047** from ground and thus deenergize the relays **R1090**, **R1120** and **R1170**. The relay **R1170**, upon restoring, opens its contacts **1172** and **1176** to interrupt the dialing loop to the switch train of the toll switching apparatus **1140**, and thus initiate the release of this train. At the contacts **1174**, the control conductor **1178** is disconnected from the ground. At the contacts **1173**, the control conductor **1178** is connected to battery through the winding of the relay **R1130**. At its contacts **1175**, the relay **R1170** opens the above-traced operating circuit for the supervisory relay **R1135**. With the relay **R1090** in its restored position, the initially traced circuit is completed for energizing the line lamp **1193** in response to the sequential release of the relays **R1055** and **R1080** which occurs when the recall signal is transmitted to the access circuit **1000** from the calling operator's position **441**. Thus, it will be observed that following the release of the connection at the delay operator's position **1154**, the recall signal transmitted to the access circuit **1000** results in the same control operations as occur when a call is initially routed to the operator's position **1154**. Also, the same relay operations occur when the operator attending this position answers the recall signal.

As indicated above, the operator attending the position **1154**, in order to release the position equipment provided at this position, momentarily operates the release key **1191** to its off-normal position to cause the deenergization and release of all of the relays illustrated in Fig. 11; the release of the toll switch train through which the call was routed to the called substation **T4**; and the release of the relay **R1090** embodied in the access circuit **1000**. It will be noted that the relay **R1090**, upon restoring, opens its contacts **1093** to interrupt the path for impressing ground potential upon the supervisory lead **C1024**. Thus, the supervisory relay **R1310** is deenergized and restores to transmit the usual on-hook supervisory signal to the calling operator's position **441**. The release of the access circuit **1000** is under the control of the calling operator attending the position **441**. More specifically, when this operator opens the dialing circuit to cause the deenergization and release of the line relay **R1300**, the toll line circuit **442** is released. During the release of this circuit, ground potential

is removed from the control conductor C453 in the manner previously explained, and the simplex relay R1055 is deenergized and restores. When the control conductor C453 is disconnected from ground, the toll transmission selector 300 and the toll switching selector 700 are released in the manner previously described. Since the control conductor C1023 is also disconnected from ground in response to the release of the toll line circuit 442, the relays R1070 and R1060 are deenergized and restore. The relay R1055, upon restoring, opens the locking circuit for the relay R1080, whereby the latter relay is caused to restore. Thus, all of the relays embodied in the access circuit 1000 are restored to normal and this circuit is rendered available for further use.

If the connection is cleared out at the calling operator's position 441 before it is released at the delay operator's position 1154, the toll line circuit 442, the toll transmission selector 300 and the toll switching selector 700 are restored to normal in the exact manner described above. During the release of this equipment, ground potential is removed from the control conductor C1023 to cause the deenergization and release of the relays R1060 and R1070. Further, the operating circuit for the simplex relay R1055 is opened in response to the release of the toll line circuit 442. Thus, the four relays R1060, R1055, R1070 and R1080 are all deenergized and restore in response to the release of the connection at the operator's position 441. The relay R1090 is, however, held operated over its holding circuit which includes the grounded release conductor C1047. With this relay operated, ground potential is again impressed upon the control conductor C1023 over a path including the contacts 1092, 1074 and 1035, thereby to guard the access circuit 1000 against seizure, when the relay R1070 restores. Thus, the access circuit 1000 cannot be seized on an incoming call until the connection as completed between the operators' positions 1154 and 441 is cleared out at both of these positions.

In the event the above-described call is routed from the delay operator's position 1154 through the toll switching apparatus 1140 and over the trunk 1141 to the operator's position 1142 in the distant exchange 70, the extra control lead C1045 is not connected to ground at any point in the switch train through which the connection is extended to the trunk 1141. Accordingly, the three relays R1135, R1045 and R1060 are prevented from operating in response to seizure of the trunk 1141. After the call is answered at the operator's position 1142, the delay operator attending the position 1154 may retire from the connection, her services being no longer required in forwarding the connection to the desired substation. In order to disconnect her position equipment 1196 from the connection, the operator restores the key 1180 to its normal position. In response to this operation, the split relay R1110 is deenergized and restores to connect the calling operator at the position 441 through to the operator attending the position 1142. At the contact springs 1185, the lead C1046 is disconnected from ground to open the previously traced circuit for energizing the lower winding of the relay R1050. In response to the deenergization of its lower winding, the relay R1050 operates and locks to the grounded control conductor C1044 over a path including its preliminary make contacts 1053 and the contacts 1061. After this locking circuit is completed, the relay R1050

opens its operating circuit at the contacts 1054. At its contacts 1055, the relay R1050 opens another point in the previously traced circuit for energizing its lower winding. At its contacts 5 1051 and 1052, the relay R1050 disconnects the lower terminal of the simplex relay R1055 from the center tap of the resistor 1018, and connects this relay winding terminal to the upper terminal of the resistor 1018. Thus, the current flow over 10 the two variable arms of the previously described resistance bridge, which now include the two talking conductors of the trunk 1020, is unbalanced so that more current is caused to traverse one of these arms than the other. As a result, a difference of potential is developed between the bridge terminals of the two resistors 1357 and 1356. This voltage is obviously impressed across the winding of the pad control relay R1330. When thus energized, the relay 20 R1330 operates and opens its contacts 1331 to disconnect the pad switching relay control lead C1309 from ground. At its contacts 1332, the relay R1330 connects the indicated control lead to the negative terminal of the exchange battery over a path including the contacts 1354 and 1331, and the resistor 1308. When negative battery potential is impressed upon the lead C1309, the pad switching relay embodied in the network 1370 operates to remove the loss pads from the voice current transmission channel, thereby substantially to increase the amplification in the channel and thus compensate for the loss occasioned by the extension of the connection over the relatively long inter-office trunk line 1141. 30 From the above explanation it will be apparent that, depending upon the potential impressed upon the extra control lead C1045, the pad switching relay of the network 1370 is either energized or held deenergized to determine the voice current transmission level over the established connection.

After the connection has been forwarded to the operator's position 1142, and the delay operator attending the position 1154 has retired from the connection, the various recall and other supervisory signals may be transmitted between the toll operator's position 441 and the delay operator's position 1154 in the manner explained above with reference to the extension of the call to the substation T4.

Provisions are made in the system for through supervision between the calling operator's position 441 and the operator's position 1142 in the distant exchange 70 on a call of the character 45 under consideration. This is accomplished in two ways, depending upon the particular type of supervision required with respect to particular trunks. According to one method, a supervisory control relay may be provided in the trunk circuit terminating the trunk 1141 in the central exchange which responds to switchhook operations, or the equivalent thereof performed at a called substation served by the exchange 70 or the operator's position 1142, by impressing high resistance ground pulses through the operated toll switch train upon the extra control lead C1045, thereby to energize the supervisory relay R1135 in parallel with the upper winding of the relay R1060. In such case, a marginal relay 60 R1060 is used, which is so constructed, arranged and adjusted that it does not operate when its upper winding is energized over a high resistance ground circuit, but only operates when this winding is energized over a low resistance ground circuit having a terminating resistance of from 65 70 250

to 450 ohms. In this case, an extremely sensitive supervisory relay R1135 is used which is constructed and adjusted to operate when energized over a ground circuit having either a high or a low terminating resistance. In this manner, the relay R1135 may be controlled over a high resistance operating circuit by the supervisory relay of the trunk circuit terminating the trunk 1141 in the central exchange 20 and these control operations may be effected without causing the operation of the relay R1060. In this regard it will be understood that the relay R1135 directly controls the supervisory lamp 1194, and indirectly controls the supervisory relay R1310 so that suitable supervisory signals are displayed at both the calling operator's position 441 and the delay operator's position 1154.

In accordance with the second method by which passing supervision may be obtained, the alternating current relay R1125, operating in conjunction with the alternating current relay R1040', is utilized to control the position of the supervisory relay R1045. This method entails the transmission of supervisory pulses of ringing current back over the trunk 1141 from the called operator's position 1142 for the purpose of controlling the two relays R1040' and R1125. If this method is followed, the called operator 1142 may transmit a flashing recall signal to the calling operator at the toll operator's position 441, and a steady or continuous recall signal to the delay operator's position 1154 by operating her ringing key to transmit splashes of ringing current over the trunk 1141 and through the operated switch train in the switching apparatus 1140. Each time ringing voltage is applied to the conductors of the trunk 1141, the relay R1125 is energized in series with the condenser 1127. This relay, upon operating at the beginning of the first pulse of ringing current transmitted thereto, is mechanically locked in its operated position by means of a mechanical interlock of conventional design between this relay and the split relay R1110. Upon operating, the relay R1125 completes a circuit including the contacts 1126 and the conductor C1043 for energizing the supervisory lamp 1194 in parallel with the lower winding of the supervisory relay R1045. This circuit is held completed following the first pulse of ringing current transmitted over the trunk 1141 due to the locked-up condition of the relay R1125. Accordingly, the supervisory lamp 1194 is continuously energized after the first supervisory pulse of ringing current is transmitted over the trunk 1141. The relay R1040', which is bridged across the talking conductors of the trunk 1040 in series with the condenser 1003, also operates in response to the pulse of ringing current transmitted over the trunk 1141. This relay, in operating, closes its contacts 1041 to complete an obvious circuit for energizing the upper winding of the supervisory relay R1045. Since the relay R1045 is of the differentially wound type, it does not operate during the ringing interval when both of its windings are energized. At the end of the pulse, however, the relay R1040' is deenergized and restores to open the circuit for energizing the upper winding of the relay R1045. The latter relay now operates to open its contacts 1046 and thus disconnect the supervisory lead C1024 from ground. At the beginning of the second pulse of ringing current transmitted over the trunk 1141, the relay R1040' again operates to energize the upper winding of the supervisory relay R1045 and thus cause the release

of the latter relay. It will thus be apparent that when splashes of alternating current are transmitted over the trunk 1141 from the operator's position 1142, the relay R1040' controls the supervisory relay R1045 in a manner such that the latter relay is operated during the spacing periods between the current splashes, and is restored during the current splash periods. Thus, a series of ground pulses is transmitted over the supervisory lead C1024 to the supervisory relay R1310. This supervisory relay, in following the pulses, transmits the previously described flashing recall signal to the calling operator's position 441.

15 The continuous energization of the supervisory lamp 1194 serves to inform the delay operator attending the position 1154 that she is being recalled from the operator's position 1142. In order to reenter the connection, the delay operator actuates the key 1180 to its talk position, thereby to cause the reoperation of the split relay R1110 in the manner previously described. As indicated above, the split relay R1110 mechanically controls the locking element for the alternating current relay R1125. More specifically, the mechanical interlock between these two relays is such that the relay R1125 is locked operated when energized at a time when the relay R1110 is restored, and is released in response to the subsequent energization and operation of the relay R1110. Thus, when the delay operator reenters the connection, the relay R1125 restores to interrupt the circuit for energizing the lower winding of the supervisory relay R1045 and the supervisory lamp 1194 in parallel. The relay R1045, upon restoring, again impresses ground potential upon the supervisory lead C1024, whereby the supervisory relay R1310 reoperates to transmit an off-hook supervisory signal to the calling operator's position 441.

From the above explanation it will be understood that if a single pulse of alternating current is transmitted over the trunk 1141 from the operator's position 1142 to cause the operation of the relays R1125, R1040' and R1045, the latter relay operates at the end of the pulse and remains in its operated position. Accordingly, no ground pulses are transmitted over the supervisory lead C1024 to the supervisory relay R1310, but this relay is deenergized. Thus, the relay R1310 is caused to restore to transmit a continuous on-hook or disconnect supervisory signal to the calling operator's position 441.

55 The manner in which the operated switch train, including the access circuit 1000 and the delay operator's position equipment illustrated in Fig. 11, is released under the control of the operators respectively attending the positions 441 and 1154, is exactly the same as described above with reference to the call extended to the substation T4 from the delay operator's position 1154.

60 From the above explanation it will be understood that the operator's position circuit illustrated in Fig. 11 of the drawings is utilized solely as an access circuit to permit the other toll operators of the system to obtain quick access to the delay operator's position 1154. With respect to the toll and other operators attending the switchboard 1150 in the central exchange 20, connections may be routed to the delay operator's position 1154 over the trunk 1119 which is accessible to certain of the toll selectors embodied in the toll switching apparatus associated with the switchboard 1150. The manner in which

these inter-position calls are handled is well understood in the art and, accordingly, a detailed consideration thereof is unnecessary.

NIGHT SERVICE

As pointed out above with reference to the operation of the access circuit 900, the delay operator's position 1154 is, in the arrangement illustrated, one of the operator's positions at which night traffic is handled. Thus, when the night transfer relay R950 is operated, the conductors of the trunk 920 are directly multiplied to the conductors of the trunk 1020 so that calls intended for the information operator's position 1153 are directly by-passed through the access circuit 1000 to the delay operator's position 1154. The manner in which these calls are handled, and the relay operations which occur incident to the extension of the calls through the access circuit 1000 to the delay operator's position 1154 and the supervision of the calls, is exactly the same as described above. Similar multiples may be provided between the trunk 1020 and the trunks incoming to the access circuits associated with other information and delay operators' positions provided at the switchboard 1150. With this arrangement, the light traffic which is normally handled during the late evening hours is concentrated and automatically directed to the delay operator's position 1154. If required, two or more of the delay operators' positions may be reserved for night service by splitting the night multiples into groups and terminating the multiples of the groups at different trunks incoming to access circuits associated with different delay operators' positions which are individual to the groups. If the delay operator's position 1154 is not to be used for night service, the access circuit 1000 is equipped with a night transfer relay R1030 which, when operated, disconnects the conductors of the trunk 1020 from the access circuit 1000 and connects these conductors to the conductors of a night trunk extending to the access circuit associated with a delay operator's position which is arranged to handle night traffic. This night transfer relay is arranged to be controlled over a lead C1005 which, when connected to ground through the contact springs of a night key provided at the operator's position 1154, serves to energize the relay R1030, providing the access circuit 1000 is not occupied with a call. Upon operating, the relay R1030 locks through its contacts 1039 to the grounded lead C1005 and connects the trunk 1020 to the night trunk extending to the delay operator's position 1154 arranged to handle night traffic. The relay R1030 remains in its operated position until the night key provided at the delay operator's position 1154 is restored to normal to disconnect the lead C1005 from ground.

OPERATION OF THE ALARM EQUIPMENT

As indicated in the general description of the apparatus, the equipment illustrated in Fig. 2 of the drawings is provided for the purpose of producing an alarm when any one of the switching units provided in the central exchange 20 fails to operate in its intended manner. These switching units are divided into five groups according to the particular functions assigned thereto, and each group is served by a common alarm lead. Thus, the toll transmission selector 300 and the other switches of this character have commonly associated therewith an alarm lead C231. The alarm lead C231 is associated with another group

of switching units. The remaining three alarm leads are similarly individually associated with different groups of switching units.

The operation of the alarm equipment may best be explained by again considering the operation of the toll transmission selector 300. In the explanation pertaining to the operation of this selector, it is pointed out that a path including the contacts 546 and 541 is completed for impressing ground potential upon the permanent supervisory or alarm lead C231 in response to seizure of the selector over the trunk 450. When this lead is connected to ground, a circuit including the contacts of the reset key 238, the filament of the alarm lamp 213, and the contacts 211 is completed for energizing the high resistance upper winding of the start relay R220. The resistance of this relay winding is such that the lamp 213 is not energized to incandescence by the current flow therethrough when the circuit just traced is completed. In a similar manner, if ground potential is impressed upon the second alarm or supervisory lead C232, the alarm lamp 214 is energized in series with the high resistance upper winding of the relay R225. The three remaining alarm signal lamps are arranged for energization in series with the upper windings of their respective associated alarm relays when the alarm or supervisory leads individually associated therewith are connected to ground through seizure of switching units in the associated switch unit groups. Each of the start relays R220, R225, etc., is arranged to complete an obvious operating circuit for the slow-to-operate control relay R240. Thus, the relay R220, upon operating in response to seizure of the toll transmission selector 300, closes its contacts 222 and thus completes one of the obvious multiple operating circuits for the relay R240. At its contacts 221, the relay R220 locks to the grounded lead C231 over a circuit including its upper winding and the filament of the lamp 213. Upon operating, the relay R240 opens, at its contacts 242, a point in the circuit for energizing the release magnet 264 of the timing switch 260. At its contacts 241, the relay R240 completes an obvious circuit for energizing the slow-to-release cut-off relay R210. At its contacts 243, the relay R240 completes a circuit for transmitting current pulses from the interrupter element 237 to the operating magnet 263 of the timing switch 260. The cut-off relay R210, upon operating, opens its normally closed break contacts, thereby to interrupt the operating circuits for the five start relays individually associated with the five alarm leads. This arrangement prevents the alarm equipment from responding to more than one supervisory signal at a time unless the signals are transmitted to the equipment substantially simultaneously. In the latter case, the two or more start relays which respectively correspond to the simultaneously grounded alarm leads will be locked energized through their associated upper make contacts prior to operation of the cut-off relay R210, and one timing operation on the part of the switch 260 will suffice to determine the alarm or non-alarm character of each of the simultaneous signals.

Following operation of the relay R240, current pulses are transmitted to the operating magnet 263 of the timing switch 260 at a rate determined by the speed of rotation of the interrupter element 237. Preferably, this element is rotated to transmit a current pulse to the magnet 263 at the end of each thirty-second interval. The magnet

263 responds by advancing the wiper 261 one step for each current pulse transmitted thereto. When this wiper is moved off normal, the off-normal springs 265 are moved into engagement to prepare the operating circuit for the release magnet 264. After the wiper 261 is operated through eight steps, corresponding to an elapsed time of four minutes, it engages its associated eighth contact to complete an obvious circuit for energizing the slow-to-operate alarm relay R250. The relay R250, upon operating, locks to ground over a path including the contacts 251 and 241. At its contacts 252, the relay R250 opens the above-traced circuit for transmitting current pulses to the operating magnet 263. Thus, the stepping operation of the timing switch 260 is arrested. At its contacts 254, the relay R250 opens the normally completed circuit for energizing the signal lamp 235. At its contacts 253, the relay R250 completes an obvious circuit for energizing the audible signal device 236. At its contacts 255, the relay R250 completes an obvious path for connecting the low resistance lower winding of the start relay R220 in parallel with the high resistance upper winding of this relay. When the resistance included in the circuit for energizing the lamp 213 is thus reduced, this lamp is energized to incandescence and is illuminated to produce a visual signal indicating that one of the switching units of the associated group is in a faulty condition. It will be observed that the relay R250 includes additional make contacts which are provided for shunting the lower windings of the other four start relays across their respective associated upper windings. Thus, the operation of the alarm relay R250 in all cases results in the energization of the signal lamp associated with the group of switching units having a faulty unit included therein. The operation of the audible signal device 236 serves to inform the exchange attendants that one of the switching units provided in the exchange has been held operated for an excessive period of time and is probably in a faulty condition. Further, the illuminated condition of the lamp 213 indicates that the faulty switching unit is included in the group associated with the alarm lead 231. By inspecting the switching units of this group, a station attendant may locate the faulty switch unit and correct the trouble. In order to release the alarm equipment following the operation thereof in the manner just explained, the reset key 238 may be operated to its off-normal position to open the above-traced locking circuit for the relay R220, and to interrupt the locking circuits for any of the other start relays which may be operated. When this relay or these relays restore, the operating circuit for the relay R240 is interrupted. The relay R240, in releasing, opens the initially completed operating and locking circuits for the relays R210 and R250, respectively. At its contacts 243, the relay R240 opens another point in the above-traced circuit for transmitting current pulses to the operating magnet 263 of the timing switch 260. At its contacts 242, the relay R240 completes the prepared operating circuit for the release magnet 264. This magnet, in operating, attracts its holding pawl, permitting the wiper 261 to be restored to its normal position, at which time the off-normal springs 265 are opened to interrupt the operating circuit for the release magnet and to open the locking circuits for the two relays R210 and R250. When the two last-mentioned relays restore, the alarm equipment is fully released and is conditioned to respond to an-

other supervisory signal transmitted thereto over one of the five associated alarm leads.

The above explanation pertaining to the operation of the alarm equipment is based upon the premise that ground potential is maintained upon the alarm or supervisory lead C231 by the release of the toll transmission selector 300 for a period in excess of four minutes, this period being required for the timing switch 260 to complete the operating circuit for the alarm relay R250. This assumption presupposes a faulty condition of the toll transmission selector 300 since, under normal operating conditions, one of the two relays R540 and R545 will be controlled to open the path for impressing ground potential upon the lead C231 before the four-minute time interval expires. Thus, the start relay R220 is normally deenergized to cause the release of the relay R240, followed by the release of the timing switch 260 and the cut-off relay R210 before the timing switch operates to complete the circuit for energizing the alarm relay R250. It will be understood, therefore, that in any case where ground potential is impressed upon one of the five alarm leads and is removed before the expiration of the four-minute timing period, the alarm equipment is restored to normal without causing the energization of any of the alarm signal devices included therein. It will further be understood that if two or more of the five alarm leads are simultaneously grounded, the timing operation of the switch 260 continues until all of the leads are again disconnected from ground and that the start relays R220, R225, etc., are individually deenergized during such a timing operation as ground potential is removed from the associated alarm leads. It will also be apparent that by changing the rate at which the time pulses are transmitted to the operating magnet 263 of the timing switch 260, the timing interval may be varied to suit the requirements of any particular installation.

While there has been described what is at present considered to be the preferred embodiment of the invention, it will be understood that various modifications may be made therein, and it is contemplated to cover in the appended claims all such modifications as fall within the true spirit and scope of the invention.

50. What is claimed is:

1. In a telephone system, a plurality of operators' positions, supervisory signals at said operators' positions, means including automatic switching apparatus for routing a call from a calling substation of the system through a plurality of said operators' positions in tandem to either of two called substations of the system, means operative in the event said call is routed to one of said called substations for concurrently controlling the supervisory signals provided at at least two of said tandem connected operators' positions in accordance with the switch hook operations performed at said one called substation, and means operative in the event said call is routed to the other of said called substations for controlling the supervisory signal provided at only one of the tandem connected operators' positions in accordance with the switch hook operations performed at said other called substations.
2. In a telephone system, a plurality of operators' positions, supervisory signals at said operators' positions, means including automatic switching apparatus for routing a call from a calling substation of the system through a plurality of said operators' positions in tandem to

either of two called substations of the system, means operative in the event said call is routed to one of said called substations for concurrently controlling the supervisory signals provided at at least two of said tandem connected operators' positions in accordance with the switch hook operations performed at said one called substation, and means operative in the event said call is routed to the other of said called substations for controlling the supervisory signal provided only at the final operator's position of the tandem connected operators' positions in accordance with the switch hook operations performed at said other called substations.

3. In a telephone system, a first exchange including a toll operator's position, a second exchange including a delayed call operator's position, a third exchange including a third operator's position, supervisory signals at said operators' positions, means including automatic toll switching apparatus included in said second exchange for routing a call from a calling substation served by said first exchange by way of said toll operator's position and said delayed call operator's position to a substation served by said second exchange or by way of said third operator's position to a called substation served by said third exchange, means operative in the event said call is routed to a substation served by said second exchange for concurrently controlling the supervisory signals of the toll and delayed call operators' positions in accordance with the switch hook operations performed at the called substation, and means operative in the event the call is routed to a substation served by said third exchange for controlling only the supervisory signal at said third operator's position in accordance with the switch hook operations performed at the called substation.

4. In a telephone system, an exchange, a trunk extending to said exchange, means for routing a connection from said trunk to a called line terminating at said exchange, said connection comprising one or more conductors defining a control path, means controlled over said path for controlling the voice current transmission level over said trunk, and means also controlled over said path for transmitting a supervisory signal over said trunk.

5. In a telephone system, an exchange, a trunk extending to said exchange, means including automatic switching apparatus for routing a connection from said trunk to a called line terminating at said exchange, said connection comprising a pair of conductors defining a communication channel, and a third conductor defining a control path, means controlled over said path for controlling the voice current transmission level over said trunk, and means also controlled over said path for transmitting a supervisory signal over said trunk.

6. In a telephone system, an exchange, a trunk extending to said exchange, an operator's position including position equipment and a supervisory signal, means including said operator's position equipment for routing a connection from said trunk to a called line terminating at said exchange, said connection comprising one or more conductors defining a control path, means controlled over said path for controlling the voice current transmission level over said trunk, and means also controlled over said path for controlling said supervisory signal.

7. In a telephone system, an exchange, a trunk extending to said exchange, means for routing

a connection from said trunk to a called line terminating at said exchange, said connection comprising one or more conductors defining a control path, the resistance of said control path being varied between two values in response to supervisory operations performed at the distant end of said called line, means operative in response to the completion of said path when the called line is seized for changing the voice current transmission level over said trunk, said last-named means being locked operated following its operation, and means also operative in response to the completion of said path for transmitting a supervision signal over said trunk and thereafter operative in response to variations in the resistance of said path between said values to transmit additional supervisory signals over said trunk.

8. In a telephone system, an exchange, a trunk extending to said exchange, means for routing a connection from said trunk to a called line terminating at said exchange, said connection comprising one or more conductors defining a control path, the resistance of said control path being varied between two values in response to supervisory operations performed at the distant end of said called line, means controlled over said path for determining the voice current transmission level over said trunk, and means controlled over said path in accordance with variations in the resistance of said path between said values for transmitting supervisory signals over said trunk.

9. In a telephone system, an exchange, a trunk extending to said exchange, means for routing connections from said trunk to called lines terminating at said exchange, each of said connections comprising one or more conductors defining a control path extending to the exchange terminus of the called line, the terminating impedances of said control paths being different for different lines, means controlled over said paths in accordance with the terminating impedances thereof for determining the voice current transmission level over said trunk, and means also controlled over said paths for transmitting supervisory signals over said trunk.

10. In a telephone system, an exchange, a trunk extending to said exchange, means for routing connections from said trunk to called lines terminating at said exchange, each of said connections comprising one or more conductors defining a control path extending to the exchange terminus of the called line, the terminating impedances of said control paths being different for different lines, means controlled over said paths in accordance with the terminating impedances thereof for determining the voice current transmission level over said trunk, the resistance of at least one of said paths being variable between two values in response to supervisory operations performed at the distant end of the called line, and means operative in response to variations in the resistance of said one path between said values for transmitting supervisory signals over said trunk.

11. In a telephone system, an exchange, a trunk extending to said exchange, means for routing connections from said trunk to called lines terminating at said exchange, each of said connections comprising one or more conductors defining a control path extending to the exchange terminus of the called line, the terminating impedances of said control paths being different for different lines, a supervisory relay

and a transmission level control relay connected to be energized in parallel over a completed one of said paths, said transmission level control relay being marginal in character whereby it only operates if the terminating impedance of a completed one of said control paths is less than a predetermined value, means controlled in accordance with the setting of said transmission level control relay for determining the voice current transmission level over said trunk, said supervisory relay being operative between its two positions in response to predetermined changes in the resistance of a completed one of said control paths, and means controlled by said relay for transmitting supervisory signals over said trunk.

12. In a telephone system, an exchange, a trunk extending to said exchange, means for routing a connection from said trunk to a called line terminating at said exchange, said connection comprising a pair of conductors defining a communication channel and a third conductor defining a control path and a section of said communication channel, and means controlled over said path for controlling the voice current transmission level over said trunk.

13. In a telephone system, an exchange, a trunk extending to said exchange, means for routing connections from said trunk to called lines terminating at said exchange, each of said connections comprising a pair of conductors defining a communication channel and a third conductor defining a control path which extends to the exchange terminus of the called line, the terminating impedances of said paths being different for different lines, and means controlled over said paths in accordance with the terminating impedances of said paths for controlling the voice current transmission level over said trunk.

14. In a telephone system, an exchange, a trunk extending to said exchange, a trunk circuit in said exchange, automatic switching apparatus including said trunk circuit for routing connections from said trunk to called lines terminating at said exchange, each of said connections including a control path extending from said trunk circuit to the terminus of the called line, the terminating impedances of said paths being different for different lines, a relay comprising a winding included in the common portion of said paths and selectively controlled in accordance with the terminating impedances of said paths, and means controlled in accordance with the setting of said relay for controlling the voice current transmission level over said trunk.

15. In a telephone system, an exchange, a trunk extending to said exchange, a trunk circuit in said exchange, automatic switching apparatus including said trunk circuit for routing connections from said trunk to called lines terminating at said exchange, said trunk circuit including a differentially wound relay having windings concurrently energized each time a connection is routed by way of said trunk circuit to a called line, each of said connections including a control path extending from said trunk circuit to the terminus of the called line, the terminating impedances of said paths being different for different lines, a second relay comprising a winding included in the common portion of said paths and selectively controlled in accordance with the terminating impedances of said paths, means including said second relay for selectively controlling the energization of one winding of said differentially wound relay, and means controlled by said differentially wound relay for controlling the

voice current transmission level over said trunk.

16. In a telephone system, an exchange, a trunk extending to said exchange, an operator's trunk circuit in said exchange, means for routing calls from said trunk to said trunk circuit, said trunk circuit including a differentially wound relay having windings concurrently energized when a call routed to said circuit is answered, means including automatic switching apparatus for extending connections from said trunk circuit to called lines terminating at said exchange, each of said connection extensions including a control path extending from said trunk circuit to the terminus of the called line, the terminating impedances of said paths being different for different lines, means controlled in accordance with the terminating impedances of said control paths for selectively deenergizing one winding of said relay, and means controlled by said relay for controlling the voice current transmission level over said trunk.

17. In a telephone system, an exchange, a trunk extending to said exchange, an operator's trunk circuit in said exchange, means for routing calls from said trunk to said trunk circuit, said trunk circuit including a differentially wound relay having windings concurrently energized when a call routed to said circuit is answered, means including automatic switching apparatus for extending connections from said trunk circuit to called lines terminating at said exchange, each of said connection extensions including a control path extending from said trunk circuit to the terminus of the called line, the terminating impedances of said paths being different for different lines, a second relay comprising a winding included in the common portion of said paths and selectively controlled in accordance with the terminating impedances of said paths, means including said second relay for selectively controlling the energization of one winding of said differentially wound relay, and means controlled by said differentially wound relay for controlling the voice current transmission level over said trunk.

18. In a telephone system, an exchange, a line extending to said exchange, a line circuit terminating said line in said exchange, a switching unit, means including automatic switching apparatus for routing a connection from said line through said switching unit to a called line terminating at said exchange, said connection comprising a resistance bridge including in its arms the talking conductors of the portion of the connection extending between said line circuit and said switching unit, and means controlled in accordance with the balanced or unbalanced condition of said bridge for determining the voice current transmission level over said first-named line.

19. In a telephone system, an exchange, a line extending to said exchange, a line circuit terminating said line in said exchange, a switching unit, means including automatic switching apparatus for routing a connection from said line through said switching unit to a called line terminating at said exchange, said connection comprising a resistance bridge including in its arms the talking conductors of the portion of the connection extending between said line circuit and said switching unit, the arms of said bridge which include said talking conductors being progressively extended at each switching stage of said portion of the connection, and means controlled in accordance with the balanced or unbalanced condition of said bridge for determining the voice

current transmission level over said first-named line.

20. In a telephone system, an exchange, a line extending to said exchange, a line circuit terminating said line in said exchange, a trunk circuit, means including automatic switching apparatus for routing a connection from said line through said trunk circuit to a called line terminating at said exchange, said connection comprising a resistance bridge including in its arms the talking conductors of the portion of the connection extending between said line and trunk circuits, means controlled in accordance with the directory number designation of said called line for determining the balanced or unbalanced condition of said bridge, and means controlled in accordance with the balanced or unbalanced condition of said bridge for controlling the voice current transmission level over said first-named line.

21. In a telephone system, an exchange, a line extending to said exchange, a line circuit terminating said line in said exchange, a trunk circuit, means including automatic switching apparatus for routing a connection from said line through said trunk circuit to a called line terminating at said exchange, said connection comprising a resistance bridge including in its arms the talking conductors of the portion of the connection extending between said line and trunk circuits, the arms of said bridge which include said talking conductors being progressively extended at each switching stage of said portion of the connection, means controlled in accordance with the directory number designation of said called line for determining the balanced or unbalanced condition of said bridge, and means controlled in accordance with the balanced or unbalanced condition of said bridge for controlling the voice current transmission level over said first-named line.

22. In a telephone system, an exchange, a line extending to said exchange, a line circuit terminating said line in said exchange, a trunk circuit, means including automatic switching apparatus for routing a connection from said line through said trunk circuit to a called line terminating at said exchange, said connection comprising a resistance bridge including in its arms the talking conductors of the portion of the connection extending between said line and trunk circuits, the arms of said bridge which include said talking conductors being progressively extended at each switching stage of said portion of the connection and being so proportioned that said bridge is balanced, means operative in the event said connection is extended to a called line of a particular character for unbalancing said bridge, and means operative to change the voice current transmission level over said first-named line in response to the unbalancing of said bridge.

23. In a telephone system, an exchange, a line extending to said exchange, a line circuit terminating said line in said exchange, a trunk circuit, means including automatic switching apparatus for routing a connection from said line through said trunk circuit to a called line terminating at said exchange, said connection comprising a resistance bridge including in its arms the talking conductors of the portion of the connection extending between said line and trunk circuits and a control path extending between said trunk circuit and the terminus of the called line, the terminating impedance of said control path being different depending upon the charac-

ter of the called line, means controlled in accordance with the terminating impedance of said control path for determining the balanced or unbalanced condition of said bridge, and means controlled in accordance with the balanced or unbalanced condition of said bridge for controlling the voice current transmission level over said first-named line.

24. In a telephone system, an exchange, a line extending to said exchange, a line circuit terminating said line in said exchange, a trunk circuit, means including automatic switching apparatus for routing a connection from said trunk through said trunk circuit to a called line terminating at said exchange, said connection comprising a resistance bridge including in its arms the talking conductors of the portion of the connection extending between said line and trunk circuits and a control path extending between said trunk circuit and the terminus of the called line, the arms of said bridge which include said talking conductors being progressively extended at each switching stage of said portion of said connection and the terminating impedance of said control path being different depending upon the character of the called line, means controlled in accordance with the terminating impedance of said control path for determining the balanced or unbalanced condition of said bridge, and means controlled in accordance with the balanced or unbalanced condition of said bridge for controlling the voice current transmission level over said first-named line.

25. In a telephone system, an exchange, a line extending to said exchange, a line circuit terminating said line in said exchange, an operator's trunk circuit, means including automatic switching apparatus for completing a connection between said line and trunk circuits, said connection including in its arms the talking conductors of said connection, said trunk circuit including a differentially wound relay having windings concurrently energized in response to the call answering operation of said trunk circuit, means including additional automatic switching apparatus for extending the connection from said operator's trunk circuit to a called line terminating at said exchange, the extended portion of said connection including a control path extending between said trunk circuit and the terminus of the called line, the terminating impedance of said control path being different depending upon the character of the called line, means controlled over said path and operative in the event the terminating impedance of said path is below a predetermined value for deenergizing one of the windings of said relay, means controlled by said relay for determining the balanced or unbalanced condition of said bridge, and means controlled in accordance with the balanced or unbalanced condition of said bridge for controlling the voice current transmission level over said first-named line.

26. In a telephone system, an exchange, a line extending to said exchange, a line circuit terminating said line in said exchange, an operator's trunk circuit, means including automatic switching apparatus for completing a connection between said line and trunk circuits, said connection including in its arms the talking conductors of said connection, said trunk circuit including a differentially wound relay having windings concurrently energized in response to the call answering operation of said trunk circuit, means including additional automatic switching apparatus

for extending the connection from said trunk circuit to a called line terminating at said exchange, the extended portion of said connection including a control path extending between said second trunk circuit and the terminus of the called line, the terminating impedance of said control path being different depending upon the character of the called line, a second relay comprising a winding included in said control path and operative only in the event the terminating impedance of said path is below a predetermined value, means responsive to operation of said second relay for deenergizing one winding of said differentially wound relay, means responsive to the resulting operation of said differentially wound relay for changing the balance of said bridge, and means responsive to the changing of the balance of said bridge for changing the voice current transmission level over said first-named line.

27. In a telephone system, an exchange, a line extending to said exchange, means including automatic switching apparatus for extending a connection from said line to a called line terminating at said exchange, said connection comprising two conductors defining a communication channel and a third conductor defining a control path extending to the terminus of said called line, and means controlled over said control path and a section of said communication channel for controlling the voice current transmission level over said first-named line.

28. In a telephone system, a plurality of operators' positions, means for routing a connection through said positions in tandem, and means operative in response to a supervisory operation performed by the operator attending one of said positions for transmitting over said connection a supervisory signal of one character to the operator attending a second of said positions and a supervisory signal of different character to the operator attending a third of said positions.

29. In a telephone system, a plurality of operators' positions, and means for routing a connection through said positions in tandem, and means operative in response to a supervisory operation performed by the operator attending one of said positions for transmitting over said connection an uninterrupted supervisory signal to the operator attending a second of said positions and an intermittent supervisory signal to the operator attending a third of said positions.

30. In a telephone system, a plurality of operators' positions, means for routing a connection through said positions in tandem, and means operative in response to ringing current transmitted from one of said positions over said connection to a second of said positions for transmitting a supervisory signal of one character to the operator attending said second position and a supervisory signal of different character to the operator attending a third of said positions.

31. In a telephone system, a plurality of operators' positions, means for routing a connection through said positions in tandem, and means operative in response to ringing current transmitted from one of said positions over said connection to a second of said positions for transmitting an uninterrupted supervisory signal to the operator attending said second position and an intermittent supervisory signal to the operator attending a third of said positions.

32. In a telephone system, a plurality of operators' positions, means for routing a connection through said positions in tandem, and means operative in response to splashes of ringing cur-

rent transmitted from one of said positions over said connection to a second of said positions for transmitting a supervisory signal of one character to the operator attending said second position and a supervisory signal of different character to the operator attending a third of said positions.

33. In a telephone system, a plurality of operators' positions, means for routing a connection through said positions in tandem, and means operative in response to splashes of ringing current transmitted from one of said positions over said connection to a second of said positions for transmitting an uninterrupted supervisory signal to the operator attending said second position and an intermittent supervisory signal to the operator attending a third of said operators' positions.

34. In combination with first and second trunks, trunk circuit apparatus including a supervisory signal device and a plurality of relays for controlling the energization of said signal device and the application of supervisory pulses to said conductor, said relays being so connected and arranged that the relay directly controlling said signal device operates and locks in response to a first supervisory pulse transmitted to said trunk circuit apparatus over said first trunk and the other relays cooperate to transmit supervisory pulses over said second trunk in response to additional supervisory pulses transmitted over said first trunk.

35. In combination with first and second trunks, trunk circuit apparatus including a supervisory signal device and a plurality of relays for controlling the energization of said signal device and the application of supervisory pulses to said conductor, said relays being so connected and arranged that the relay directly controlling said signal device operates and locks in response to a first splash of ringing current transmitted to said trunk circuit apparatus over said first trunk and the other relays cooperate to transmit supervisory pulses over said second trunk in response to additional splashes of ringing current transmitted over said first trunk to said trunk circuit apparatus.

36. In combination with a first trunk and a second trunk including a supervisory conductor, an operator's position circuit including a supervisory signal device, a connect switch having two operating positions, and a plurality of relays for controlling the energization of said signal device and the application of supervisory pulses to said conductor, said relays being so connected and arranged that the relay directly controlling said signal device operates and locks in response to a first supervisory pulse transmitted to said operator's position circuit over said first trunk and the other relays cooperate to transmit supervisory pulses over said conductor in response to additional supervisory pulses transmitted over said first trunk to said operator's position circuit, and means operative in response to operation of said switch from one of said two operating positions to the other for unlocking the relay directly controlling said signal device.

37. In combination with a first trunk and a second trunk including a supervisory conductor, an operator's position circuit including a supervisory signal device, a connect switch having two operating positions, and a plurality of relays for controlling the energization of said signal device and the application of supervisory pulses to said conductor, said relays being so connected

and arranged that the relay directly controlling said signal device operates and locks in response to a first splash of ringing current transmitted to said operator's position circuit over said first trunk and the other relays cooperate to transmit supervisory pulses over said conductor in response to additional splashes of ringing current transmitted over said first trunk to said operator's position circuit, and means operative in response to operation of said switch from one of said two operating positions to the other for unlocking the relay directly controlling said signal device.

38. In combination with first and second trunks, trunk circuit apparatus including a supervisory signal device and a pair of relays concurrently energized in response to supervisory pulses transmitted to said trunk circuit apparatus over said first trunk, one of said relays being operative to control said signal device, means for locking said one relay in its operated position in response to the energization thereof, a differentially wound supervisory relay including one winding energized in response to operation of said one relay and a second winding energized in response to operation of the other of said pair of relays, whereby said supervisory relay is operated during the spacing intervals between supervisory pulses transmitted over said first trunk, and means controlled by said supervisory relay for transmitting supervisory pulses over said second trunk.

39. In combination with first and second trunks, trunk circuit apparatus including a supervisory signal device and a pair of relays concurrently energized in response to ringing current transmitted to said trunk circuit apparatus over said first trunk, one of said relays being operative to control said signal device, means for locking said one relay in its operated position in response to the energization thereof, a differentially wound supervisory relay including one winding energized in response to operation of said one relay and a second winding energized in response to operation of the other of said pair of relays, whereby said supervisory relay is operated during the spacing intervals between splashes of ringing current transmitted over said first trunk, and means controlled by said supervisory relay for transmitting supervisory pulses over said second trunk.

40. In combination with first and second trunks, an operator's position circuit including a supervisory signal device, a connect switch having two operating positions, and a pair of relays concurrently energized in response to supervisory pulses transmitted to said circuit over said first trunk, one of said relays being operative to control said signal device, means for locking said one relay in its operated position in response to the energization thereof, a differentially wound supervisory relay including one winding energized in response to operation of said one relay and a second winding energized in response to operation of the other of said relays, whereby said supervisory relay is operated during the spacing intervals between supervisory pulses transmitted over said first trunk, means controlled by said supervisory relay for transmitting supervisory pulses over said second trunk, and means operative in response to operation of said switch from one of its two positions to the other for unlocking said one relay.

41. In combination with first and second trunks, an operator's position circuit including a supervisory signal device, a connect switch having

5 two operating positions, and a pair of relays concurrently energized in response to ringing current transmitted to said circuit over said first trunk, one of said relays being operative to control said signal device, means for locking said one relay in its operated position in response to the energization thereof, a differentially wound supervisory relay including one winding energized in response to operation of said one relay and a second winding energized in response to operation of the other of said relays, whereby said supervisory relay is operated during the spacing intervals between splashes of ringing current transmitted over said first trunk, means controlled by said supervisory relay for transmitting supervisory pulses over said second trunk, and means operative in response to operation of said switch from one of its two positions to the other for unlocking said one relay.

15 42. In a telephone system, a trunk, an operator's trunk circuit including a signal device, impulse responsive automatic switching apparatus controllable over said trunk to route a connection from said trunk to said trunk circuit, said trunk circuit including means operative in response to the impulse or impulses of one or more digits transmitted over said trunk after said trunk circuit is seized for controlling said signal device and for otherwise absorbing the impulse or impulses.

25 43. In a telephone system, a trunk, an operator's trunk circuit including a signal device, impulse responsive automatic switching apparatus controllable over said trunk to route a connection from said trunk to said trunk circuit, said trunk circuit including means operative in response to the first impulse of one or more digits transmitted over said trunk after said trunk circuit is seized for energizing said signal device and for otherwise absorbing the digit or digits.

35 44. In a telephone system, a trunk, an operator's trunk circuit including a signal device having two energizing circuits and a control switch operable between two positions, means including impulse responsive automatic switching apparatus controllable over said trunk for routing a connection from said trunk to said trunk circuit, said trunk circuit including means operative in response to one or more impulses transmitted over said trunk after said trunk circuit is seized for completing one or the other of said energizing circuits depending upon the position occupied by said control switch and for otherwise absorbing the impulse or impulses.

45 45. In a telephone system, a trunk, an operator's trunk circuit including a signal device having two energizing circuits and a control switch operable between two positions, means including impulse responsive automatic switching apparatus controllable over said trunk for routing a connection from said trunk to said trunk circuit, said trunk circuit including a relay operative to open both of said energizing circuits in response to the completion of said connection, and means operative in response to one or more impulses transmitted over said connection for causing the release of said relay, thereby to cause the completion of one or the other of said circuits depending upon the position of said control switch, and for otherwise absorbing the impulse or impulses.

55 46. In a telephone system, a trunk, an operator's trunk circuit including a signal device and a control switch operable between two positions,

first and second energizing circuits for said signal device, means including impulse responsive automatic switching apparatus controllable over said trunk for routing a connection from said trunk to said trunk circuit, a relay operative to open both of said energizing circuits in response to the completion of said connection and released to complete said first circuit in response to an impulse transmitted over said trunk following the completion of said connection, and means operative in response to operation of said control switch from one of its positions to the other for interrupting said first circuit, for preparing said second circuit and for causing the reoperation of said relay, said relay being released to complete said second circuit in response to the transmission of another impulse over said trunk.

47. In a telephone system, a trunk, a line, means including a selector and an access circuit connected in tandem in the order named for routing a connection from said trunk to said line, said connection comprising one or more conductors defining a control path extending between said selector and said access circuit, means included in said access circuit and controlled over said path from said selector for controlling the application of ringing voltage to said line, and means included in said selector and controlled over said path from said access circuit for controlling the transmission of supervisory signals over said trunk.

48. In a telephone system, a trunk, a line, means including a selector and an access circuit connected in tandem in the order named for routing a connection from said trunk to said line, said connection comprising a pair of conductors defining a communication channel and a third conductor defining a control path extending between said selector and said access circuit, means included in said access circuit and controlled over said path from said selector for controlling the application of ringing voltage to said line, and means included in said selector and controlled over said path from said access circuit for controlling the transmission of supervisory signals over said trunk.

49. In a telephone system, a trunk, a line, means including a selector and an access circuit connected in tandem in the order named for routing a connection from said trunk to said line, said connection comprising one or more conductors defining a control path extending between said selector and said access circuit, a ringing control relay included in said access circuit and operative to control the application of ringing voltage to said line, an operating circuit for said relay, said operating circuit including said control path, means operative in response to the operation of said selector to seize said access circuit for completing said operating circuit for a limited time interval, and means included in said selector and controlled from said access circuit over said control path for controlling the transmission of supervisory signals over said trunk.

50. In a telephone system, a trunk, a line, means including a selector and an access circuit connected in tandem in the order named for routing a connection from said trunk to said line, said connection comprising one or more conductors defining a control path extending between said selector and said access circuit, a ringing control relay included in said access circuit and operative to control the application of ringing voltage to said line, an operating circuit

for said relay, said operating circuit including said control path, a timing device, means operative in response to the operation of said selector to seize said access circuit for completing said operating circuit and for initiating the operation of said timing device, means controlled by said timing device for opening said operating circuit a predetermined time interval after it is completed, and means included in said selector and controlled from said access circuit over said control path for controlling the transmission of supervisory signals over said trunk.

51. In a telephone system, a trunk, a line, means including a selector and an access circuit connected in tandem in the order named for routing a connection from said trunk to said line, said connection comprising one or more conductors defining a control path extending between said selector and said access circuit, a ringing control relay included in said access circuit and operative to control the application of ringing voltage to said line, an operating circuit for said relay, said operating circuit including said control path, a timing device, means operative in response to the operation of said selector to seize said access circuit for completing said operating circuit and for initiating the operation of said timing device, means controlled by said timing device for opening said operating circuit a predetermined time interval after it is completed and for arresting the operation of said timing device, means controllable over said trunk for recompleting said operating circuit and for reinitiating the operation of said timing device, whereby said operating circuit is held completed for a second predetermined time interval, and means included in said selector and controlled over said path from said access circuit for controlling the transmission of supervisory signals over said trunk.

52. In a telephone system, a trunk, a line, an impulse responsive selector including a line relay operative to direct the selecting operations of said selector in response to impulses transmitted thereto, means including said selector and an access circuit connected in tandem in the order named for routing a connection from said trunk to said line, said connection comprising one or more conductors defining a control path extending between said selector and said access circuit, a ringing control relay included in said access circuit and operative to control the application of ringing voltage to said line, an operating circuit for said control relay, said operating circuit including said control path, a timing device comprising an impulse responsive switch, means operative in response to the operation of said selector to seize said access circuit for completing said operating circuit, for transmitting impulses to said line relay and for connecting said line relay to repeat said impulses to said switch, means controlled by said switch for opening said operating circuit and for terminating the transmission of impulses to said line relay a predetermined time interval after said operating circuit is completed, and means included in said selector and controlled from said access circuit over said control path for controlling the transmission of supervisory signals over said trunk.

53. In a telephone system, a line selecting switch including outlet contacts, movable line contacts and an incoming trunk normally reactively coupled to said line contacts through a voice current repeating element, a plurality of switching units each including an incoming

trunk terminating at the outlet contacts of said switch, certain of said units being arranged for loop circuit control over their incoming trunks and others of said units being arranged for simplex circuit control over their incoming trunks, means for operating said movable line contacts to select one of said units, and means operative only in the event the selected unit is arranged for simplex circuit control for conductively connecting said movable line contacts to the line conductors of the trunk incoming to said line selecting switch.

54. In a telephone system, a line selecting switch including outlet contacts, movable line contacts and an incoming trunk normally reactively coupled to said line contacts through a voice current repeating element, a plurality of switching units each including an incoming trunk, certain of said units being arranged for loop circuit control over their incoming trunks and others of said units being arranged for simplex circuit control over their incoming trunks, the trunks incoming to said units being connected to said outlet contacts and being grouped according to the control circuit arrangement of the units to which they respectively extend, means for operating said movable line contacts to first select a group of trunks and to then select an idle trunk of the selected group, a relay operative conductively to connect said line contacts to the line conductors of the trunk incoming to said switch, an operating circuit for said relay, means operative in response to the selection of said group of trunks for preparing said operating circuit, and means operative in response to the selection of said idle trunk for completing said operating circuit.

55. In a telephone system, a line selecting switch of the vertical and rotary type comprising outlet contacts and movable line wipers adapted to be operated vertically to a position opposite a level of outlet contacts and to then be rotated to engage a particular set of outlet contacts of the selected level, a switching mechanism including control contacts operated into engagement in response to operation of said line wipers to a position opposite a predetermined level of said outlet contacts, a trunk incoming to said switch, said trunk including line conductors normally reactively coupled to said line contacts through a voice current repeating element, a plurality of switching units each including an incoming trunk terminating in said predetermined level of outlet contacts, said switching units being arranged for simplex circuit control over their incoming trunks, a plurality of additional switching units each including an incoming trunk terminating in one of the other levels of said outlet contacts, said additional switching units being arranged for loop circuit control over their incoming trunks, a relay operative conductively to connect said line contacts to the line conductors of the trunk incoming to said switch, an operating circuit for said relay, said operating circuit including said control contacts and being prepared in response to operation of said line wipers to a position opposite said predetermined level of outlet contacts, and means for completing said circuit in response to operation of said line wipers into engagement with a particular set of outlet contacts in said predetermined level.

56. In a telephone system, a selector including control equipment having two settings, an impulse repeater accessible to said selector and

including a digit counting device, automatic switching apparatus including said selector and said repeater for routing a connection from a calling line to a called line of the system in response to a plurality of impulse digits transmitted to said apparatus over the calling line, and means controlled by said digit counting device for causing said control equipment to shift from one of its settings to the other after a predetermined number of impulse digits have been transmitted to said apparatus over the calling line.

57. In a telephone system, a selector including control equipment having two settings, an impulse repeater accessible to said selector and including a digit counting device, automatic switching apparatus including said selector and said repeater for routing a connection from a calling line to a called line of the system in response to a plurality of impulse digits transmitted to said apparatus over the calling line, and means controlled by said digit counting device for controlling said control equipment over the portion of the connection extending between said selector and said repeater to shift said control equipment from one of its settings to the other after a predetermined number of impulse digits have been transmitted to said apparatus over the calling line.

58. In a telephone system, a selector including control equipment having two settings, an impulse repeater accessible to said selector and including a digit counting device, automatic switching apparatus including said selector and said repeater for routing a connection from a calling line to a called line of the system in response to a plurality of impulse digits transmitted to said apparatus over the calling line, said connection comprising a pair of conductors defining a communication channel extending between said selector and said repeater, and means controlled by said digit counting device for controlling said control equipment over at least one of said conductors to shift said control equipment from one of its settings to the other after a predetermined number of impulse digits have been transmitted to said apparatus over the calling line.

59. In a telephone system, a selector of the impulse repeating type including control equipment having an impulse repeating setting and a ringing setting, an impulse repeater accessible to said selector and including a digit counting device, automatic switching apparatus including said selector and said repeater for routing a connection from a calling line to a called line of the system in response to a plurality of impulse digits transmitted to said apparatus over the calling line, and means controlled by said digit counting device for causing said control equipment to shift from its impulse repeating setting to its ringing setting after a predetermined number of digits have been transmitted to said apparatus over the calling line.

60. In a telephone system, a selector of the impulse repeating type including control equipment having an impulse repeating setting, a ringing setting and a call answered setting, an impulse repeater accessible to said selector and including a digit counting device, automatic switching apparatus including said selector and said repeater for routing a connection from a calling line to a called line of the system in response to a plurality of impulse digits transmitted to said apparatus over the calling line, means controlled by said digit counting device for causing said

control equipment to shift from its impulse repeating setting to its ringing setting after a predetermined number of digits have been transmitted to said apparatus over the calling line, and means included in said repeater for causing said control equipment to shift from its ringing setting to its call answered setting in response to a call answering operation performed at a telephone station associated with the called line.

61. In a telephone system, a selector of the impulse repeating type including control equipment having an impulse repeating setting, a ringing setting and a call answered setting, an impulse repeater accessible to said selector and including a digit counting device, automatic switching apparatus including said selector and said repeater for routing a connection from a calling line to a called line of the system in response to a plurality of impulse digits transmitted to said apparatus over the calling line, means controlled by said digit counting device for causing said control equipment to shift from its impulse repeating setting to its ringing setting after a predetermined number of digits have been transmitted to said apparatus over the calling line, means included in said repeater for causing said control equipment to shift from its ringing setting to its call answered setting in response to a call answering operation performed at a telephone station associated with the called line, and means included in said control equipment for transmitting a supervisory signal over the calling line in response to the shifting of said control equipment from its ringing setting to its call answered setting.

62. In a telephone setting, a selector of the impulse repeating type including control equipment having an impulse repeating setting, a ringing setting, a call answered setting and a connection released setting, an impulse repeater accessible to said selector and including a digit counting device, automatic switching apparatus including said selector and said repeater for routing a connection from a calling line to a called line of the system in response to a plurality of impulse digits transmitted to said apparatus over the calling line, means controlled by said digit counting device for causing said control equipment to shift from its impulse repeating setting to its ringing setting after a predetermined number of digits have been transmitted to said apparatus over the calling line, means included in said repeater for causing said control equipment to shift from its ringing setting to its call answered setting in response to a call answering operation performed at a telephone station associated with the called line and to shift from its call answered setting to its connection released setting in response to a connection release operation performed at said telephone station, and means included in said control equipment for transmitting one supervisory signal over the calling line in response to the shifting of said control equipment from its ringing setting to its call answered setting and for transmitting a different supervisory signal over the calling line in response to the shifting of said control equipment from its call answered setting to its connection released setting.

63. In a telephone system, a selector of the impulse repeating type including control equipment having an impulse repeating setting, a ringing setting, a call answered setting and a connection released setting, an impulse repeater

accessible to said selector and including a digit counting device, automatic switching apparatus including said selector and said repeater for routing a connection from a calling line to a called line of the system in response to a plurality of impulse digits transmitted to said apparatus over the calling line, means controlled by said digit counting device for causing said control equipment to shift from its impulse repeating setting to its ringing setting after a predetermined number of digits have been transmitted to said apparatus over the calling line, means included in said repeater for causing said control equipment to shift from its ringing setting to its call answered setting in response to a call answering operation performed at a telephone station associated with the called line and to shift between its call answered and connection released settings in response to call answering and connection release operations performed at said telephone station, and means included in said control equipment for causing a supervisory signal to be transmitted over the calling line each time said control equipment is shifted from one of its call answered and connection released settings to the other.

64. An impulse responsive selector comprising a set of movable contacts including a control contact, means including a line relay for directing the movement of said contacts in response to impulses transmitted to said selector, a timing device including an impulse responsive switch, means operative in response to operation of said selector to seize one of the lines to which it has access for transmitting impulses to said relay, for connecting said line relay to repeat said last-named impulses to said switch and for impressing a predetermined potential upon said control contact, and means controlled by said switch for removing said potential from said control contact and for terminating the transmission of impulses to said relay a predetermined time interval following the operation of said last-named means.

65. An impulse responsive selector comprising a set of movable contacts including a control contact, means including a line relay for directing the movement of said contacts in response to impulses transmitted to said selector, a timing device including an impulse responsive switch, means operative in response to operation of said selector to seize one of the lines to which it has access for transmitting impulses to said relay, for connecting said line relay to repeat said last-named impulses to said switch and for impressing a predetermined potential upon said control contact, means controlled by said switch for removing said potential from said control contact and for terminating the transmission of impulses to said relay a predetermined time interval following the operation of said last-named means, and means operative in response to an impulse transmitted to said selector following the operation of said last-named means for again impressing said potential upon said control contact and for reinitiating the operation of said switch, whereby said potential is impressed upon said control contact for another predetermined time interval.

66. An impulse responsive selector comprising a set of movable contacts including a control contact, means including a line relay for directing the movement of said contacts in response to impulses transmitted to said selector, a timing device including an impulse responsive switch, a local source of impulses, means operative in re-

sponse to operation of said selector to seize one of the lines to which it has access for connecting said line relay to said impulse source, for connecting said line relay to repeat the impulses transmitted thereto from said source to said switch and for impressing a predetermined potential upon said control contact, and means controlled by said switch for removing said potential from said control contact and for disconnecting said relay from said impulse source a predetermined time interval following the operation of said last-named means.

67. In a telephone system, a trunk, a subscriber line, an intercepting operator's position, means including automatic switching apparatus for routing a connection from said trunk to said line, call intercepting apparatus operative to extend said connection to said operator's position, and means for transmitting a signal to said operator's position indicating that the intercepted call is a trunk call.

68. In a telephone system, a trunk, a subscriber line, an intercepting operator's position, means including automatic switching apparatus for routing a connection from said trunk to said line, call intercepting apparatus operative to extend said connection to said operator's position, and means for transmitting a signal over said trunk indicating that the call routed to said line has been intercepted and for transmitting a signal to said operator's position indicating that the intercepted call is a trunk call.

69. In a telephone system, a trunk, a subscriber line, an intercepting operator's position, means including automatic switching apparatus for routing a connection from said trunk to said line, call intercepting apparatus operative to extend said connection to said operator's position, and means operative when said connection is extended to said operator's position for impressing a special signal voltage upon said connection, thereby to indicate to the calling party that the call routed to said line has been intercepted and to indicate to the operator attending said position that the intercepted call is a trunk call.

70. In a telephone system, a trunk, a pair of subscriber lines, an intercepting operator's position, a call intercepting apparatus operative to extend to said operator's position at least a portion of the connections routed to one of said lines, and means including an impulse responsive selector for routing a connection from said trunk to a substation served by the other of said lines or through said call intercepting apparatus to said operator's position, said selector including relay means selectively controlled in accordance with the terminating point of said connection to transmit a supervisory signal over said trunk in response to a call answering operation performed at said substation or to transmit a special signal to said operator's position in response to a call answering operation performed at said operator's position.

71. In a telephone system, a trunk, a pair of subscriber lines, an intercepting operator's position, call intercepting apparatus operative to extend to said operator's position at least a portion of the connections routed to one of said lines, and means including an impulse responsive selector for routing a connection from said trunk to a substation served by the other of said lines or through said call intercepting apparatus to said operator's position, said selector including relay means selectively controlled in accordance with the terminating point of said connection to

transmit supervisory signals over said trunk in response to call answering and connection release operations performed at said substation or to impress a special signal voltage upon the connection in response to a call answering operation performed at said operator's position.

72. In a telephone system, a trunk, a pair of subscriber lines, an intercepting operator's position, call intercepting apparatus operative to extend to said operator's position at least a portion of the connections routed to one of said lines, means including an impulse responsive selector for routing a connection from said trunk to a substation served by the other of said lines or through said call intercepting apparatus to said operator's position, the line resistance of the portion of the connection extending forward from said selector being substantially different depending upon whether said connection extends to said substation or to said operator's position, and means including a marginal relay controlled over said portion of the connection in accordance with the line resistance of said portion of the connection for transmitting a supervisory signal over said trunk in response to a call answering operation performed at said substation or for transmitting a special signal to said operator's position in response to a call answering operation performed at said operator's position.

73. In a telephone system, a trunk, a pair of subscriber lines, an intercepting operator's position, call intercepting apparatus operative to extend to said operator's position at least a portion of the connections routed to one of said lines, means including an impulse responsive selector for routing a connection from said trunk to a substation served by the other of said lines or through said call intercepting apparatus to said operator's position, the line resistance of the portion of the connection extending forward from said selector being substantially different depending upon whether said connection extends to said substation or to said operator's position, and means including a marginal relay controlled over said portion of the connection in accordance with the line resistance of said portion of the connection for transmitting supervisory signals over said trunk in response to call answering and connection release operations performed at said substation or for impressing a special signal voltage upon the connection in response to a call answering operation performed at said operator's position.

74. In a telephone system, a trunk, a pair of subscriber lines, an intercepting operator's position, an impulse responsive selector including a pair of back-bridge relays, means including said selector for routing a connection from said trunk to a substation associated with one of said lines, said relays being jointly controllable over said connection from said substation to transmit supervisory signals over said trunk, means including said selector for routing a second and non-concurrent connection from said trunk to the other of said lines, and call intercepting apparatus operative to extend said second connection to said operator's position, one of said relays being operative to transmit a signal to said operator's position indicating that the intercepted call is a trunk call when the call is answered at said operator's position.

75. In a telephone system, a trunk, a pair of subscriber lines, an intercepting operator's position, an impulse responsive selector including a pair of back-bridge relays, means including said

selector for routing a connection from said trunk to a substation associated with one of said lines, said relays being jointly controllable over said connection from said substation to transmit supervisory signals over said trunk, means including said selector for routing a second and non-concurrent connection from said trunk to the other of said lines, and call intercepting apparatus operative to extend said second connection to said operator's position, one of said relays being operative to impress a special signal voltage upon said second connection when the call thus routed to said operator's position is answered, thereby to indicate to the calling party that the call has been intercepted and to indicate to the operator attending said position that the intercepted call is a trunk call.

76. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a timer, means operative in response to the application of said predetermined potential simultaneously to a plurality of said conductors for initiating the operation of said timer, means controlled by said timer for energizing the signal devices associated with the conductors of said plurality which have said predetermined potential thereon at the expiration of a predetermined time interval measured by said timer, and means individual to said plurality of conductors for preventing the associated signal devices from being energized under the control of said last-named means in the event said predetermined potential is removed from the associated conductors during said predetermined time interval.

77. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a timer, means operative in response to the application of said predetermined potential simultaneously to two or more of said conductors for initiating the operation of said timer and for disassociating the other alarm conductors and their associated signal devices from said timer, means controlled by said timer for energizing the signal devices associated with the conductors of said plurality which have said predetermined potential thereon at the expiration of a predetermined time interval measured by said timer, and means individual to said plurality of conductors for preventing the associated signal devices from being energized under the control of said last-named means in the event said predetermined potential is removed from the associated conductors during said predetermined time interval.

78. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a

5 timer including an element having a normal position and operative away from said normal position to measure increments of time, means operative in response to the application of said predetermined potential simultaneously to a plurality of said conductors for initiating the operation of said timer, means controlled by said timer for energizing the signal devices associated with the conductors of said plurality which have said predetermined potential thereon at the expiration of a predetermined time interval measured by said timer, means individual to said plurality of conductors for preventing the associated signal devices from being energized under the control of said last-named means in the event said predetermined potential is removed from the associated conductors during said predetermined time interval, and means for restoring said timing element to its normal position in the event said predetermined potential is removed from all of said plurality of conductors during said time interval.

20 79. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a timer including an element having a normal position and operative away from said normal position to measure increments of time, means operative in response to the application of said predetermined potential simultaneously to a plurality of said conductors for initiating the operation of said timer and for disassociating the other alarm conductors and their associated signal devices from said timer, means controlled by said timer for energizing the signal devices associated with the conductors of said plurality which have said predetermined potential thereon at the expiration of a predetermined time interval measured by said timer, and means individual to said plurality of conductors for preventing the associated signal devices from being energized under the control of said last-named means in the event said predetermined potential is removed from the associated conductors during said predetermined time interval.

45 80. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a timer including a timing element having a normal position and operative away from said normal position to measure increments of time, means operative in response to the application of said predetermined potential simultaneously to a plurality of said conductors for initiating the operation of said timing element, means controlled by said timer for energizing the signal devices associated with the conductors of said plurality which have said predetermined potential thereon and for arresting the operation of said timing element at the expiration of a predetermined time interval measured by said timing element, means individual to said plurality of conductors for preventing the associated signal devices from being energized under the control of said last-named means in the event said

predetermined potential is removed from the associated conductors during said predetermined time interval, and means for restoring said timing element to its normal position in the event said predetermined potential is removed from all of said plurality of conductors during said predetermined time interval.

81. In a telephone system, alarm signaling equipment comprising a group of alarm conductors individually corresponding to different groups of switching units and each adapted to have a predetermined potential applied thereto when a switching unit of the associated group occupies a predetermined setting, signal devices individually corresponding to said conductors, a timer including a timing element having a normal position and operative away from said normal position to measure increments of time, means operative in response to the application of said predetermined potential simultaneously to a plurality of said conductors for initiating the operation of said timing element and for disassociating the other alarm conductors and their associated signal devices from said timer, means controlled by said timer for energizing the signal devices associated with the conductors of said plurality which have said predetermined potential thereon and for arresting the operation of said timing element at the expiration of a predetermined time interval measured by said timing element, means individual to said plurality of conductors for preventing the associated signal devices from being energized under the control of said last-named means in the event said predetermined potential is removed from the associated conductors during said predetermined time interval, and means for restoring said timing element to its normal position in the event said predetermined potential is removed from all of said plurality of conductors during said predetermined time interval.

82. In a telephone system, an incoming line, outgoing lines, means including a selector switch for connecting said incoming line to any one of said outgoing lines, a simplex circuit including the talking conductors of said selector,

5 a relay associated with said incoming line and operative in response to the unbalancing of said simplex circuit, signal receiving means for repeating signals from the incoming line over said simplex circuit, and signaling means associated with said outgoing line for unbalancing said simplex circuit to cause the operation of said relay.

10 83. In a telephone system, an incoming line, signal receiving means associated with said line, a selector comprising talking conductors, a control conductor and a fourth conductor, groups of outgoing lines accessible to said selector, a simplex circuit including said talking conductors for repeating directive signals received by said signal receiving means to said selector, means in said selector responsive to said signals for selecting the desired group of outgoing lines and for selecting an idle line in the selected 15 group, a network connected in the incoming end of said incoming line, circuit means including a relay operative in response to an unbalanced condition of said simplex circuit for controlling said network to determine the signal current transmission level over said incoming line, and circuit means including said fourth conductor for transmitting supervisory signals from said selected line to said incoming line.

20 84. In a telephone system, an incoming line, 30 a network connected in the incoming end of said line, an outgoing line, a selector including a pair of talking conductors and a non-talking conductor, means including said selector for establishing a connection between said lines, 35 means including a circuit comprising said talking conductors in parallel for controlling said network, means including a circuit comprising said talking conductors in parallel for repeating supervisory signals transmitted over said incoming line to said outgoing line, and means including a circuit comprising said non-talking conductor for repeating supervisory signals transmitted over said outgoing line to said incoming line.
